20 Claims. (Cl. 235—61.9)

This invention relates to printing and adding machines for producing individual records or the like having data printed thereon including itemized accounting data in the form of numerical amounts.

Records such as business instruments, bills, statements or the like printed with accounting data can be produced in printing and adding machines of the kind described in Patent Nos. 2,501,444 and 2,568,064, these machines operating under control of individual printing and control devices of a well-known kind which bear representations of the data to be printed on the business instruments, such representations being in the form of imprinting embossures on a printing plate of such a device and punched hole data carried on the device usually in association with a printing plate.

A machine of the aforesaid kind embodies what amounts to a primary printing unit for printing from such embossures, and auxiliary printing means in an adding unit for printing numerical amounts, these units of the machine being operatively associated and interrelated. At the primary printing unit, a printing station is afforded whereat a printing and control device of the aforesaid character having a printing plate thereon can be associated with a sheet to be printed from embossures on the printing plate. The printing means of the adding unit are in the form of settable type segments that cooperate with a platen to imprint a sheet disposed between the platen and the type segments. In a cycle of the machine, a printing and control device is advanced from a supply station in the machine to a primary sensing station. At this sensing station, control and numerical data in the form of punched openings or the like formed in the printing and control device are sensed. The printing and control devices are adapted also to bear tabs selectively located in identifying or indicating positions, and incidental to the aforesaid sensing operation, conditions are established in the machine under control of such tabs which determine whether or not a particular printing and control device is to be used at the primary printing station to imprint a sheet from the aforementioned printing plate, and at the same time conditions are established whereby the numerical data in the form of punched openings or like coded indicia on the device are transmitted to data receiving means in the adding unit which are adapted to control the setting of the numerical representing type segments for printing numerical amounts on a proof sheet or the like. The amounts thus transmitted to the adding unit are adapted also to be entered and stored in registers so that totals or sub-totals can be taken and printed.

There are many instances where it would be advantageous to prepare in a machine of the foregoing kind records relating to individual accounts containing itemized or segregated accounting entries broken down into different categories, and at the same time to totalize on the same sheet related of the itemized entries. A particular instance of this kind can easily be explained in

2

connection with the preparation of real estate tax bills, mailed or otherwise allocated to individual taxpayers. In this instance, it will be appreciated that the tax bill mailed, or for that matter any record of the tax, needs to be imprinted with taxpayer and property identifications together with property valuations and the individual tax items that may be involved, and additionally the total tax due and payable. Thus, for example, a tax bill for a current year, or as is commonly the case for the half year, customarily sets forth the name and address of the taxpayer, a description of the property against which a tax has been levied, the taxable valuation of the property, the current year or half year tax based on the property valuation, delinquent taxes if any, special tax assessments if any, and finally a total of the current tax, delinquent tax and special tax assessment due and payable.

From the foregoing it will be seen that in addition to setting forth the taxpayer's name, address, property description and property valuations on the bill, it is desirable that the separate tax amounts and the total tax due and payable be itemized as a clear and definite record for each taxpayer. Preparation of a tax record of this kind entails a proper orientation of the data involved, that is, the bill forms are usually pre-printed with column headings, descriptive legends and line rulings under which the several kinds of data are to be printed.

Printing and control devices of the kind described above afford a convenient way of accomplishing detailed accounting procedures represented by the foregoing example. Thus, resorting again to the preparation of a tax bill as an example of detailed accounting, it will be realized that in the majority of cases a particular taxpayer continues for prolonged periods to occupy a designated parcel of land, and hence printing and control devices of the foregoing kind enable a permanent file to be established so far as the name and address of the taxpayer are concerned, the property description, lot number or the like, and usually the assessed valuation of the freehold that is subject to taxation and the assessed valuation of fixture improvements thereon. In other words, so far as taxpayer identity, property description and assessed tax valuations are concerned, these represent relatively fixed or permanent conditions, and hence data of this kind in the form of embossures on printing plates and punched hole representations provided on printing and control devices of the foregoing kind can be used repeatedly for printing tax bills or tax records with data of this relatively permanent nature.

Assessed property valuations are not as a rule often changed, but what may be changed from one year to the next is the tax rate, and of course special assessment or delinquent taxes may vary considerably from year to year. Even so, printing and control devices of the aforesaid character can be conveniently used to handle changeable or variable tax computation aspects in spite of that fact that these may not be valid from one year to the next. Thus, it is a relatively simple matter to punch or otherwise provide in the control and numerical data representing area of devices of the aforesaid kind numerical data representing the value of special tax assessments for a particular taxing period, delinquent taxes due from a previous year, and the current tax which is affected by the established or current period tax rate.

Therefore, by establishing for each taxpayer a printing and control device bearing the relatively permanent or unchangeable data thereon in the form of embossures on a printing plate and coded numerical data in the control area thereof, and associating with this device a set of related devices pertaining solely to the computation or accounting of changeable or variable tax amounts, a convenient association of printing and control devices is established referred to herein as a "deck" representing

all of the data required to prepare a tax bill for a particular taxpayer in a machine of the foregoing kind. In other words, by bringing into association a printing and control device devoted mainly to permanent data such as taxpayer identity, property description and taxable valuations, and other devices of a specialized nature devoted mainly to variable tax amounts, such group or deck of devices represents a complete file of data pertaining to a particular taxpayer for a particular tax year.

Printing and adding machines of the kind exemplified by the above patents are, in a primary sense, well adapted to handle a taxpayer data reproducing file or deck made up in the foregoing manner, which is to say that machines of this kind are adapted to print a form sheet such as a tax bill with an address and like relatively permanent data from corresponding embossures of a printing plate, and are also adapted to perform adding and listing operations which of course are involved in the preparation of a tax bill in respect of expressly set forth tax amounts.

In preparing a tax bill for an individual taxpayer in accordance with the present invention, printing and control devices of different orders are required to complete a deck, namely, computing devices which bear the numerical accounting data pertaining to the current tax amount, special tax assessment and delinquent tax devices allocated especially to the representation of these respective tax amounts where involved, and finally what will be termed a parcel device carrying relatively unchangeable auxiliary data pertaining strictly to taxpayer and property identification and property valuations. As will be described in more detail below, only the parcel device of such a deck carries a printing plate provided with embossed type characters representative of permanent data, and printing plates are not used in connection with the other three categories of printing and control devices.

To prepare the bill, two runs on the individual bill forms are required, the first such run being one wherein in the bill forms are advanced one by one through the printing station of the primary printing unit, and the second such run being one wherein the bill forms are advanced through the printing station of the adding unit. During the first of these runs, each bill form is printed from and under control of a related parcel device only, which bears a printing plate for printing the bill form with the name and address of the taxpayer and related fixed or unchangeable data to appear on the bill, and it is advantageous at the same time to be able to print at the adding unit a proof sheet with numerical data represented by punched openings in the control area of each parcel device. During this same run, no computing plates bearing the tax accounting data pertaining strictly to current tax amounts are associated with the related parcel devices. However, the devices bearing accounting data pertaining to special tax assessments and delinquent devices are present, and it is therefore necessary to hold the bill forms stationary during those times when a special assessment or delinquent device has been fed to the printing station of the primary printing unit. In this way, the several bill forms separably attached one to the other in a fan-fold or the like will be successively printed from the embossed type characters carried by the parcel devices. Inasmuch as special assessment and delinquent devices are present in each taxpayer deck of printing and control devices during the first run on the bill, these devices will be sensed at the sensing station much in the same manner as the parcel devices are sensed, and it is therefore advantageous to interrupt operation of the adding unit of the machine in connection with the occurrence of special assessment and delinquent devices at the primary sensing station during the first run on the tax bill. As a consequence of this, only the punched hole data on the parcel devices are

acted upon or utilized for proof sheet printing at the adding unit.

For the second run on the tax bill under the present invention, the tax bill forms and the feed means therefore are transferred from the primary printing unit to the adding unit so that there can be entered on each tax bill form in an itemized manner the several tax amounts involved and finally the total tax which is the total of current tax, delinquent tax and any special tax assessment. This requires accurate and predetermined control spacing of the tax bill forms during the second run insofar as areas of the bill allocated to the different tax items are concerned. Moreover, as will be described, a special area of the tax bill form in each instance is allocated to the printing of the total tax amount due and payable. This total tax may, in fact, be the same as the current tax, assuming no delinquent or special tax assessment to be involved on the part of a particular taxpayer, and one of the primary objects of the present invention is to enable the tax bill during the second run at the adding unit to be spaced variable amounts depending upon the number of orders of tax amounts involved for a particular bill. A related object is to enable a new bill form to be spaced forward at the adding unit during the second run after a total tax has been printed on a previous bill, thus completing preparation of such previous bill.

It will be seen from the foregoing that the machine of the present invention basically operates under two different control conditions, and another object of the present invention is to so equip the machine from a control standpoint that the machine will operate in respectively different ways for the respective runs on the tax bill.

During the second run of the tax bill form at the adding unit, the machine operates first on the computing devices which are assigned fractional amounts of the current tax. This particular fractional breakdown of the current tax amount for each taxpayer will be described in greater detail hereinbelow, but at this point it may be mentioned briefly that the total current tax is computed, and then is broken down into fractions of the total and these fractions are carried by as many computing devices as there are fractions of a particular current tax. In other words, a plurality of computing devices will be required in most instances to represent the total current tax for each taxpayer. Therefore, as the computing devices are passed from the supply magazine of the machine to the primary sensing station during the second run, the sensed fractional tax amounts are transmitted to the adding unit and are added without being printed on the tax bill.

When, however, the related parcel device arrives at the primary sensing station next subsequent to the last computing device pertaining thereto, the adding unit is conditioned to print on the related tax bill the current tax amount thus accumulated previously from the computing devices, and another object of the present invention is to enable this sequence of suppression of printing and then activation of printing at the adding unit to be accomplished by so arranging the adding unit that fractional tax items are stored in an adding unit register until a parcel device calls for the amount thus stored to be printed on the bill as the current tax.

Inasmuch as the total tax may comprise not only the current tax and special assessment and delinquent amounts, another object of the invention is to restore to the adding unit the current tax amount that was taken from the register assigned thereto and printed on the bill, so that the current tax after being printed will be restored to the adding unit to enable any delinquent or special tax assessment amount to be added thereto as aspects of the total tax to be printed on the bill. A related object of the present invention is to space the tax bill subsequent to the printing of a current tax so that

any delinquent tax or special tax assessment will be printed on the bill at the proper place.

Detailed accounting of this specialized nature wherein amounts of different orders are involved, as for instance orders that are to add up to the total tax and orders that are not to include current tax, need to be segregated for record purposes, and another object of the present invention is to so control and assign an accumulator register of the adding unit as to separately accumulate each special assessment and delinquent tax amount billed out, so that after all the bills have been printed a grand total of special assessment and delinquent tax for the entire billing can be taken out of this register, and a related object of the present invention is to so control and assign still another accumulator register of the adding unit that as each tax total in that register is printed on the bill the total is transferred to still a third register allocated solely to a grand total of total taxes billed.

Considered in the light of the foregoing, objects of the invention, broadly, are to enable a bill, record or the like to be printed at one unit of a printing and adding machine with data of a fixed kind, and to be printed at another unit of the machine with accounting or changeable data; to enable data accumulating registers in an adding machine to be controlled automatically so that accounting data of different orders are segregated for sub-total and total operations; to suppress printing of numerical accounting amounts in an adding machine under pre-determined conditions, so that these amounts are accumulated in the machine until such time as a sub-total or total thereof is to be taken and printed; and to subject a bill or like accounting form to variable spacing control so that accounting items are properly entered thereon at designated areas.

Other and further objects of the present invention will be apparent from the following description and claims and are illustrated in the accompanying drawings which, by way of illustration, show a preferred embodiment of the present invention and the principles thereof and what we now consider to be the best mode in which we have contemplated applying these principles. Other embodiments of the invention embodying the same or equivalent principles may be used and structural changes may be made as desired by those skilled in the art without departing from the present invention and the purview of the appended claims.

GENERAL DESCRIPTION OF THE MACHINE

A printing and adding machine of the kind representative of that involved under the present invention is illustrated in Fig. 1 of the drawings as comprising a printing machine unit 100 and an adding machine unit AU. This particular designation of a printing machine unit and an adding machine unit is merely one of convenience for purposes of the present disclosure, since printing is involved in both units. A printing and adding machine of this kind is adapted to operate from and under control

of printing and control devices D, Fig. 1, which are adapted to be stacked in a supply magazine SM supported upright at the rear of the machine. Printing and control devices of this kind are more particularly exemplified by the printing and control device PD shown in Fig. 9 of the drawings which includes a printing plate PP having embossed type characters ED and ET thereon as well as a control card CC provided with punched hole data, the designation D being presently used as a general classification, since other kinds of printing and control devices of a specialized nature are also involved as shown in Fig. 9, and such other devices as shown in Fig. 9 have no printing plate PP associated therewith.

Printing and control devices of this kind are well known in the art and include a relatively rigid rectangular frame on which may be mounted in one general area one or more printing plates, and which has another area in which both control and numerical coded data may be provided. Such coded data are conveniently in the form of accurately related and oriented punched openings adapted to be sensed or read by sensing pins to correspondingly control operations of the machine or establish numerical representing conditions in the adding unit AU as will be described in more detail hereinbelow. Each frame of a printing and control device is also adapted to carry control tabs as CT, Fig. 9, which will be explained in more detail below.

The printing machine unit 100 is of the general kind disclosed in Patent No. 2,359,849 and thus embodies a platen supporting arm 102 which serves as a mounting head for platen structure 103 normally disposed in a retracted position at a printing station PRS. When the machine is in operation, a printing and control device as D will be positioned at the printing station PRS, and any embossed printing plate carried by such a device D has the embossed type characters thereon facing upwardly at the printing station PRS.

Sheet feeding means as will be described are adapted to be associated with the printing machine unit 100 so as to dispose a sheet to be printed on the table T of the machine in association with a printing and control device D having a printing plate disposed at the printing station PRS, and an inked ribbon or the like is afforded at the printing station PRS between the embossed type characters on the printing plate and the sheet to be printed thereby. When a print is to be made, the platen 103 is actuated first forwardly through an idle stroke and then is retracted rearwardly in such a way as to bring about printing engagement between the embossures on the printing plate, the inked ribbon and the sheet to be printed as described in Patent No. 2,359,849.

The printing and adding machine shown in Fig. 1 operates under control of a selector which conditions the platen 103 either for what is known as a "print" or "skip" operation, which is to say that the circumstances may be that not all the devices D arranged in the supply magazine SM are to be used for printing but rather some are to be ineffective to print a sheet at the printing station. Accordingly, a sensing station generally indicated at SS in Fig. 1 is arranged forwardly of the magazine SM, and in each cycle of the printing machine unit 100 a printing and control device D is advanced from the bottom of the supply magazine SM to the sensing station SS. It is at the sensing station SS where means are effective to establish the essential setting of the selector, such selection being accomplished primarily as a result of positioning of control tabs on the frames of the printing and control devices, such as the tabs CT shown on certain of the printing and control devices of Fig. 9.

Many of the operational aspects of the adding unit AU of the present machine are described in Patent No. 2,501,444, and Patent No. 2,568,064 describes in detail the general way in which the printing machine unit 100 and the adding unit AU are operatively associated. Thus, while a printing and control device is undergoing

sensing and selection at the sensing station SS, the numerical and control data in the form of punched openings associated therewith are sensed at the same time, and these data are transmitted from the sensing station SS to related data receiving columns in the adding unit AU. Means are then effective to set the adding unit AU in operation through a cycle in those instances where data are thus transmitted to the adding unit. The general way in which sensing and selection is accomplished at the station SS will be described below in connection with Figs. 3 to 5 of the drawings.

The work sheet that is printed under the present circumstances is a tax bill fan-fold BFF, Figs. 2 and 8, and in Fig. 2 the associated sheet feeding attachment is illustrated. Thus, the bill form sheet or fan-fold is stacked at 110 on a support 111 above the printing station PRS and is fed by a feed shaft 113, a gear drive for the shaft 113 being housed in a housing 114 at one side of the machine. The fan-fold is played over a guide 115 above the forward edge of the printing machine unit 100, beneath a lower guide 116, and from the guide 116 beneath the platen structure 103 at the printing station PRS, the printed individual bills travelling from the station PRS to the feed means 113 and then downward on to a stacker platform 117 at the rear of the machine.

A sheet feeder of this kind is also adapted to be arranged at the adding unit AU to feed the bill fan-fold through the printing station of the adding unit AU as will be described. In each instance, however, the feed shaft as 113 is subjected to a variable control, because there are circumstances, particularly at the adding unit AU, where a particular bill to be printed may require three different length spacings. It may be mentioned that in Patent No. 2,700,334 one kind of variable drive for the feed shaft 113 is described. Essential aspects of the variable drive shown in Patent No. 2,700,334 are utilized in the present instance, but it should be pointed out, however, that a separate drive motor is used for shaft 113 in the present instance, and this motor is timed as will be described, for the required length of sheet feed.

The primary control over the machine emanates from the sensing station SS, and for a full description of the operating structure at this station reference should be had to Patent No. 2,568,064. What is necessary for explanation here is shown in Figs. 3 to 7, and referring to Fig. 3, which illustrates the sensing station with its cover removed, it will be observed that a guideway is defined by spaced-apart supporting rails 118 and 119. These rails are beneath the table T of the machine and extend from the bottom of the supply magazine SM forwardly to and through the sensing station SS. Carrier bars 120 are arranged to reciprocate in unison inwardly of the rails 118 and 119, and these carrier bars serve to advance the printing and control devices from the supply magazine to and through the sensing station SS, the relation being such that the devices D are disposed horizontally between the carrier bars 120 with the area thereof allocated to the mounting of printing plates representing the leading portion and the area allocated to the formation of control or numerical punched openings representing the trailing end portion. Each such printing device is arrested temporarily at the printing station PRS in each cycle of the machine, that is, in one cycle of operation of the machine unit 100 a device D is transferred from the supply station SM to the sensing station SS and undergoes sensing in the same cycle. After the sensing operation has been performed the device is advanced in the next cycle of operation of unit 100 forwardly out of the sensing station. Through successive cycles, the printing and control device that was sensed eventually reaches the printing station PRS, and a platen operating clutch 156, Fig. 7, may then be effective to actuate the platen 103 as will be explained.

While arrested at the sensing station, each printing and control device undergoes a sensing operation, and such

operation is attained by lowering a sensing head SH, Figs. 3, 4 and 5, which is provided with sensing pins 220 allocated to the control and numerical punched openings as PO, Fig. 9, adapted to be formed in columns on the control cards CC of the printing and control devices. Each such column on a control card is assigned five possible positions in which a punched opening may be provided. Accordingly, as will be observed in Fig. 5, the sensing pins 220 are arranged column-wise in mounting plates associated with the sensing head SH, and five such sensing pins are afforded in each column. A printing and control device D is illustrated in Fig. 5 in position at the sensing station SS to be sensed, and in this particular instance a sensing pin 220-1 encountered a punched opening in a control card CC, and passed through such opening to actuate a plunger associated with a related Bowden wire 225 sheathed in a cable 226, and as will be described below the Bowden wires 225 represent transmitting means for transmitting data sensed at the sensing station SS to corresponding data receiving columns in the adding unit AU.

Other sensing pins as 240 are associated with the sensing head SH, and these sensing pins are arranged in a mounting bar in position to detect selectively positionable control means adapted to be carried by the printing and control devices in the form of control tabs such as the tabs CT shown in Fig. 9 projecting from the upper edges of certain of the printing and control device frames F. Such control tabs while shown in one form in Fig. 9, that is either full or notched, are provided in many different forms, but in any event when a sensing pin as 240 encounters a solid portion of a control tab of this kind on a printing and control device, a rocker 245, Fig. 5, pivotally mounted on the sensing head SH is rocked counterclockwise as viewed in this figure, and such motion is transmitted to an arm 246, Figs. 3 and 4. A link 250 is connected to the arm 246, and the link 250 in turn actuates the setting mechanism of a rotary selector switch E40 which will be described in detail hereinbelow. Such switch setting mechanism includes a latch pawl 250' co-operating with a ratchet 251, and the position of the ratchet in turn determines the position of the rotary switch blades embodied in the switch E40. The pins 240 are furnished in different sizes, as for example, "regular" and "reversing." Thus, the size of a pin 240 located in position on the sensing head SH to contact a relatedly positioned control tab as CT, Fig. 9, on the frame of a printing and control device determines the extent of rotary setting movement in switch E40. In the event no control tab is encountered by a pin 240, the arm 246 is not actuated and the selector switch E40 remains in its restored or at-rest position.

To assure that a printing and control device is accurately positioned at the sensing station SS so that the desired sensing operation can be properly performed, a so-called V-notch pawl 255 is arranged at one side of the sensing station. This pawl has a V-shaped projection thereon, as described in Patent No. 2,568,064, adapted to engage a complementary recess in the adjacent side edge of the frame of a printing and control device at the sensing station SS as will be apparent in connection with the device PD, Fig. 9, and such engagement upon inward movement of the pawl 255 produces proper alignment of the printing and control device in the event that there is misalignment. A switch E36, Fig. 3, is closed when the pawl 255 is properly in its printing and control device aligning position. This switch, as well as a carrier bar safety switch E53, Fig. 3, play important roles in establishing conditions making possible completion of certain electrical circuits as will be described. Thus, the carrier bar safety switch E53 is closed when the carrier bars 120 are in their forward positions, having passed a printing and control device from the supply station to the sensing.

Another switch is afforded at the sensing station, namely, a switch E230, Fig. 3, forward of the sensing

head SH. This switch is adapted to be closed by a rocker arm 268, Figs. 3 and 5 pivotally mounted at 270 in the sensing head SH. As shown in Fig. 5, this rocker arm has a rearward extension 271 adapted to overlie the upper end of a long or special purpose sensing pin as 240 disposed in position to engage a No. 1 control tab as CT, Fig. 9, at the number one tab position on the frame of a particular printing and control device as will be described.

It was mentioned that during the course of a sensing operation, conditions are established through the selector switch E40, Fig. 4, which determine whether or not the platen 103 is to be operated. It was also mentioned that storage of this sensing result must be afforded, since several cycles are required for the printing and control device that was sensed to reach the printing station PRS. To this end, a platen delay solenoid E30, Fig. 6, is arranged in the machine unit 100 beneath the sensing station SS. Another solenoid E90 is afforded adjacent the solenoid E30, and the solenoid E90 is associated with a bell sounding system to indicate to the operator when certain classes of printing and control devices are at the printing station PRS. This class may consist entirely of devices to be "skipped" through the printing station, and operation of the bell solenoid E90 is fully explained in Patent No. 2,568,064.

Solenoids E30 and E90 include armatures 329 and 330, and when either solenoid is energized as a result of sensing, the corresponding armature actuates a related 30 striker arm 339 or 340 as described in Patent No. 2,568,064. Storage drums 341 and 342 are associated with the striker arms 339 and 340, and these drums are provided with storage pins as 345. When a solenoid E30 or E90 is energized to actuate its striker arm, the striker arm in turn sets one of the pins 345 in a stored position. If the printing and control device sensed is one that is to be used for printing, solenoid E30 is energized, and the setting of the storage pin 345 on the related storage drum 341 stores this information so that the platen 103 will be actuated at the proper time. Thus, as shown in Fig. 7, an actuated or stored pin 345 on the storage drum 341 is eventually effective to engage an arm 346 allowing the platen clutch 156 to engage.

In a cycle where a printing and control device is sensed, the punched hole data that may be present on the device are transmitted by Bowden wires 225, Fig. 5, to data receiving means afforded in columns of the adding unit AU, Fig. 10, and the terminal ends of the cables 225 are shown at 100A in Fig. 10. Slides 120A of the adding unit are adapted to be set up to the digital amounts represented by the cables 100A, and a timing switch operated by the machine unit 100 is adapted under predetermined conditions to allow a clutch for the adding unit to engage to set the main cam shaft 140A, 55 Fig. 10, of the adding unit AU in operation. As will be described in more detail below, printing segments 110A, Fig. 10, are adapted to be set up simultaneously with the slides 120A, and under such circumstances printing may be effected on a proof sheet at the adding 60 unit, as will be described for the first run on a tax bill, and on the second run of the tax bill amounts are entered on the tax bills as shown on the bill B1 in Fig. 8. In the latter portion of the cycle of the adding unit, the slides 120A are restored, and amounts may be entered into some of the registers AC1, AC2 and AC3 of the adding unit, Fig. 10.

In connection with proof sheet printing, the machine is illustrated in Fig. 1 as adapted for this operation. Thus, a roll of paper 400 is provided at the adding unit, and 70 is adapted to be fed between the type segments 110A, Fig. 10, and an associated platen 114A as will be explained.

The printing machine unit 100 includes a drive motor 75 DM, Fig. 7A, adapted to be energized in a manner to

11

be described below, and this motor serves to drive a pulley 448 connected by gearing 448G, Fig. 7B, to a universal joint 448U adapted to drive a shaft 448S, the shaft 448S being connected to the main drive gear "245" so identified in the adding unit as described in Patent No. 2,501,444.

Pulley 448 drives a chain 449 which in turn drives a sprocket 450 mounted loosely on the main drive shaft 451 of the machine unit 100. A master clutch 455, Fig. 7C, is adapted when engaged to transmit motion from sprocket 450 to the main drive shaft 451 as described in Patent No. 2,568,064, and when shaft 451 is driven the platen clutch 156, Fig. 7, when engaged picks up the motion of shaft 451 to operate the platen structure 103. The master clutch 455 is controlled by a solenoid E8 as will be explained below, and this solenoid when energized releases a control arm 470 for the clutch 455 thereupon enabling the master clutch to engage, and at the same time a switch E15 is closed for establishing a holding circuit to solenoid E8 as will be described.

The foregoing describes generally the operations entailed at units 100 and AU of the printing and adding machine of the present invention, and there will be described hereinbelow detailed aspects of the preparation of tax bills or like accounting forms, the details of the adding unit AU, and finally the way in which over-all operation of the machine in respect of units 100 and AU is controlled.

THE ADDING UNIT

Introduction to tax billing

In many instances, it is common practice in preparing tax bills to list separately on the bill the various items comprising the tax, and such items may include a current tax assessment, any tax delinquency, and any special assessment tax that may have been invoked for the current tax year. Additionally, the tax bill usually carries an identification of the lot or sub-division that is being taxed, its valuation, the valuation of any realty improvements on the freehold such as buildings or the like, and a total valuation of land and improvements.

In Fig. 8 there are illustrated two typical tax bills B1 and B2, and in this particular instance the bills are shown as a fragment of the bill fan-fold BFF mentioned above wherein the several bill blanks are separably attached to one another along tear lines TL. Of the bills B1 and B2, the bill B1 has had its tax accounting items as set forth above printed thereon, whereas the bill B2 has not as yet been printed with its tax items. Each bill was previously printed in the printing machine unit 100 with the address AD of the person being taxed. Additionally, each bill was previously printed with other tax data TD such as the section, block number, lot size, and acreage, and in this connection it may be pointed out that the tax bill fan-fold as originally furnished for use in the machine has been pre-printed or blocked off with the grid divisions and various headings such as "Lot No.," "Pay This Amount," and so on appearing on the bills B1 and B2 under which the lot number, assessments, valuations, and data as TD are to be listed.

Thus, as shown particularly in connection with the bill B1 for John and Mary Doe the address AD of these joint taxpayers was printed in a previous first run of the bill fan-fold together with the land section designation "73," the block number "5540," the lot size "40 x 120," the acreage ".11" together with the additional land designation "PTS Elm Grove-Wooded." During subsequent processing of the bill B1 during a second run through the machine as will be described in detail below, the lot number "465" is printed in three instances, the land valuation "1680" and building valuation "2760" are entered under their separate headings, the total valuation and current valuation ("4440" in each instance) are entered, and also the current first half tax "62.16" 75

12

(sixty-two dollars, sixteen cents). All valuations and tax amounts are, of course, in dollars and cents.

It so happens that the taxpayers of bill B1 had a special assessment of forty-four dollars for paving, and in this connection it will be noted that the bill B1 as furnished carries a special assessment legend wherein paving is identified as item "1," and it is for this reason that the forty-four dollar amount under the special assessment heading has the digit "1" printed in a column assigned thereto to the left of the forty-four dollar paving assessment.

The taxpayers of bill B1 were delinquent in the amount of twenty-three dollars and sixteen cents. This amount has also been entered under the column "Amount Due," 15 and it will be noted that additionally the special assessment item of forty-four dollars has also been printed in the amount due column. The separate items under the amount due column are totaled as "129.32."

In delineating the lot number, momentary amounts, and legend "1" thus described in connection with bill B1, this is accomplished under control of individual printing and control devices that are passed through the machine, and these devices as were mentioned are adapted to carry in code form the lot number, monetary amounts, and 20 certain legends as "1" that are to be printed on the bill under the separate headings described above.

The present method of billing is one wherein the total taxable valuation of four thousand, four hundred and forty dollars (4,440) is first broken down into fractions 25 of the total, and the current tax on these fractions is computed separately and entered in the form of punched openings into control devices to be described below. As the computing devices pass through the machine, the fractional tax amounts that have been representatively punched therein are added, and when the total amount of current tax has been accumulated by the adding unit AU of the machine for a particular taxpayer this amount is then printed on the bill as a sub-total "S." Thus, the current tax amount of sixty-two dollars and sixteen cents appearing on bill B1 is the result of accumulation of fractions thereof as will be described.

Likewise, in those instances where special tax assessments or delinquencies occur, these amounts are carried by other control devices so as to be printed on the bill 45 subsequent to, that is, below the current tax item on the bill. Also, each special assessment and delinquent control device preferably carries the lot number so that this can be entered on the bill opposite the special assessment amount or delinquent tax amount as shown on the bill 50 B1, and also any legend that may be required to identify the category of any special assessment.

Thus, it will be seen that in preparing each bill, control devices of an accounting or computing nature are required and, additionally, control devices for special assessments 55 and delinquencies, but only in those instances where these latter two occur. In addition to these two categories of control devices, a third kind of device is used, namely, a parcel printing and control device. The parcel control device bears data of the punched hole kind for the lot number, the land valuation, the building valuation and the total valuation, and the appearance of the parcel device governs and controls certain aspects of bill printing as will be described below. The entire group of control devices for a particular taxpayer will be referred to herein 60 as a "deck," which is to say that there is a separate deck of control devices for each bill that is prepared.

Thus, as shown in Fig. 9 the deck of control devices for preparing bill B1 comprises six individual control devices, and the path of these through the machine is indicated by the arrow. The leading control devices consist in this instance of three computing devices CD1, CD2 and CD3, which are shown fragmentally. These devices in effect are modifications of the next member in the deck, namely, the parcel device PD, and hence the parcel device PD will first be described in detail.

The parcel device PD represents a well known kind of printing and control device which in addition to certain embossed data thereon is also provided with definite fields of punched openings as will be described. Devices of this kind are exemplified by those shown in U.S. Patent Nos. 2,132,412 and 2,568,064. Thus, the parcel device PD comprises a frame F of light weight metal, and removably mounted on the frame F are two printing plates PT each bearing embossed data in the form of type characters that were used previously to print the address AD and the related property data TD appearing separately in the lower portion of the bill B1. The upper of the two printing plates PT carries embossed printing characters ED for printing the address AD on the bill B1, and the lower of the two printing plates PT carries embossed printing characters ET that were used to print the supplementary or related property data TD on the bill B1. These embossed data are in mirror form, that is, reverse reading as will be observed in Fig. 9, and this is so because in printing the data AD and TD in the printing machine unit 100 the printing plates PT are disposed beneath the bill B1 and print the bill B1 through a ribbon interposed between the plates PT and the bill B1 as is well known.

Positioned above the two printing plates on the frame F is a removably mounted control card CC, and the card CC in the present instance bears predetermined control and reproducible data in the form of punched openings as PO, in four separate fields in this instance. The first such field F1 is allocated to lot number, the second such field F2 is allocated to land valuation, the third such field F3 is allocated to building valuation, and the fourth such field F4 is allocated to total valuation, that is, the total of land plus building valuation. The monetary data thus carried by the card CC are coded by the punched openings PO, and the particular code that has been used in this connection is illustrated in Fig. 9A. Comparing the various fields bearing punched data PO to the code of Fig. 9A, it will be observed that the lot number to which the parcel device PD pertains is "465," the land valuation is "1680," the building valuation "2760," and the total valuation is "4440" these amounts being dollars values. The data thus punched in the card CC, it will be observed, appear on the bill B1, and the way in which printing of the bill B1 is accomplished to this extent from and under control of the card CC thereon will be described in more detail hereinbelow.

The computing devices, three in this instance, which precede the parcel device PD through the machine are frames of the same size as the parcel device PD, but inasmuch as the computing devices have only to do with the accumulation in the adding unit AU of tax amounts the devices CD1, CD2, and CD3 carry no printing plates as PT on their frames below their control cards CC. It will be recalled that the total valuation for tax purposes insofar as the parcel device PD is concerned is "4440." This is in accordance with one taxing method wherein units of ten dollars only are considered significant for tax purposes, and in computing the total first-half taxes on a total valuation of four thousand four hundred forty dollars this is accomplished in accordance with the present invention by breaking the total down into, first, a four thousand dollar fraction, second, a four hundred dollar fraction, and finally a forty dollar fraction. A computing device is identified with each of these three multiples. Thus, the computing device CD1, which is the first member of the deck, represents the forty dollar fraction, the computing device CD2 represents the four hundred dollar fraction, and the computing device CD3 represents the four thousand dollar fraction. Each control card CC on a computing device as CD1, CD2 and CD3 is printed at FV1 with the fractional tax valuation and further is provided with a punched opening FV2 also representing the fractional tax valuation.

Had the total tax valuation been but four thousand dollars, there would be but one computing device in the

deck, namely, the device CD3. Further, had the total valuation been but four thousand forty dollars, there would be but two computing devices, namely, CD3 and CD1. Further, if the total valuation had been four thousand four hundred fifty dollars, the computing devices CD2 and CD3 would be present, but the device CD1 would be substituted by a fifty dollar device, and the way in which the computing devices are assigned and set up will now be described.

10 The computing devices are predetermined, that is, the tax rate is known and it is also known that the computing devices will fall into categories of so many thousands of dollars, or so many hundreds of dollars, or so many tens of dollars, or combination thereof, depending upon the total taxable valuation.

15 The three computing devices in this instance are provided with sorting tabs ST4 which are removably secured in the No. four tab mounting pocket at the back of each computing device frame as F, each frame F having

20 twelve such tab mounting pockets as is well known. Thus, in the present instance, the tax amounts represented by each of the three computing devices have in common the digit four (4,000, 400, and 40) and these devices when stored in a drawer or the like in the presence of other devices not having a sorting tab at the

25 No. four position can be separated from such other devices merely by passing a sorting needle through the tabs of the computing devices at the No. four tab position to separate these from the remaining non-related devices.

30 The hundreds computing devices, namely each device as CD2, have a second sorting tab STH in what constitutes the hundreds tab mounting position so far as sorting is concerned, and likewise the thousands computing devices as CD3 have a second sorting tab STT in what con-

35 stitutes the thousands tab mounting position. Once all of the devices having a tab ST4 have been sorted, these can then be subdivided into hundreds devices and thousands devices by sorting needles respectively passed through the hundreds tabs STH and the thousands tabs

40 STT.

In this manner, the several computing devices required for a particular deck to represent fractions that add up to the total taxable valuation can be selected for each deck.

45 The computing devices which represent fractions of any given total taxable valuation for a particular deck are punched with numerical data representing the tax on the amount represented by that computing device. Referring to the tax bills B1 and B2, it will be observed

50 that these as furnished have been printed in the lower right hand corner with a tax rate of \$1.40 per one hundred dollars valuation, and such can be printed on each bill by a pre-set printing attachment arranged at the printing station PRS so as to print each bill with the set

55 tax or final tax rate. Now, the forty dollar computing device CD1 represents forty percent of one hundred dollars, so that under the above tax rate the tax on forty dollars is fifty six cents, and this tax is represented by the punched openings TC in the first computing device

60 CD1. In like manner, the tax on four hundred dollars, namely, five dollars and sixty cents is represented by the punched openings TH in the control card on the device CD2, and the tax on four thousand dollars, namely, fifty six dollars is represented by the punched openings

65 TT in the control card of the computing device CD3.

These individual tax amounts total \$62.16 which it will be observed is the amount appearing on the bill B1 as the current tax.

It is here appropriate to point out that the tax data

70 TC, TH, and TT thus described are of course accurately punched, and each control card as CC is adapted to be punched in any one of twenty seven columns reading from left to right across the card. In forming the openings as TC representing the individual tax items that

75 total the current tax, resort is had to columns twenty-

four and twenty-five for cents values up to ninety-nine cents; resort is had to columns twenty-two and twenty-three for dollars values up to ninety-nine dollars; and so on. Thus, it should be pointed out that the tax TC on the device CD1 appears in columns twenty-four and twenty-five; the tax amount TH on device CD2 appears in columns twenty-three and twenty-four, noting that there were no cents units amounts for the tax on four hundred dollars; and the tax amount TT carried by the device CD3 appears in columns twenty-two and twenty-three noting that there were no cents amounts at all for the tax on four thousand dollars.

It so happens that under the present circumstances, mil amounts are not involved, but the handling of mil amounts will be described under a separate heading hereinbelow since the present machine has this capacity.

The taxpayers to whom the bill B1 is to be sent experienced a special assessment and were delinquent. Accordingly, the deck for these taxpayers includes a delinquent device DD and a special assessment device SAD. These devices, as shown in Fig. 9, are similar to the computing devices inasmuch as the special assessment device and the delinquent device carry no printing plates. The delinquent device DD has been punched in the first three columns of the control card thereon with the lot number LN, and this is likewise true with respect to the special assessment device SAD. The delinquent device DD has been punched with the delinquent amount, namely "23.16" in two different areas, namely, DA1 and DA2, and in this connection it will be observed that a delinquent tax amount appears twice on the bill B1, once under its own "delinquent tax" heading and again under the amount due column. Thus, the delinquent amount DA2 is punched in columns twenty-two-three-four and five so that this amount will be printed on the bill B1 immediately below the current tax of "62.16" as shown on the bill B1, and the same amount at D1 is advantageously punched in columns eighteen, nineteen, twenty and twenty-one. The DA2 amount is to be added to the current tax (62.16) as will be described and hence is accurately associated with the tax amounts in the columns of the control cards on the computing device. The amount DA1 on the other hand is only to be printed.

Likewise, the special assessment amount on the device SAD appears at two different areas, namely, SA1 and SA2, noting that in this instance also the special assessment amount appears twice on the bill B1. The special assessment amount in the area SA2 of the device SAD which is forty-four dollars is punched in columns twenty-two and twenty-three, and again in columns thirteen and fourteen, so that this amount will be entered under the current tax and the delinquent tax headings as indicated on the bill B1. In this connection it should be pointed out that the data DA2 and SA2 appear in the same field columns. This causes these different data to be added or accumulated in predetermined data receiving columns in the adding unit AU for a purpose to be mentioned. The data DA1 and SA1 on the other hand are in different fields so as to effect printing of those amounts on the tax bill under the special assessment and delinquent tax headings.

It was mentioned above that it is desirable to categorize special assessment amounts on the printed bill. The special assessment in this instance was for paving requiring the legend "1." This legend is punched at LG on the control card of the special assessment device in column eleven so as to print "1" at the side of the special assessment amount appearing under that heading of the tax bill.

It was mentioned that the control cards on the various devices comprising the deck are arranged for punching in twenty-seven columns. In the present instance, the first of these columns has been allocated to lot number, and the intermediate columns up to and including column twenty-five have been allocated to various fields for

the purposes mentioned. Column twenty-seven is allocated to control features that will be described hereinbelow, as was mentioned, and column twenty-six is reserved for mil accounting. Also, the delinquent device and the special assessment device carry control tabs CT removably mounted in pockets at the back thereof, and the way in which these tabs exercise control over the machine during preparations of the bill will likewise be described hereinbelow.

It will be observed that the bill forms include a heading "Current Valuation." This in effect represents a machine proof column for verifying that the total of the taxable units represented by the computing devices is equal to the total valuation punched in certain columns of control card CC on the parcel device PD which is "4440" in this instance. Thus, each computing device is punched at FV2 with the fractional part of the total tax it represents. These FV2 fractions are added in the adding unit of the machine and will print a total (4400") in this instance under "Current Valuation" on the bill. By checking "current valuation" against "total valuation" it can be determined if the computing devices used for a deck did in fact total up to the taxable property value.

THE ADDING UNIT

Means for printing the bill

The unit AU of the machine in which the tax bill is printed is in most respects identical to the adding unit that is described in connection with Figs. 37 to 90 of U.S. Patent No. 2,501,444, and reference may be had to that patent for many details of operation that need not be repeated herein.

The adding unit AU, Fig. 10, is adapted to be set up for adding and printing the items on the tax bill under control of the various printing and control devices in the deck described above. Thus, the control devices comprising the several decks required to complete a tax billing operation are arranged in the supply magazine SM of the machine so that the computing devices are first fed from the supply magazine to the primary sensing station SS of the machine by the carrier bars 120 followed by the related parcel device, then the delinquent device, if any, and finally the special assessment device, if any. As the devices in each deck are thus sequenced through the machine, these are held one by one temporarily at the primary sensing station SS where the punched openings in the various fields of the control cards thereof are sensed by the sensing pins 220. The sensing pins for which there are openings in a control card of a control device actuate the Bowden cables 225 which in turn are adapted to transmit the result of sensing to data receiving columns in the adding unit AU. Thus, the sensing mechanism whereat the punched data on the devices are sensed is arranged in accordance with the code shown in Fig. 9A, which is to say that there are a plurality of columns of Bowden cables 225 extending from the primary sensing station to related data receiving columns in the adding unit AU. The end portions of the same data transmitting means are shown at 100A, Fig. 10, in keeping with the reference characters for the adding unit AU, and there are accordingly five Bowden cables 100A in each such column at the adding unit terminating at a code set-up or translating mechanism 101A of the adding unit AU as shown in Fig. 10. At the set-up station there is associated with each Bowden cable 100A a data receiving plunger 103A adapted to be elevated to represent data when the associated cable 100A is actuated by a sensing pin 220 during sensing of the control device, and the plungers 103A are of course actuated in accordance with the above described code which is also fully explained in Patent No. 2,501,444. In this way, the amounts or quantities carried as punched openings by the control devices in each deck are in effect transmitted to receiving columns in the adding unit and there set up to be acted upon. There is no fixed or

rigidly established relation between the sensing columns and the data receiving columns, so that any five Bowden cables as 100A of a sensing column can be associated with any selected set or column of five data receiving plungers 103A. It is important of course that sensed data that are to be added be assigned the same columns in the adding unit. This is true with respect to the data TC, TH, TT, DA2 and SA2, and also the data FV2 of each computing device.

The adding unit in the present instance performs the fundamental function of accumulating and printing amounts and totals properly on the tax bill under circumstances to be described, and to this end embodies a plurality of segmental type arms 110A which are adapted to be set to print amounts on the bill in accordance with the numerical data transmitted to the adding unit AU from the sensing station. There are of course a greater number of type segments 110A than columns on a control card CC, since, as will be described, totals are printed and hence provision must be made to accommodate spill over amounts in the accumulator registers where individual amounts are successively collected and stored as totals.

The type arms 110A, Fig. 10, are arranged in side by side proximity as will be evident from what is to follow, and each is adapted to be actuated in an upward direction to print a digit on the underside of the tax bill by an impression hammer 112A which, as will be described below, in connection with printing the bill in the unit AU, is held inactive at least until the parcel device in the deck has been sensed, and this is so in order that the data on the computing devices CD which precede the parcel device PD can be added successively in the unit AU without being printed on the tax bill. It should be mentioned that when a print is to be effected, not all of the type hammers in the adding unit are necessarily active, since some of the columns in the adding unit must be allocated to spill over during accumulation as was mentioned and hence are active only when an amount has been spilled over to that column. Thus, zero suppressing means are associated with the hammers 112A as described and for the purposes mentioned in Patent No. 2,501,444, and these zero suppressors also serve to split the adding unit in to related fields so that there will be no confusion of amounts as represented by the different fields of punched data on the central cards CC described above.

Each of the type segments or arms 110A used for printing amounts carries numerical type 113A on the upper edge thereof, and these numerical type proceed from right to left as viewed in Fig. 10 so that normally a zero is adapted to be printed unless its type arm is suppressed. Cooperating with the type characters 113A is a platen 114A.

The tax bill fan-fold that is to be printed at the unit AU is placed between the type 113A and the related platen 114A, and an inked ribbon IR, Fig. 11, is interposed between the type 113A, Fig. 10, and the tax bill. The way in which the tax bill fan-fold is controlled when arranged to be printed at the adding unit will be described hereinbelow.

To set the type arms 110A for printing a digit other than zero, each type arm at its rearward end is pivotally connected to a segment 115A, Figs. 10 and 11, that is adapted to rock on a horizontal mounting shaft 116A, Fig. 10, and the pivotal mounting thus afforded for each type arm enables the type arm to be actuated against the action of springs 117A which hold the type arms normally in retracted position on the segments 115A. The extent of rocking movement of each of the segments 115A is controlled by a related slide or rack 120A, Figs. 10 and 11, normally urged in a forward direction by springs 121A. The racks 120A have teeth 122A enmeshed with the teeth 123A at the bottom of each related segment 115A. It will be appreciated that there are as

many racks 120A as here are rocking segments 115A that set up type 113A.

In setting the segments 115A and at the same time the type arms 110A, the racks 120A are adapted when released to reciprocate or shift in a forward direction under the action of the springs 121A, that is from right to left as viewed in Fig. 10, and the extent of this forward movement is governed by the way in which the plungers 103A of the set-up control 101A have been set by the wires 100A as a consequence of sensing.

Thus, the upper ends of the five plungers 103A in each column of the adding unit engage the lower ends of five related control pins 125A for controlling the extent of forward or setting motion of each rack 120A. 15 When a plunger 103A is elevated its pin 125A is elevated, and this elevates a release pawl 126A projecting forwardly from the forward end 130A of each rack 120A to which it is pivotally connected thereby freeing the pawl 126A relative to a stop plate 132A so that forward or 20 setting motion of the rack 120A can occur.

In the event that no pin 125A is active for a particular rack 120A, that rack will remain zeroized. This will occur for example in those columns where no data were sensed on a control device and in those columns not used

25 for receiving sensed amounts. This will also occur in columns allocated to spill over amounts, since these columns are active only for totals and are not activated as a consequence of normal sensing. Thus, while there are twenty-seven columns on the control cards adapted to 30 bear punched data, there are a greater number of type arms 110A and slides 120A, and some of these are assigned a special operation as will be mentioned. Otherwise, when the adding unit AU is in operation and a pin 125A is active to raise a pawl 126A, its rack 120A 35 advances forwardly to set its type arm 110A to the digit represented by the active one or ones of the pins 125A.

Toward the end of each cycle of operation, the pawls 126A are restored by a cam-controlled restoring bar 129A, Fig. 10, as described fully in Patent No. 2,501,444.

40 This restores the plungers 103A and the cables 100A, and thus cables 100A are re-set or zeroized for the next sensing operation.

Briefly, and as described in more detail in Patent No. 2,501,444, upon the occurrence of an odd digit, forward 45 motion of a rack 120A is stopped immediately by its forward end 130A engaging an elevated pin 125A, because at this time the pin 125A9 for the digit "9" is also elevated and engages the stop plate 132A. Thus, all the pins 125A are carried in a slide bar 135A, and if the 50 digit represented by the pins 125A is an even digit, the rack 120A advances forwardly until its forward end 130A engages the elevated one of the pins 125A, but the pin 125A9 is not up for an even digit, and at this time the slide 135A enables the rack 120A to advance one 55 additional step until the slide 135A engages its stop 136A.

As described in Patent No. 2,501,444, the racks 120A are released for forward movement when their release bail 139A, Fig. 10, is rocked in a counterclockwise direction as viewed in Fig. 10. Operation of the bail 139A is accurately timed from a cam 141A on the main cam 60 shaft 140A which when in operation times and controls many of the adding unit operations, and this bail also serves to restore the racks 120A at the proper time.

65 The lower edge of each rack 120A is provided with three sets of gear teeth 141A, 142A, and 143A, Fig. 10. These gear teeth are related to the accumulator wear wheels 145A of three separate accumulator registers AC1, AC2 and AC4. Normally, and except for totals, 70 the accumulator wheels are disengaged for the racks 120A when the racks 120A are in idle or restored position, but upon restoring movement of the slides 120A rearwardly from a set position the individual digits that are represented by the racks 120A at the termination of 75 their forward movement are adapted to be entered into

the accumulating wheels 145A of the particular accumulator register that has been raised to mesh its wheels 145A with the racks 120A undergoing rearward or restoring movement. It will be recognized that this is an adding operation, which is to say that in repeated cycles of the machine the amount entered into the wheels 145A of an elevated accumulator register during restoration of the racks 120A may be added to an amount already standing or stored in the wheels of that register from a previous cycle. It of course follows that the reverse operation is possible, namely, by engaging the accumulator wheels 145A of one of the registers with the racks 120A prior to commencement of forward movement of the racks 120A the accumulator register serves to enable any amount stored therein to be read out so that the type arms 110A will be set up to print what was standing in the accumulator.

In the present instance, register AC1 is used to add the individual tax amounts as FV2 and TC, Fig. 9, carried by the computing devices in a deck as described above, and upon occurrence at the ensuing station SS of the parcel device PD corresponding to its computing devices of the total of the current tax thus added in register AC1 is read out of register AC1 and is printed on the tax bill as a sub-total. This sub-total amount printed on the tax bill is then restored back to register AC1 from which it was taken, so that any subsequent delinquent tax amount or special assessment tax amount in the same deck can be added thereto to enable a total of current tax, delinquent tax and special assessment tax to be printed as a total for the deck at the bottom of the tax bill. It is for this reason that the data TC, TH, TT, DA2 and SA2 are accurately associated column-wise on their control cards. This clears the accumulator AC1 for the reception of the tax amounts occurring in the next deck of devices, and when such a total is taken, this total is then transferred to register AC2 which serves to store such individual totals as a grand total.

It should be mentioned too that when a sub-total is printed, the data represented in fields F1, F2, F3 and F4 of the parcel device are printed on the bill at the same time.

Delinquent and special assessment taxes occurring in all of the decks are successively accumulated in register AC3 thereby enabling a grand total of delinquent plus special assessment taxes to be determined for the entire billing, which can be taken from register AC3 at the end of the billing run.

As shown in Fig. 10, each accumulator register is normally in a lower or ineffective position whereat the accumulator wheels 145A are demeshed with respect to the gear teeth on the racks 120A related thereto, and to bring about engagement between an accumulator and the racks 120A it is necessary to raise that accumulator. The accumulating or adding mechanism is illustrated in detail in Figs. 13 to 19. When an accumulator is thus to be elevated to enmesh the accumulator wheels 145A with the corresponding gear teeth of the racks 120A, a control arm 150A of the accumulator that is to be elevated is rocked clockwise as viewed in Fig. 17. This causes a cam slot 151A formed in a head at the upper end of the arm 150A to engage a follower 152A on the end of the shaft 153A which supports the accumulator wheels 145A. This raises the shaft 153A to enmesh the accumulator wheels 145A with the associated gear teeth on the racks 120A. As described in Patent No. 2,501,444, this is accomplished prior to restoration of the racks 120A at the time when an accumulator is to be used for adding.

The accumulating or adding mechanism embodies a pair of side mounting plates 155A and 156A, Fig. 16, that are connected by rigid spacer bars. Thus, the accumulator mechanism supported by the mounting plates 155A and 156A is adapted to be removably mounted in the machine in the area below the racks 120A

as will be observed in Figs. 11 and 12. The shafts 153A which rotatably support the sets of accumulator wheels 145A are connected at opposite ends thereof to related pairs of end plates 160A, Fig. 16, by studs 161A, there being two such end plates for each accumulator, and the followers 152A mentioned above are journaled on the shafts 153A inwardly of the studs 161A. Thus, during raising and lowering of an accumulator, the end plates 160A thereof are also raised and lowered.

10 Rectangular guides 163A, Fig. 17, are mounted on the ends of the shafts 153A, and are disposed inwardly of the studs 161A in rectangular slots 165A formed in the side plates 155A and 156A, so that during raising and lowering of an accumulator the guides 163A assure an accurate association of the accumulator wheels with the teeth on the racks 120A allocated thereto.

It was mentioned that raising and lowering of each

20 accumulator is under the control of a rocking arm 150A, and for each accumulator there are two such arms, one outwardly of each of the two end plates 160A in each accumulator. Thus, the cam slots 151A of the rocking arms 150A embrace the followers 152A as will be observed particularly in Fig. 14. The rocking arms 150A are mounted at their lower ends on square end portions 25 as 171A, Fig. 19, of the shafts 170A, Figs. 14 and 19, which control the arms 150A in a way to be described, and in this connection it may be pointed out further that the lower edges of the end plates 160A are bifurcated at 172A, Fig. 14, and these bifurcated portions embrace the shafts 170A thus serving as bottom guides for the end plates 160A.

Normally, the rocking arms 150A are held down in limit positions by springs 173A and 174A, Figs. 15 and 17 which act on lugs 175A, Fig. 17, at the lower rear end 35 of the arms 150A to hold the followers 152A at the rearward end of the cam slots 151A, which is the condition whereat the accumulators are demeshed relative to the racks 120A.

40 In elevating a register against the return action of the springs as 173A and 174A, resort is had to a gear segment as 175A, Fig. 18, for each accumulator register AC1, AC2 and AC3. Each such gear segment 175A is carried loosely on an enlarged sleeve 176A, Fig. 19, and the sleeve 176A is provided with a square bore that is complementary 45 to a square mounting stud 180A which is an extension of the rocking shaft 170A outwardly of the side frame 155A of the accumulator unit. Each stud 180A is provided with a bore as shown in Fig. 19, and an expansion coil spring 181A is under compression between the end of the bore in the stud 180A and an end stop 185A that is mounted on the outer end of the sleeve 176A. Thus, the spring 181A serves to hold each sleeve 176A and its gear segment 175A in an outermost position on the stud 50 180A, and under this condition the gear teeth of the segments 175A are meshed with corresponding sets of related gear teeth 189A on a reciprocal add control rack 190A. Each gear segment at the lower forward end is formed with an ear 191A, Fig. 18, and an inwardly extending stud 192A, Fig. 16, having a tapered end 193A. 55 The tapered stud ends 193A are associated with an accumulator zeroizing control as will be described below.

60 As described in Patent No. 2,501,444 the add control rack 190A is arranged to be shifted rearwardly, that is to the right as viewed in Figs. 12 and 18 by means including a control lever 195A, Fig. 12, setting between arms as 196A at the forward end of the add control rack, and when this occurs a segment 175A having teeth meshed with gear teeth 189A on the rack 190A is rocked clockwise as viewed in Fig. 19. This imparts clockwise rocking motion to the rock shaft 170A having the actuated gear segment 175A mounted thereon, and the two arms 150A of the corresponding accumulator are rocked clockwise as viewed in Fig. 17, by the squared portions 171A 65 on the actuated rock shaft 170A to elevate the accumu-

lator wheels 145A and the end plates 160A of the particular accumulator.

The control lever 195A for the add rack 190A is under control of a cam on the main cam shaft 140A as fully explained in Patent No. 2,501,444, and the timing is such that an accumulator that is to be used for receiving amounts from the slides 120A is elevated at about 225° in the machine cycle, which is about 15° prior in time to restoration of the slides 120A rearwardly from the set positions. When the slides 120A have been restored after amounts have thus been added in to an accumulator, the add rack is shifted forwardly, and the accumulator that was elevated is allowed to assume its lowered normal position having received an amount.

The gear segments 175A are also adapted to be rocked under control of a second rack 220A, Fig. 19, to elevate the accumulators, and this second control rack is a total rack having sets of gear teeth, like the ones on the rack 190A, operative to elevate a selected accumulator for reading a total out of that accumulator. The total control rack 220A is operated similar to the add rack 190A, except the timing is different, and as shown in Fig. 28 the total rack is under control of an operating arm 221A' having a roller 222A' acting in a cradle on the rack 220A afforded by arms as 223A'. Thus, where it is desired to take from a register an amount standing therein, the total rack is actuated and the corresponding gear segment 175A is first shifted inwardly on the stud 180A against the return action of the spring 181A in a way to be described to mesh the gear teeth on the segment 175A with corresponding gear teeth on the total control rack 220A. This is timed to occur, as described in Patent No. 2,501,444, early after initial commencement of a machine cycle and of course prior in time to release of the slides 120A by the bail 139A. Since the accumulator wheels 145A of an accumulator register are thus engaged with teeth on the slides 120A prior to forward movement of the slides 120A, the slides 120A serve to zeroize the accumulator, and when the accumulator is zeroized each rack or slide 120A controlled at this time by a data storing accumulator wheel 145A will travel forwardly a distance corresponding to the digital amount represented by that accumulator wheel. When the accumulator has been zeroized in this manner, the type arms 110A will be set to print the total or sub-total that was standing in the accumulator register.

ADDING UNIT

Tens carry and zeroizing operations in the accumulator

The tens carry and zeroizing operations are described fully in Patent No. 2,501,444, but a brief repetition is here appropriate. Moreover, there are certain advantageous differences in structure as will now be explained.

The accumulator wheels 145A prior to any amounts being entered there stand, of course, in their zero positions, and each such zero position is defined by a wide tooth 145W, Figs. 14 and 16 disposed opposite a stop finger 225A of a zero stop pawl plate 226A. In receiving an amount from a slide 120A, an accumulator wheel is turned clockwise as viewed in Fig. 14. Diametrically opposite the zero stop finger 225A is a carry cam 228A in the form of a narrow vertical arm having an engageable point or nose 230A disposed in the rotative path of each wide accumulator tooth 145W. Each accumulator wheel has twenty teeth, and between the stop finger 225A and the carry cam 228A are ten positions, such that when a wide tooth 145W passes clockwise from its nine position on the upper side of the point 230A on the carry cam 228A to its zero or ten position on the lower side of the point 230A the cam 228A is rocked clockwise as viewed in Fig. 14 by a wide tooth 145W engaging the nose 230A. Such movement of the accumulator wheel from nine to ten position will occur of course in most instances at a time when a slide 120A is operative to enter an addend in the register to turn the

accumulator wheel from an augend representing position less than ten to a sum position of ten or higher, and when this occurs a carry of one is entered into the next higher ordered accumulator wheel 145A adjacent the accumulator wheel 145A that received the addend as will be explained.

The carry cams 228A are pivoted on shafts 231A that extend between the end plates 160A of the accumulator unit so that the cams 228A are raised and lowered with the accumulator. Rearwardly of and aligned with each carry cam 228A is a carry latch 235A adapted to rock on a shaft 236A rearwardly of and parallel to the pin 231A on which the carry cams 228A are mounted as a set in each register. The shaft 236A is immovable, 15 being attached at opposite ends to the frame plates 155A and 156A of the accumulator unit. Springs 237A are effective on arms of the latches 235A below the shaft 236A to normally hold each latch against its cam 228A as shown in Fig. 13. Associated with the cam 228A and 20 its latch 235A is a limit lug 240A having shoulders complementary to aligned recesses in the upper ends of the cams 228A and the latch 235A to define the normal positions of each related cam 228A and latch 235A.

When a wide tooth 145W is effective on a cam 228A 25 in a particular order, the cam 228A rocks its latch 235A clockwise and this releases a finger 241A at the bottom of the latch 235A relative to an opposed finger 244A projecting upwardly from a rocking carry segment 245A adapted to rock on the shaft 170A which, is will be recalled, does not move vertically with the end plates 160A of the accumulator. When a carry segment 245A is thus released, springs 246A are effective on an arm 247A at the bottom of the released carry segment 245A to rock the carry segment 245A counterclockwise as viewed in 30 Figs. 13 and 14 at a time when a lower step 251A of a carry trip latch 252A is positioned above a toe 253A of the carry segment 245A rearwardly of the vertical fingers 244A. This represents what can be termed the primary trip. No carry has as yet been made, and it may 35 be mentioned that this primary trip motion of the carry segment 245A is but slight in order that gear teeth 255A carried at the upper end of the gear segment will not be misaligned for the essential final carry function when the accumulator AC1, AC2 or AC3 is lowered.

It was mentioned that at the time when a carry segment 245A is conditioned for a carry, the toe 253A thereof engages a step 251A on a carry trip latch 252A, and the way in which the carry trip latch is held in this position will be mentioned below. At about 335° in the 40 cycle when the accumulator wheels have been lowered to engage the teeth 255A on the carry segments 245A, the trip latch 252A which is common to all segments 245A rocks counterclockwise as viewed in Fig. 14 to its normal position to disengage the step 251A thereof from the toe 253A of the carry segment 245A, and when this occurs the springs 246A are then effective to rock such of the carry segments 245A as have been released from a finger 241A one step counterclockwise to advance the 45 associated accumulator wheel with which the carry segment 245A is engaged one step to enter a carry therein. The carry is thus completed when the toe 253A of the carry segment engages a second step 254A on the carry trip latch 252A above the step 251A. To thus complete the carry, it is necessary to allow the trip bar 252A to rock from a biased or held position shown in Fig. 14 to normal position shown in Fig. 13, and the 50 way this is accomplished will now be described.

The carry segment trip latches 252A are each under 55 control of an elongated slide arm 260A, Fig. 15, which in turn is controlled by a rocking lever 261A controlled by a cam 262A on the main cam shaft 140A of the adding unit AU. The rise of the cam 262A is presented to the cam follower 263A until about 200° in the machine cycle, and a spring 265A is not effective to rock 60

the arm 261A counterclockwise as viewed in Fig. 15 until this time, whereupon the arm 260A shifts in a forward or left hand direction on guide pins 265A. The cam 262A presents its dwell, to the follower until about 355° in the machine cycle at which time the lobe or rise is again effective on the follower 263A to shift or restore the slide 260A to the right.

Associated with each carry trip 252A is an end plate 270A tensioned by a torsion spring 271A so as normally to tend to pivot clockwise on a shaft 275A that extends between the end plates 155A and 156A of the accumulator mechanism for supporting the trip latch 252A. At the lower end of each plate 270A is a stop pin 277A which is normally held by the spring 271A against the left hand end of a slot 278A provided in the slide arm 260A forwardly of each guide pin 265A. The slide arm 260A in its normal position bears forcefully on the pins 277A to bias the carry trip latches in the rear position shown in Fig. 13 which is a released position whereat a carry can be made. When the arm 260A shifts forwardly later in the cycle, however, each carry trip latch under the action of its spring 271 rocks forward to the position shown in Fig. 14 where the stop 251A is effective to limit the primary trip action as above described. Then, almost at the end of the cycle, the arm 260A shifts back, presenting the step 254A to the carry latch, and the carry latch, if it is to do so, enters a carry.

It is of course necessary to restore any carry segment 245A that may have been used to effect a carry. This is accomplished as an incident to elevation of an accumulator, since it is only when an accumulator is being lowered that the carry segment must be in normal position to effect a carry if required. To this end, the arms 150A are formed with rearwardly extending ears 280A, Fig. 18, at their lower ends, and these ears carry between them a restoring bail 281A, such that when the pair of arms 150A of an accumulator are rocked counterclockwise by the springs 173A any carry segments 245A that have performed carries are restored clockwise and latched up by the latches 235A.

It may happen that a carry on a carry will occur, that is, an accumulator wheel 145A into which a carry is made may itself be standing in a nine position so that when a carry is passed thereto this accumulator wheel passes from a nine to ten representing position. This can only occur of course at the time when an accumulator AC1, AC2 or AC3 is in its lower position. It will be recalled that at this time the slide arm 260A is effective to hold the carry trip latch bars 252A in their released positions shown in Fig. 13. Therefore, if a carry occurs upon a carry, the higher order accumulator wheel into which the carry is made will be effective to trip its latch 235A thereby releasing the finger 241A relative to the finger 244A of the carry segment 245A associated with the next higher ordered accumulator wheel, and inasmuch as the step 254A of the carry trip latch is presented at this time to all of the carry segments 245A, such next higher ordered accumulator wheel will receive a unit addend in the form of a carry.

When a total is to be read out of any particular accumulator, that accumulator is elevated prior to forward setting movement of the slides 120A as was mentioned, and of course at this time the slides 120A are then under control of the accumulator wheels 145A rather than under control of the set-up mechanism 101A which is active only in sensing operations on the control devices mentioned above. It was also mentioned that a total taking operation is under control of the total rack 220A, and when a total is to be taken, means are effective as will be described below to shift the gear segment 175A from its normal position whereat it is engaged with the add rack 190A inwardly so that the gear teeth on the gear segment 175A engage the related set of gear teeth on the control rack 220A. As described in detail in

Patent No. 2,501,444, the accumulator from which a total is to be taken is engaged with the slides 120A under action of the total control rack 220A approximately 20° after commencement of a machine cycle, and is not lowered until after about 160°. Moreover, at the front of the slides 120A the stop 132A is at this time in its lower position, that is, ineffective to release the slides 120A, and the way in which this is accomplished is described fully in Patent No. 2,501,444.

10 In taking a total, it is necessary to afford means for stopping the accumulator wheels in their zero positions. To this end, the zero stop pawl plate 226A mentioned above is active. Thus, referring to Figs. 13 and 14, it will be noted that the stop plate 226A in each accumulator is positioned forwardly of the accumulator wheels. The stop plate 226A includes at either side an ear 290A, and these ears serve to pivot the related stop plate 226A on pins 291A on the end plates 160A of each accumulator. Each ear 290A carries a stub pin 293A, Fig. 14, disposed in an enlarged opening 296A formed in each accumulator end plate 160A, and springs 298A, each anchored at one end on the end plate 160A and at the other end to a related stub pin 293A, are effective to normally hold the stop plates 226A away from the accumulator wheels 145A.

Mention was made above of studs 192A projecting inwardly from ears 191A at the forward lower ends of the gear segments 175A, these studs having tapered ends 193A. When a gear segment 175A is shifted inwardly to a total taking position in alignment with the total control rack 220A, the tapered end 193A of the stud 192A wedgingly engages the lower end of the related stop plate 226A, thereby rocking the stop plate 226A clockwise to the extent allowed by movement of the stub pin 293A disposed in an opening 296A in the accumulator end plate, and the extent of this rearward movement of the stop plate 226A is such that the stop fingers 225A thereof are disposed inwardly of and between the accumulator wheels 145A so as to be in the path of the wide teeth 145W. During the total taking or read out operation, the accumulator wheels are rotated counterclockwise as viewed in Figs. 13 and 14 until the wide tooth 145W of each accumulator wheel 145A engages a stop finger 225A on a stop pawl plate 226A. In this manner, the accumulator wheels are zeroized, and the forward setting movement of each rack 120A which is under control of an accumulator wheel undergoing zeroizing movement will cease when the related type arm 110A stands at the digit that was standing in the accumulator wheel.

50 It is desirable to lock the accumulator wheels 145A against rotation while being raised and lowered. This is accomplished by plates 300A, Fig. 13, having spaced teeth 301A at their upper edges aligned with and related to the accumulator wheels so that when a plate 300A is pivoted inwardly toward the accumulator wheels in a particular accumulator the teeth 301A thereof fit neatly in the spaces between the teeth of the accumulator wheels. To this end, the plates 300A have arms 302A at either side pivoted on pins 303A carried by the end plates 160A 55 of the accumulators. Springs 305A are effective to urge the plates 300A inwardly, but the arms 302A have rounded lower cam edges normally engaging the upper surfaces of ears 306A projecting forwardly from the rocking arms 150A. When an arm 150A in an accumulator is rocked clockwise, Fig. 14, to raise an accumulator, the corresponding plate 300A is also raised, and progressively increasing clearance is established between the lower edge of arm 302A of the plate 300A and the upper edge of ear 306A of the rocking arm 150A. Consequently, the 60 springs 305A are momentarily effective to rock the plate 300A inwardly to lock the accumulator wheels against inadvertent rotation, but the cam edge on each arm 302A is such that just prior to the accumulator wheels engaging the teeth on the slide 120A the upper edge of the ear 306A on the related arm 150A now in limit clockwise 65

position is once again effective to hold the plate 300A with the teeth 301A disengaged from the accumulator wheels 145A. The teeth 301A are also effective when an accumulator AC1, AC2 or AC3 is lowered.

ADDING UNIT

Control of entry of amounts in and totals taken from an accumulator

It will be recognized from the foregoing that entry of amounts into and totals taken from any particular accumulator centers primarily about the gear segments 175A which are adapted to engage either the add control rack 190A or the total control rack 220A, Fig. 19, and it may be further pointed out in this connection that the gear segments 175A are each adapted to assume what amounts to a neutral position between the two racks 190A and 220A whereat the gear segments 175A are ineffective to exert any control over the related accumulators.

In controlling the positioning of the gear segments 175A so as to locate these either in an add, neutral, or total position on each related sleeve 176A, inwardly rocking levers 320A1, 320A2 and 320A3, Figs. 20 and 21 are disposed outwardly of and in alignment with a related sleeve 176A which carries a gear segment 175A. Each rocking lever is provided at its lower end with a lug as 322A, Fig. 21, and an adjustable set screw 323A is provided in each such lug so as normally to engage the outer end of the related sleeve 176A and hold the related gear segment 175A in engagement with the related teeth on the add rack 190A. Such normal positions for the rocking levers 320A1-2-3 are determined by cams as will be described below.

The rocking levers 320A1-2-3 are arranged for independent rocking movement conveniently on a sub-total shaft 325A, Figs. 12 and 20, and to this end each such rocking lever is provided at its upper end with a sleeve as 326A journaled loosely on the subtotal shaft 325A, Figs. 12 and 20. Each rocking lever 320A1-2-3 is adapted to be controlled independently and automatically as an incident to sensing of the control devices under certain conditions, and the way in which this is accomplished will be described hereinbelow.

Preliminary to the description of the way in which the rocking levers 320A1-2-3 are controlled under the present invention, it may be well to point out that these rocking levers are also adapted to be controlled from a total shaft 330A, Figs. 12 and 20 which is positioned above and parallel to the sub-total shaft 325A. The shafts 325A and 330A extend forwardly from the rear of the machine at one side thereof, and at their forward ends are provided with respective control knobs 331A and 332A so that each shaft 325A and 330A can be independently controlled manually. Three cams 335A1, 335A2 and 335A3 are affixed in spaced relation along the total control shaft 330A and these cams are allocated respectively to control over follower pins as 336A1-2-3, Fig. 23, which project forwardly from the forward face of each rocking lever as 320A3. The cams 335A1, 335A2, and 335A3 have lobes and dwells formed on the lower edges thereof in a definite predetermined manner as shown in Fig. 23, so that by operating the total shaft 330A to one of its three positions, a corresponding one of the cams 335A1, 335A2, or 335A3 is operative in respect of its rocking lever 320A1-2 or 3 to shift its gear segment 175A out of add position and inwardly to a total or neutral position.

In the present instance, the cams 335A1, 335A2 and 335A3 are effective in normal position to enable the gear segments 175A to engage the add rack as can be seen in Fig. 23. When the total shaft 330A is turned from its normal position to its first total position, a total can be taken manually from accumulator AC1 and at the same time cam 335A2 is effective on its follower pin 336A2 to cause gear segment 175A in register AC2 to mesh with

the total rack 220A as shown in Fig. 24. The setting of Fig. 24 is attained in a way to be described below, and gear segment 175A of register AC3 has been set by a solenoid.

In the second position of the total shaft (manual) a total can be taken manually from accumulator AC2 and the gear segments 175A in registers AC1 and AC3 are cammed to neutral position as shown in Fig. 25. In the third position of the total shaft 330A a total can be taken from accumulator AC3, and the gear segments 175A in registers AC1 and AC2 are cammed to neutral position as shown in Fig. 26.

As described in Patent No. 2,501,444, a latch including a latch arm 340A, a latch pawl 341A and a manual release arm 342A, Fig. 11, is effective to hold the total shaft 330A in its normal position, and this latch is also effective to hold the total shaft 330A in any one of its three set positions. At substantially the end of the cycle operation of the adding unit AU, the latch for the total shaft is actuated to a released position by a cam on the main cam shaft acting on a follower of the latch lever for the total shaft, thereby enabling the total shaft to re-set.

In achieving the desired automatic control over the gear segments 175A as distinguished from manual control in accordance with the present invention, this occurs as an incident to sensing of the control devices at the primary sensing station SS in the machine unit 100 where the bills are addressed, and the arrangement in the present instance is such that upon the occurrence of computing devices which carry predetermined fractions of the current tax amount at the primary sensing station the amounts represented thereby are successively added in register AC1 during restoration of the slides 120A, and at these times accumulators AC2 and AC3 are set in neutral position so that no amounts are entered therein during restoring movement of the slides 120A. Forward setting movement of the slides 120A in each computing device sensing cycle occurs without the amounts being printed, and under the present invention suppressing means are afforded to suppress the hammers 112A in each instance of a computing device at the primary sensing station.

However, upon the occurrence of a parcel device at the primary sensing station, and the transfer of its data to the set-up mechanism 101A for the slides 120A, the data sensed on the parcel device in fields F1, F2, F3 and F4 are printed on the corresponding tax bill at the proper places as well as the total of FV2 data accumulated from the computing devices (under "Current Valuation" heading on the tax bill) and at the same time a sub-total is taken from accumulator AC1 and printed on the bill at S, Fig. 8, under the heading "Amount Due—Current Tax." The bill form BFF at the adding unit AU is then given a short space as will be described. Indeed, any time the bill is printed with an amount, it is spaced. As mentioned, this is a sub-total operation, which is to say that the amount taken from register AC1 and printed on the bill at this time is then transferred back into accumulator AC1. Thus, the sub-total amount "S" printed is in effect restored as an augend of the total tax due and payable, since the total tax due and payable also is to include any delinquent amount and any special assessment amount that may be in the deck, and it is for this reason that the current tax that was accumulated from the computing devices must be held in accumulator AC1 until any delinquent amount and any special amount in the form of addends have been entered in the accumulator AC1. During the taking of a sub-total, registers AC2 and AC3 are neutralized, so that no sub-total is entered therein, by having the gear segments 175A thereof positioned between the add rack 190A and the total rack 220A. If there is in fact no delinquent or special assessment device in the deck, the bill, after being printed at S with the sub-total amount, is fed forward to its home position where the amount S is again printed in the position "A," Fig. 8, on the bill. This did not occur for the

bill B1, but if it had "62.16" would appear at A, Fig. 8, on bill B1.

In any event, the last device in the deck, whether this be a special assessment device, a delinquent device (in the absence of any special assessment device), or a parcel device (in the absence of both a delinquent device and a special assessment device), is provided with a control tab as CT, Fig. 9, on its frame F, as will be described, which causes whatever amount is standing in accumulator AC1 to be taken therefrom, printed as a total at A on the tax bill above "Pay This Amount," transferred to accumulator AC2, and the accumulator AC1 cleared for the next deck. In this way, accumulator AC2 will carry a running total of the taxes billed.

It will thus be seen that control over an accumulator for receiving an amount from a control device in a deck is instituted primarily as a result of sensing control indicia on the devices of the deck either in the form of tabs or punched openings, and in this connection it will be recalled that in the description of the control devices set forth above it was mentioned that certain of the control cards are adapted to be punched in column twenty-seven, that is, in the last column with control openings. Referring back to Fig. 9 it will be observed that the computing devices CD1, CD2, and CD3 have no control opening formed in the last column thereof, and moreover the computing devices have no control tabs CT mounted on the frame thereof. This is significant, because the absence of a control tab and a control opening in column twenty-seven of a control card determines that the data TC, TH, TT and FV2 of the computing or accounting devices are merely sensed, transferred to the set-up mechanism 101A, and there used to control forward setting of the slides 120A in the related data columns of the adding unit AU above described, and the amounts thus represented by the slides 120A in their set positions are not printed but are only added in the accumulator AC1 during restoration of the slides 120A. Such repeated adding eventually totals the tax fractions as current tax, and also the accumulated data FV2 as a machine proof total of "Current Valuation" which printed on the bill should correspond to "Total Valuation" punched in the parcel device to be printed on the bill.

It will be observed in Fig. 9 that in column twenty-seven of the control card CC of the parcel device PD an opening SO is punched therein, and referring to the code of Fig. 9A, it will be noted that this single opening is representative of code digit "2." When an opening SO carried by a parcel device in the deck is sensed, this determines that the accumulated amount standing in accumulator AC1 is to be read out, printed as a sub-total and restored back in the accumulator AC1, and at the same time the other punched hole data formed on the control card CC of the parcel device PD in the fields F1, F2, F3 and F4 are likewise to be printed.

In connection with the delinquent device and the special assessment device of the deck shown in Fig. 9, it will be observed that the control cards CC on these devices are provided in column twenty-seven with two punched openings which in accordance with the code shown in Fig. 9A represent the code digit "5." Upon the sensing of code "5" in a special assessment or delinquent device the amounts such as DA1, DA2, and SA1, SA2 are printed at the appropriate places on the tax bill, and these amounts are also added into registers AC1 and AC3 but not in AC2 which is reserved solely for totals transferred from AC1. Also the lot numbers LN are printed on the bill at the appropriate place, as well as any legend as LG used to identify the category of any special assessment.

The last device in the deck bears a tab CT at the No. 1 tab position as shown in Fig. 9. This calls for a total to be taken from register AC1, printed on the bill, and a new bill then fed forward beneath the platen 114A (identifying the printing position in the adding unit AU) in position to receive its own sub-total at "S," Fig. 8.

The arrangement in the present instance is such that the transmitting wires or cables 100A for representing digit "5" (or any other predetermined code) in column twenty-seven of the control cards on the delinquent and special assessment devices at the primary sensing station

5 are allocated to a slide 120A1, Fig. 29, so that the plungers 125A, Fig. 10, corresponding to these two column twenty-seven transmitting wires are adapted when actuated by related sensing pins 220, Fig. 5, to stop forward setting of the slide rack 120A1 at its "5" position, and in turn 10 this set position of the slide 120A1 exercises control over the gear segments 175A of accumulators AC1 and AC3 as will now be described. The zeroized position of the slide 120A1 is also significant in relation of control over 15 the gear segments 175A as will be pointed out.

Pivoted to the rear of the slide 120A1, Fig. 29, is a bell crank 350A pivoted in turn at 351A to a side frame plate of the adding unit AU. Attached to the lower arm 352A of the bell crank 350A is a vertical link 355A, and 20 this link is provided with rack teeth 357A along its forward edge. Forwardly of the rack 357A is a horizontal rock shaft 358A to which are fixed in spaced relation three cam discs 361A, 362A and 363A, Fig. 35. A pinion 365A is fixed to the shaft 358A to mesh with the 25 rack teeth 357A.

Associated with each cam disc on the shaft 358A is a switch trip in the form of a bell crank 370A, and each such bell crank is mounted loosely on a horizontal rock shaft 375A forwardly of and below the shaft 358A. The 30 upper arm 376A of each bell crank 370A is provided with a sensing finger 377A adapted to sense the edge of its related cam disc 361A, 362A, or 363A, and the lower arm 379A of each bell crank 370A at its rear edge engages the plunger 380A of a micro switch, there being a micro switch 381A for the cam 361A, a micro switch 382A for the cam 362A, and a micro switch 383A for the cam 363A.

Pinned to one end of the rock shafts 375A so as to be 35 rocked upon turning movement of the rock shaft 375A is 40 a relatively short vertical link 385A, and this link at its upper end is pivotally connected to a relatively long forwardly extending operating arm 386A which at its forward end is provided with a yoke 388A. The end of the yoke 388A opposite the end connected to the arm 386A is bifurcated at 390A so as to embrace a guide boss 45 carried by the main cam shaft 140A. Intermediate its ends, the yoke 388A is provided with a cam follower 391A that is associated with a cam 392A that rotates with the main cam shaft 140A.

50 Springs 395A are connected between the lower arms 379A of the bell cranks 370A and studs on a vertical mounting plate 396A. The mounting plate 396A supports the three micro switches mentioned above as well as bearing arms for the shafts 358A and 375A. Arranged 55 in spaced relation along the shaft 375A are three arms as 397A, and each such arm has a pin 398A normally engaging the rear edge of the arm 379A of a bell crank 370A so as to prevent closure of the related switch plunger 380A. The arms 397A are pinned to the shaft 375A so as to rock therewith.

The cam 392A is so configured that the dwell 399A thereof is presented to the follower 391A at approximately 130° in the machine cycle, and it continues to be presented to the cam follower 391A until after about 60 170° of adding unit cycle. At the time when the cam follower 391A is on the dwell of the cam 392A just prior to restoration of the slides 120A, the springs 395A are effective to rock one or more of the bell cranks 370A counterclockwise in certain instances and under certain conditions. If such occurs, a switch as 381A may be actuated as will now be described, and the arm 386A is shifted inwardly to the left as viewed in Fig. 29 since each bell crank when rocked counterclockwise acts on the pin 398A of the related arm 396A which is pinned to the rock shaft 375A.

The three cam discs 361A, 362A, and 363A are illustrated schematically in Fig. 35. Each such cam disc has a position corresponding to one of several possible positions of the slide 120A1. Thus, when in its zero position, the cam disc 361A presents a rise to the sensing finger 377A of its bell crank 370A, the cam disc 362A presents a recess to the sensing finger 377A of its bell crank 370A, and the cam disc 363A when at zero position presents a recess to the sensing finger 377A of its bell crank 370A. Inasmuch as the "zero" and "5" positions of the cam discs are primarily significant in respect of control of the gear segments 175A the corresponding relations are set forth in a chart at Fig. 34.

Neither the parcel devices PD nor the computing devices CD are punched with any control data in column twenty-seven of their control card related to control over the slide 120A1. The opening SO, Fig. 9, in the parcel device PD has a special attribute as will be mentioned. Therefore, at each occurrence of a computing or parcel device at the primary sensing station in the machine where the addresses are printed, the slide 120A1 will remain zeroized since none of the Bowden wires 100A for the slide 121A1 will be actuated. The pinion 365A therefore remains stationary so that all of the cam discs on the shaft 365A remain zeroized. When the dwell 399A of the cam 392A is presented to the follower 391A, the bell cranks 370A of the two cam discs 362A and 363A will rock counterclockwise as viewed in Fig. 29, since these two cam discs have recesses at their zero positions. Accordingly, the two micro switches 382A and 383A corresponding to the two cam discs 362A and 363A alone will be operated, and this has the effect of neutralizing registers AC2 and AC3 as will be mentioned. When the lobe or rise of the cam 392A returns to the follower 391A, arm 386A shifts to the right, shaft 375A rocks clockwise, and the pins 397A on the control arms 396A are effective to restore the bell cranks 370A to open the two switches 382A and 383A.

In like manner, when a delinquent device or a special assessment device carrying the register control code "5" in column twenty-seven of the control card thereon is sensed, only the cam disc 362A will present a recess to the sensing finger 377A of its bell crank 370A, and micro switch 382A is the only one of the three operated. This has the effect of neutralizing register AC2.

Thus, when a micro switch as 382A or 383A is thus operated, conditions are established which cause a corresponding gear segment 175A for accumulator AC2 or AC3 to be shifted from normal position aligned with the add rack 190A to an actuated neutral position between the add rack and the total rack 220A. It will be observed in this connection, that under the present circumstances, neither in its zero nor "5" position is the cam 361A effective to allow its switch 381A to operate. This is so because under the present tax bill circumstance, register AC1 from its automatic control aspect does not require a neutral position, but different circumstances may require use of switch 381A for control over accumulator AC1 to determine its activity state and hence the flexibility of the present control is obvious.

Each micro switch as 381A, 382A, or 383A when operated completes a circuit to a related solenoid 385A, Fig. 31, so that the armature 386A thereof is pulled down, and this operates a linkage arrangement causing the related rocking lever 320A1, 320A2 or 320A3 carried on the sub-total shaft to be rocked counterclockwise as viewed in Figs. 31 and 32 to bear against the outer end of the sleeve 176A which carries the gear segment 175A, and in this manner the gear segment is shifted to a neutral position between the add rack and the total rack. There are of course three solenoids 385A.

Thus, a vertical link 390A is connected to the armature 386A of each solenoid 385A, and the upper end of each link 390A is connected to a point on a related tri-

angular rocking plate 393A pivoted at 394A to a stationary arm 395A.

The link 390A is notched at 390N, and the switch blades of a holding circuit switch 391A are associated therewith. When link 390A is pulled down, switch 391A is actuated for purposes to be explained.

Each of the plates 393A at a point above the pivot 394A is connected to a horizontal arm 397A which is supported in the adding unit AU for lateral shifting movement. The end of each of the arms 397A opposite the end associated with a rocking plate 393A bears against the lower end of a related bell crank 400A pivoted on a shaft 401A at the side of the machine. The upper arm 402A of each bell crank 400A is connected to a vertical link 403A, and these links extend upwardly and are each connected as at 405A to respective arms 406A. The arms 406A are arms of bell cranks of which the rocking levers 320A1, 320A2 and 320A3 are the other arms, and in this way a rocking lever on the shaft 325A is rocked inwardly against the action of a spring 407A, Fig. 32, when a related solenoid 385A is energized upon closure of a related switch 381A, 382A or 383A. This positions the related gear segment 175A in its neutral position between the add rack 190A and the total rack 220A and the accuracy of such positioning is attained by the adjustable set screw 323A at the lower end of each rocking lever 320A1, 320A2 and 320A3, Fig. 22, and an adjustable nut 409A at the inner end of the link 397A, Fig. 31.

For purposes of clarity, the settings of the gear segments 175A in the three accumulators under control of the setting of the cam discs 361A, 362A and 363A in conformance with the "0" or "5" register control positions of the slide 120A1 are illustrated schematically in Fig. 33. Thus, in the idle or normal setting of the adding unit AU, the three gear segments 175A of the respective registers are normally disposed with their gear teeth in alignment with the add rack 190A. At zero, that is, "no code" setting of the slide 120A-1, the gear segment 175A in accumulator AC1 remains disposed in alignment with the add control rack 190A, whereas at this time, the other two gear segments 175A as was mentioned are shifted inwardly to a neutral position.

For register control code "5" setting of the slide 120A-1 (that is, for a delinquent or special assessment device) the gear segment 175A in accumulator AC2 is set in neutral position while the gear segments 175A in accumulators AC1 and AC3 remain engaged with the add rack 190A, so that at this time any delinquent or special assessment tax amount will be added both in accumulator AC1 and accumulator AC3. Thus, since the special assessment and delinquent devices follow the computing devices, the delinquent or special assessment amounts, if any, that are in the deck, will be added to the current tax standing in accumulator AC1, and will be independently added into accumulator AC3. As was mentioned, accumulator AC3 carries a running total of special assessment plus delinquent amounts.

In the instance of a parcel device carrying the code "2" in column twenty-seven of the control card thereon, such causes a sub-total to be taken from accumulator AC1, that is, the current tax, and printed on the bill in a manner to be described hereinbelow. The settings of the gear segments 175A under this circumstance are also shown in Fig. 33. It may be mentioned at this stage that under such circumstance, registers AC2 and AC3 are neutralized, as above described, because rack 120A-1 remains stationary.

Release of the hammer suppressing means

It was mentioned in connection with the forward setting of the slides 120A that type segments 110A are at the same time set up to print amounts represented by the slides 120A in their forward set positions. In order that no printing of the fractional tax amounts carried by computing devices will occur at the adding unit AU at least

until the sensing of a parcel device which requires a subtotal to be taken and printed at the adding unit, means are afforded to suppress operation of the hammers 112A which otherwise are normally effective to strike the lower edges of the type arms 110A in their set positions. Thus, as described fully in Patent No. 2,501,444, when a sensed amount is to be printed at the adding unit the type hammers 112A are released after the type arms 110A are set up, this being accomplished just prior to completion of the first half of the adding unit cycle of the machine upon release of a latch bar 420A, Fig. 10, carried at the upper end of a bell crank arm 421A that is fixed to a rock shaft 422A. Cam means operating between the main cam shaft 140A and the rock shaft 422A are effective to pivot the bell crank arm 421A in a clockwise or releasing direction as viewed in Fig. 10 at the proper time in the machine cycle, and when this occurs the type hammers 112A are normally freed to the action of relatively strong springs 425A for operating the hammers 112A.

Prior to the time when the slides 120A are to be restored, the hammers 112A are restored as described in Patent No. 2,501,444 by a restoring bail 430A, Fig. 10, that is cam controlled from the main cam shaft 140A. Thus, the bail 430A is adapted to be moved to the left as viewed in Fig. 10 at the proper time in the latter portion of the adding unit cycle to engage an inclined surface 431A forwardly of the pivot 433A for the hammers so as to restore the hammers in a clockwise direction as viewed in Fig. 10, and the latch bar 420A is then effective to retain the hammers in their restored positions.

Under the present invention, a hammer suppressor is afforded, which, until released, prevents operation of the hammers 112A even though the latch bar 420A for the hammers has been shifted to a released position in a cycle of the machine. In the present instance, the hammer suppressor takes the form of a blade 435A, Fig. 10, which has the upper edge thereof disposed beneath an arcuate surface 436A at the bottom of each of the hammers 112A forwardly of the pivot 433A. Thus, until the blade 435A is relieved relative to the surfaces 436A of the hammers 112A, the hammers 112A cannot be operated under the action of the springs 425A.

As shown in Fig. 36, the hammer suppressing blade 435A is mounted in a slot in a rock shaft 440A which extends laterally through the adding unit AU. At one end, the shaft 440A is provided with a relatively short link 441A, Fig. 37, and this link is connected to a relatively long link 442A which extends downwardly at the side of the machine to a pivot plate 445A to which it is connected. The pivot plate 445A is pivoted at 446A on a mounting plate 447A at the side of the machine opposite the total and sub-total shafts 325A and 330A, and at an intermediate section the plate 445A is connected to the armature 448A of a normally deenergized hammer suppressing solenoid 450A. When the hammer suppressing means is to be released under conditions to be described hereinbelow, the solenoid 450A is energized thereby causing the link 442A to turn counterclockwise as viewed in Fig. 10 to relieve the blade 435A relative to the edges 436A of the hammers 112A. This occurs, of course, at a time when the hammers are to be released for operation upon release of the latch bar 420A.

Accounting for mils

It will be appreciated that depending upon the tax rate and the value of the property to be taxed mils may be involved, and where mil amounts are involved the computed mil amount is punched in column twenty-six of the control cards on the computing devices. These mil amounts are sensed, and are transmitted to the column of the code translating or set-up mechanism 101A which corresponds to the slide rack next adjacent rack 120A1 which is allocated to register control as described above. Thus, as successive mil amounts on the computing de-

vices are transmitted to the adding unit these are added in the usual fashion, and any carry will represent one cent which will be carried over to the accumulator wheel 145A which is next adjacent the accumulator wheel 145A corresponding to the mil amounts. In this connection, it will be recalled that there is no printing of amounts from the computing devices.

Inasmuch as there may be a mil amount standing in the accumulator wheel 145W of register AC1 allocated to mils when the parcel device is sensed, a carry of one cent should be made in accordance with the usual practice if the mil amount thus standing in register AC1 is five mils or more. To enable such carry to be effected, the parcel device in each deck as shown in Fig. 9 is punched at 5M with a five mil amount.

Thus, upon the occurrence of a parcel device at the primary sensing station, the five mil punching 5M is sensed and is transmitted to the set-up station 101A, and when the slide racks are released for forward setting movement the slide rack 120A allocated to mils will be set in its digit five representing position. Therefore, if the related accumulator wheel 145W allocated to mils was standing in a five position or higher prior to the sensing of the punched data 5M in the control card of the parcel device the desired carry of one cent into the accumulator wheel allocated to cent tax amounts will occur. On the other hand, if the mil amount accumulated from the computing devices in prior sensing cycles was less than five mils there will be no carry of one cent.

Inasmuch as mils are not printed on the bill but only determine carries of a cent, no printing segment as 110A is required for the slide 120A corresponding thereto, and this is likewise true with respect to the slide 120A-1 allocated to register control. Moreover, since mil accounting is used only in register AC1 accumulator wheels 145A for mils are not required in registers AC2 and AC3.

Taking totals and sub-totals automatically-total unit

It was mentioned that when a parcel device is sensed, a sub-total is to be taken automatically from accumulator AC1 and printed at S on the bill, and that upon the sensing of the last device in the deck a total is to be taken from accumulator AC1 and printed at A on the bill. A new bill as B2 is then to be advanced forward in position to be printed with its sub-total amount. In these two instances of total operation, the sub-total and total shafts 325A and 330A are respectively actuated automatically in the proper sequence. It may happen of course that the parcel device is the last one in the deck, so that the "S" amount will first be printed, the bill advanced to position to be printed with the "A" amount which will be the same as "S" amount printed, and a new bill form fed forward at the adding unit. In achieving such automatic control over the accumulator registers, the sub-total shaft 325A is controlled by a vertical link 500A, Fig. 20, and the total shaft 330A is controlled by a second vertical link 501A.

At its upper end, the link 500A is loosely pinned to an arm 503A, Fig. 22, which is pivoted at 504A intermediate its ends on a bracket 505A. At the end opposite the end connected to the link 500A, the arm 503A is connected to a lever 506A which is fast on the sub-total shaft 325A adjacent the rear end thereof.

Fixed to the sub-total shaft 325A forwardly of the arm 506A is an arm 507A, Fig. 27, having a pin and slot connection 508A with a sub-total cam 509A. The cam 509A is mounted loosely on the total shaft 330A in a spring-biased position as described in Patent No. 2,501,444, and the way in which the sub-total cam 509A is controlled under the present invention will be described presently. A spring 510A, Fig. 22, is effective normally to dispose the link 500A in a rearward inactive position in a guide bracket 511A in engagement with the forward edge of a triangular cam plate 512A which is pivoted at 513A.

The link 501A which controls the total shaft 330A is likewise disposed adjacent its lower portion in a guide bracket 514A, Fig. 20. At its upper end, the link 501A is attached to a relatively short arm 518A, Fig. 31, which at its opposite end is fast on the total shaft 330A.

Each link 500A and 501A at its lower end is provided with a shoulder 520A and 521A, respectively, Figs. 22 and 31, and as described particularly in Patent No. 2,501,444 a rocking arm "240B" shown in Fig. 37 of that patent and illustrated in Figs. 11 and 12 hereof constantly rocks closely adjacent but normally spaced from the shoulders 520A and 521A. Thus, the rocking arm "240B" is normally ineffective with respect to the links 500A and 501A, but when either of the links 500A or 501A is shifted clockwise outwardly as viewed in Figs. 22 and 31 hereof the aforementioned shoulder thereon is in position to be engaged by said rocking arm "240B," and when such engagement occurs the corresponding link 500A or 501A pulled downwardly to rock the related total or sub-total shaft.

Some of the possible settings of the cams 335A1-2-3 on the total shaft 330A have been mentioned above. These settings are shown in Fig. 23, and as was mentioned such settings can be attained manually. However, when an automatic total is to be instituted by and under control of the last device in the deck, actuation of total control link 501A, in a way to be described, sets cams 335A1-2-3 in their first position shown whereat the total standing in register AC1, which is the total current tax, is taken therefrom, printed on the bill, and upon restoration of the slide 120A is transferred to register AC2 thereby clearing register AC1. The way in which the hammer suppressor 435A, Fig. 10, is released to enable a total to be printed will be described below. In this connection, it may be pointed out that since the total amount "A" on the bill, Fig. 8, alone is significant, the bill is blanked out at B0 so that totals in register AC1 which have no significance are not readable on the bill.

By setting cams 335A1-2-3 in their second position, a total of the various current tax amounts transferred to register AC2 can be taken and printed on a separate proof sheet as described in Patent No. 2,501,444 and by setting these cams in their third position a total of the various special assessment plus delinquent tax amounts transferred to register AC3 can be taken and printed in a like manner. These latter total operations are manual operations.

When a sub-total is to be taken, the control link 500A is shifted outwardly in position to be pulled down as was mentioned above causing the arm 506A and the sub-total shaft 325A, Fig. 22, to rotate clockwise. The arm 507A is likewise carried clockwise and this sets the sub-total cam 509A in position to effect the taking of a sub-total from register AC1. Thus, as shown in Fig. 27, the sub-total cam 509A has a projection thereon which in its set position engages the follower 336A1 which is carried by the rocking lever 320A1, and referring to Fig. 20, it will be noted that the sub-total control cam 509A and total control cam 335A1 are arranged substantially in side-by-side relation on the total shaft 330A. When engagement is thus established between cam 509A and the follower 336A1, the rocking lever 320A1 is shifted inwardly against the sleeve 176A of the gear segment 175A of register AC1, and the disposition of the parts is such that at this time gear segment 175A engages the total taking control rack 220A. When a sub-total is taken, the hammer suppressor is released to enable the sub-total to be printed as will be described.

Inasmuch as a sub-total is one that is taken from an accumulator register, printed, and then restored back to the register, means must be afforded to maintain the accumulator wheels of register AC1 not only in engagement with the slides 120A during forward zeroizing setting of the slides to enable the sub-total to be printed but also in engagement with the slides during rearward restoring

movement thereof. In other words, latching means are effective to prevent the reciprocatory movement of the total rack 220A which normally would be effective to rock the gear segment 175A of register AC1 in such direction as to enable register AC1 to be lowered from out of engagement with the slides 120A during rearward restoring movement of the slides 120A. The latch that is thus afforded for the total rack 220A is the same as that described in Patent No. 2,501,444 in connection with the sub-total operation there described, but briefly, and as shown in Figs. 27 and 28 hereof, a latch arm 530A is pivotally mounted adjacent the total rack 220A and tends to be urged upwardly by a spring 531A acting between the arm 530A and a post 532A, noting that in these figures the setting shown is one wherein the sub-total cam has been actuated to its sub-total control position. The latch 530A is formed with a shoulder 533A, and when the latch 530A is released as will be described, the shoulder 533A engages a tooth 535A on a bracket 536A which holds the total control rack 220A stationary so as to maintain register AC1 meshed with the slides 120A throughout substantially the entire sub-total taking cycle.

The latch 530A is normally held in an ineffective lower position by a projecting arm 540A, Fig. 27, on the sub-total cam 509A, that is, the arm 540A of cam 509A normally overlies the latch arm 530A to maintain the shoulder 533A disengaged from the latch tooth 535A. However, when the sub-total cam is in its set position as shown in Fig. 27, the latch arm 530A is released. As described in Patent 2,501,444, the same latch that is effective to hold the total shaft in a set position is also effective to hold the sub-total shaft 325A in a set position, and this latch is released at the end of a cycle in which a total or sub-total is taken to enable the related parts to restore.

Essential to actuation of the links 500A and 501A for instituting, respectively, automatic sub-total and total operations, is actuation of the respective cam plates 512A and 515A. This essential control aspect for positioning the links 500A and 501A is supplied by Bowden cables 526T2 (sub-total control) and 526T1 (total control) Figs. 22 and 31, which have terminal ends engaging projecting portions of the cam plates 512A (sub-total control) and 515A (total control) inwardly of the pivot points for these cam plates. Thus, when either cable 526T2 or 526T1 is actuated, it is effective on the lower edge of the related cam plate 512A or 515A to rock such cam plate counterclockwise as viewed in Figs. 22 and 31 forcing the related link 500A or 501A outwardly to dispose the shoulder 520A or 521A in the path of the rocking arm "240B" which is described in Patent No. 2,501,444, and it should be pointed out that these control cables are identified by like reference characters in Patent No. 2,501,444. When so disposed in the path of the rocking arm "240B," the shoulder 520A or 521A is engaged causing the link 500A or 501A to be pulled down and the related total taking cam 335A1 or the related sub-total taking cam 509A to be actuated.

The total unit controlling sub-total and total operations is illustrated generally at 590A, Fig. 38, and in many respects this total unit is similar to that described in Patent No. 2,501,444. Thus, the total unit 590A includes a constantly driven drive shaft 591A associated with a sprocket 592A and drive is extended to the sprocket 592A from the constantly driven gear of the adding unit AU. As described in Patent No. 2,501,444 a pair of normally idle drive sleeves are concentrically associated with the drive shaft 591A of the total unit 590A, and these sleeves are adapted to be independently coupled to shaft 591A through respective clutches. Such sleeves are shown schematically at 600A and 601A, Fig. 39, and are under control of respective solenoids 602A and 603A, solenoid 602A when energized instituting a sub-

total operation, and solenoid 603A when energized instituting a total taking operation.

Mounted on the sleeve 600A is a cam disk 604A representing a clutch holding sleeve 600A stationary through a dog 605A associated with a control arm 606A under control of the armature 608A of solenoid 602A. When solenoid 602A is energized, the dog 605A is disengaged from a corresponding notch in the cam disk 604A, and this allows sleeve 600A to be driven by shaft 591A as described in Patent No. 2,501,444. Cam disk 604A thus commences to drive, and a cam 609A thereon soon engages an actuating lever 610A which when actuated drives forward the subtotal control cable 526T2 mentioned above.

The same kind of control is afforded for a disk 615A associated with solenoid 603A, and when disk 615A rotates a related cable 526T1 is actuated by a cam 616A to institute a total operation as above described.

The electrical circuits for solenoids 602A and 603A are shown schematically in Fig. 39 and will be described in more detail below. Thus, circuit to solenoid 602A is extended through normally open switch contacts E210 of a relay SR to be described. Circuit for relay SR includes a normally open switch E170 adapted to be closed by the sensing cable at station SS which is actuated in the second run on the bill when a control card CC is sensed having code "2" punched in column twenty-seven thereof.

Circuit to solenoid 603A is extended through normally open contacts E266 of a relay AR to be described. Circuit for relay AR includes a normally open switch E230 at the sensing station SS adapted to be closed in the way mentioned above when a device as D bearing a tab in the No. 1 position is sensed.

Proof sheet printing

As described in Patent No. 2,501,444, numerical data set up by the printing segments 110A in the present instance are adapted to be printed on a proof sheet, and under the present circumstances such proof sheet printing may be advantageously carried out during the first run on the tax bill at the time when the tax bill is being printed at the printing station PRS from embossed type characters carried on the print plates of the parcel devices. Thus, it may be advantageous for purposes of cross checking amounts and totals to print on a proof sheet during the first run on a tax bill numerical data carried by the control cards on the parcel devices. As was mentioned above in connection with Fig. 1, a roll of paper 400 may be provided at the adding unit in the first run of the tax bill, and it will be appreciated that during the second run on the tax bill such paper roll is removed to accommodate the specialized sheet feeding apparatus shown in Fig. 2. The spindle for the paper roll 400 is so arranged at the rear of the adding unit as to enable the sheet to be passed beneath the platen 114A, Fig. 10, this being the arrangement shown in Patent 2,501,444, and as described in that patent means operating under control of a cam on cam shaft 140A, Fig. 10, are effective to feed the sheet forwardly one space each time the adding unit goes through a print cycle. Thus, as shown particularly in Fig. 12 hereof, an arm 700A is extended upwardly from the cam shaft 140A to a bell crank 701A which operates a rack 703A associated with a drive pinion 705A, Fig. 11, mounted on the shaft of the platen 114A. The lower end of the arm 700A is provided with a cam roller that engages a paper feed cam on the cam shaft 140A.

As described in Patent No. 2,501,444, the arrangement is such that single line spacing is normally imparted to the platen 114A after an amount has been printed on the proof sheet. However, a latch 707A, Fig. 12, when released from engagement with the bell crank 701A enables a long feed to be imparted to the proof sheet, and this occurs after a total has been printed on

the proof sheet. The latch 707A is under control of a solenoid identified as E430 in the wiring diagrams, and of course the solenoid E430 is effective only under the specialized circumstance of proof sheet printing as will be explained.

FIGS. 39 TO 48.—INTERCONNECTIONS CONTROLLING THE UNITS

First run on the tax bill—station PRS

- 10 The first run on the tax bill fan-fold BFF in the printing machine unit 100 is one concerned primarily with the imprinting of the individual bills from the embossed data on the parcel devices at the primary printing station PRS, which is to say that on the first run the bills are imprinted with the fixed or predetermined data embossed on the printing plates carried by the parcel devices. During this first run, the only devices in each deck for each taxpayer are the parcel device and a special assessment or delinquent device if in fact either of the latter is present in a deck. Thus, in the first run on the tax bill, computing devices CD, Fig. 9, are not present inasmuch as these are not a permanent aspect of any deck and are worked into the deck only for tax purposes related to the second run on the tax bill at which time the bills are printed with tax amounts in the adding unit AU described above.
- 15 Accordingly, the printing and control devices PD, DD and SAD required for the first run on the bill are arranged in the supply magazine SM of the printing machine unit 100 with the parcel device PD as the leading device in each instance, and when the primary printing machine unit 100 is started for its automatic operation the devices are passed one by one by the reciprocating carrier bars 120, Fig. 3, to the sensing station SS and
- 20 then in subsequent cycles to the printing station PRS where the bills are to be imprinted from the parcel devices, this feeding operation of the printing and control devices being described in full in Patent No. 2,568,064.
- 25 The fundamental sensing operation involved at this time is one that results in each parcel device being halted at the printing station PRS to imprint the related bill form, with each special assessment and delinquent device present being skipped past the printing station without operation of the platen 103. After each such bill form as B1
- 30 is printed by printing plate embossures, a new form as B2 is fed to printing position, but this occurs only as an incident to operation of the platen 103 and return thereof to home position. Simultaneously, a proof sheet can be printed at the adding unit AU with the sensed amounts
- 35 carried on the control cards CC of the parcel devices.

The machine includes a drive motor DM shown in the wiring diagram as connected by wires E1 and E2 to a plug P1 through normally open manual switches E5 and E6, and when these switches are closed the drive motor is energized. However, the motor DM is ineffective at this time to impart any drive to the printing machine unit 100 or to the adding unit AU, since the master clutch 155 so identified in Patent No. 2,568,064 mentioned above is not engaged at this time nor is the adding unit clutch 246 so identified in Patent No. 2,501,444.

The master clutch is under control of a solenoid E8 shown in the wiring diagram and the circuit for the master clutch solenoid E8 includes a normally closed switch E9 under control of a total relay AR to be described below, a normally closed foot control switch E10, and a "last plate" switch E13 which continues to be held closed so long as there is a printing device in the supply magazine. Circuit is extended from the switch E13 to a manually controlled momentary start-stop switch E14, and the start position of this switch is normally open. The circuit for solenoid E8 is extended from the stop side of the switch E14 through wires E3 and E4 to level PS-1 of a program switch. The program switch has many levels as will be described, and from this switch 75 circuit for solenoid E8 is completed to wire E7 con-

nected to the other side of the power source. Each level of the program switch includes an "S" contact (standard), a No. 1 contact (first run) and a No. 2 contact (second run), and in accordance with the designation of these three possible settings the program switch is on its No. 1 contact for the first run on the tax bill.

The master clutch solenoid E8 is energized by operating switch E14 to its start position. When the master clutch solenoid E8 is energized to engage the master clutch, an arm under control of the solenoid is effective to close the contacts of a normally open switch E15 which is in a holding circuit that shunts around the start switch E14. Thus, circuit is extended from switch E15 to a normally closed foot operated stop switch E16. From switch E16 the holding circuit has two possible paths, one through an automatic tab stop switch E17 which is normally closed and which is adapted to be conditioned for opening by a properly located stop tab provided on a printing device which is one predetermined to stop the machine. A tab of this kind is like the tabs CT described above as adapted to be selectively located in a mounting pocket at the upper edge of the frame of a printing and control device as shown in Fig. 9. From the tab stop switch E17, circuit is extended back to the stop side of the start-stop switch E14. Therefore, when the master clutch pulls in, a holding circuit is extended around the start-stop switch E14.

In the event that it is not desired to use a stop switch E17, the switch E17 is shunted by closing manually a switch E20, and when this switch is closed the holding circuit for the master clutch solenoid E8 is independent of the tab stop switch E17.

As was mentioned, solenoid E8 when energized is effective to pull in the master clutch of the machine as described in Patent No. 2,568,064, and when this occurs the carrier bars 120 described above for feeding the printing devices are effective to advance the printing devices one by one to the sensing station.

At the sensing station, the pins 220 and 240 in the sensing head SH are effective in each cycle of the machine to sense for tabs of a particular kind and also to sense the punched openings in the control cards on the printing and control devices. This determines the "print" or "skip" control that is to be established at the printing station PRS and also whether or not sensed data on the control cards of the devices are to be transmitted to the adding unit AU.

It will be observed in Fig. 9 in this connection that the delinquent and special assessment devices carry control tabs CT. The frames F of the printing and control devices have twelve mounting pockets for such tabs. Tab CT on the device DD is notched, whereas the tab CT on the device SAD is full. What this amounts to is that tab CT on the device DD occupies No. 13 tab position while tab CT on the device SAD occupies both a No. 1 and No. 13 tab position. A No. 13 tab calls for the corresponding device to be skipped through the printing station PRS, while the parcel device having no tab as CT at No. 13 position is to be held at the printing station and the platen 103 operated. The feeding of the fan-fold bill form is at the same time determined by the presence or absence of a No. 13 tab, and also whether or not the adding unit is to be operated simultaneously through a cycle for receiving and printing on a proof sheet at the adding unit the numerical data punched in the control cards CC of the devices being used in this run.

As was mentioned above, the printing station PRS of the machine where the bills are to be imprinted by embossed data on the parcel devices is provided with a reciprocating roller platen 103 which when operating is effective to cause a particular bill form to be printed. The platen operating structure is controlled by a corresponding platen clutch as described above in connection with Figs. 6 and 7 so that an imprint is effected

only in those instances where the platen clutch is pulled in.

Tab sensing determines whether or not the platen clutch is to be pulled in. Thus, the platen clutch is controlled by a platen delay solenoid E30, and as explained above this solenoid when energized positions a delay or storage pin on the storage drum in the printing machine unit 100 which in turn trips the platen clutch at the proper cycle in the machine, inasmuch as each printing 10 and control device as D after being sensed has to travel through several cycles of machine operation to the printing station, and, therefore, storage means of the aforesaid kind are required. The platen control solenoid E30 is connected through deck or level PS-2 of the program switch, and this level of the program switch is set to its No. 1 contact as was mentioned for the first run of the bill. From level PS-2 of the program switch, circuit is extended to a safety switch E36 known as a "V-notch switch" which was mentioned above in connection with the general description of the machine unit 100. Switch E36 is closed only when a printing device is properly oriented at the sensing station. It will be observed that the safety switch E36 is connected directly to one side of the power source.

25 The other side of solenoid E30 is connected to normally open contacts E37 of a timing relay TR, and the contacts E37 are connected to the other side of the power source. It will be thus seen that when the safety switch E36 is closed and the program switch is in its No. 1 setting the platen control solenoid E30 will be energized when the normally open contacts E37 are closed. The normally open contacts E37 close when the timing relay TR is energized, and the way in which this is accomplished through a rotary selector switch E40 that operates in accordance with tab sensing will now be described.

30 The selector switch E40 was mentioned above in connection with the general description of the machine unit 100. Although there are some differences, switch E40 is operated essentially in the manner described in Patent 35 No. 2,568,064, that is, as an incident to operation of the sensing head SH and contact between a tab sensing pin as 240, Fig. 4, carried by the head SH and tabs as CT on the printing and control devices thus undergoing sensing at the sensing station. In the present instance, switch E40 is rotary, and in Patent No. 2,568,064 the corresponding switch 265 so identified in the patent operates in a linear fashion. The timing relay TR as will be observed is connected at one side of the power source when the V-notch safety switch E36 is closed. The other side of the timing relay TR is connected to level PS-3 of the program switch which is in its No. 1 setting. Circuit is further extended to No. 1 contact of level PS-4 of the program switch, and from program switch level PS-4 of the program switch through normally closed contacts E41 of a control relay CR, and from the contact E41 to contact No. 3 of the selector switch E40. The control relay CR is not operative in this run, and hence the contacts E41 remain closed.

35 The selector switch E40 is provided with a rotary wiper E45 having switch arms E46, E47 and E48 fixed thereto. The switch contact E47 is provided with a crescent shaped contact E49. In its normal setting, the arm E46 of the wiper E45 is normally on contact No. 3 of switch E40, and one end of the arm E49 is extended to a wire E51. Wire E51 is connected to the contacts of a normally open switch E52 which is under control of a timing cam 52CM, and this timing cam rotates in each cycle of the printing machine unit 100 when the master clutch referred to above is pulled in upon energization of solenoid E8. In other words, as shown in the timing diagram of Fig. 43 switch E52 is closed by its cam toward the end of a cycle of unit 100 and is open at the end of the cycle.

40 From switch E52, circuit is extended to a safety switch E53, and this switch is closed when the carrier bars 120

used to feed the printing devices D are at the forward end of their stroke, that is, have fed a printing device to the sensing station as was mentioned above.

If the printing device undergoing sensing is a parcel device having no tab at No. 13 position, the timing relay will be energized, since the selector switch E40 remains restored, and this will close switch E37 enabling the platen delay solenoid E30 to energize thereby establishing a storage condition as described which will cause the platen 103 to be operated in that cycle of the machine wherein the parcel device thus sensed is at the printing station.

The tax bill fan-fold has of course been arranged to feed through printing station PRS of the machine 100 as shown in Fig. 2 so that a new bill form as B1 is in position to receive an imprint from an operative parcel device when the platen 103 is thus operated to bring about engagement between the bill form, the two embossed printing plates carried by the parcel device PD, and an inked ribbon (not shown) interposed between the parcel device and the bill form. An ancillary feature of the machine is that the adding unit AU operates through a cycle at the same time, but this need not be explained at this point.

After a bill form B1 has been printed in this manner with data AD and TD, Fig. 8, it is of course necessary to advance the next form as B2 forward to the printing station in position to be printed. As was mentioned, the sheet feed means thus utilized is of the kind described in Patent No. 2,700,334. There is, however, this difference, namely, the gearing used to operate the drive shaft of such fan-fold means is in the present instance driven by a motor SRM, Fig. 40 and the wiring diagram, which is energized for an amount of time required to feed forward each new bill form to the printing station PRS. Thus, for the first run on the tax bill, a new bill is to be advanced to the printing station each time the platen of the printing machine unit 100 operates. In other words, the motor SRM will drive through a full cycle as will be described in more detail below.

To enable this to be accomplished, circuit is extended by a wire E55 from one side of the power source to a cover switch E56 which will be closed when the fan-fold feeding attachment is properly in position on the machine either at the printing machine unit 100 or the adding unit AU. Circuit is further extended from switch E56 to a normally open stop pawl switch E57 the operation of which will be described below. Circuit is further extended to a normally closed home position switch E58, and a wire E59 is extended from the other side of motor SRM to the other side of the power source as will be observed.

The motor SRM is under control of a homing solenoid E60 and a short space solenoid E61. The solenoids E60 and E61 are connected at one side by a common wire E65 between the switches E56 and E57. Solenoid E60 is connected to the other side of the power source through a normally open switch E66 under control of a corresponding relay SR-1. In like manner, solenoid E61 is connected to the other side of the power source through a normally open switch E69 under control of a corresponding relay SR-2.

Relays SR-1 and SR-2 are timed by normally open timing switches E70 and E71 which are in parallel and associated with related timing cams 70CM and 71CM affording accurate settings for timing relays SR-1 and SR-2. The cams 70CM and 71CM are associated with the driven shaft for platen 103, so that the related switches are closed only upon operation of the platen 103 as will be explained in more detail. Thus, the switches E70 and E71 are wired by a wire E75 to one side of the power source. For the other side, a wire E78 is extended to level PS-5 of the program switch, and circuit extends from level PS-5 to relay SR-1, and from relay SR-1 through normally closed contacts E80 of what will be

referred to as a sub-relay SR. So long as relay SR is de-energized, as it will be for the first run, relay SR-1 will energize upon closure of a timing switch E70 or E71. Relay SR-2, it will be noted is connected to level PS-6 of the program switch which, it will be observed, is open at its No. 1 position, so relay SR-2 will not be operative in the first run to control its solenoid E61.

It will thus be seen that relay SR-1 will not energize until a timing switch E70 or E71 is closed by its cam, but the cams 70CM and 71CM are operative in a rotative sense only when the platen 103 is actuated. Moreover, the timing is such as shown in the timing diagram of Fig. 43 that the switches E70 and E71 are not closed until toward the end of a cycle subsequent to a bill form being printed by the platen 103.

Before describing the way in which the motor SRM is energized for accurately spacing the bill forms subsequent to a print being made at the printing station PRS, it should be explained that motor SRM will not be energized upon the occurrence of a delinquent or special assessment device, and this failure of the motor SRM to operate occurs as an incident to failure of the platen 103 to operate when a special assessment or delinquent device is at the printing station. As was mentioned, these two kinds of devices are tabbed at No. 13 tab position, and a special tab sensing pin as 240, Fig. 5, is allocated thereto in the sensing head SH. Such No. 13 tab when sensed causes the selector switch E40 to be so set that its arm E46 is on no contact, arm E48 is on contact No. 4, and the crescent arm bridges contacts Nos. 5 and 6 of the selector switch E40. This completes circuit only to a bell delay solenoid E90 when the timing relay cam switch E52 closes. Thus, the timing relay is not energized since arm E46 is on no contact of the selector switch E40. Consequently, switch E37 remains open and the platen delay solenoid E30 receives no pulse. Therefore, the platen will remain stationary when a special assessment or delinquent device arrives at the printing station, the cam switches E70 and E71 remain stationary and motor SRM is not energized. Moreover, the adding unit AU is not operated.

As shown schematically in Fig. 40, a timing disc E95 is co-axial with the motor SRM, and the timing disc is driven by the motor. The timing disc E95 is formed with motor timing elements which are here shown as cam notches, and for the present purposes, it can be assumed that the timing disc has a home position notch E96-1 corresponding to the position "A," Fig. 8, on the tax bill forms where a total can be properly printed, a new bill notch E96-2 which corresponds to the sub-total indicia receiving position "S" that is shown on the tax bill forms of Fig. 8, a notch E96-3 corresponding to the position on the bill where the delinquent amount is to be printed, and finally a notch E96-4 corresponding to the position on the tax bill where the special assessment amount is to be printed. Driven in timed relation with the timing disc E95 is a cam tooth E97, and it can be assumed that the cam tooth E97 projects from the back of the timing disc.

A stop pawl E98 is adapted to engage in any one of the timing notches, and when engaged with a timing notch sets the switch E57 in its open position. When the stop pawl is withdrawn, switch E57 is closed.

Associated with the cam tooth E97 is an actuating arm E99 of the home position switch E58, and the relation can be viewed as a dead center action, which is to say that as the cam tooth E97 travels past the actuating arm of switch E58, switch E58 is opened momentarily to break circuit to the motor SRM and then switch E58 assumes its closed position. The stop pawl E98 is under control of solenoids E60 and E61. When the solenoid E61 is energized, the stop pawl E98 is pulled away from the timing disc, closing switch E57, and since switch E58 is closed at this time the motor drives. When thus under control of the solenoid E61, the stop pawl is released

shortly after the motor SRM commences to drive, and so is conditioned to drop into the next notch, say E96-2, on the timing disc, thereby breaking the circuit to the motor SRM. When, however, the homing solenoid E60 is energized, the stop pawl E93 is again withdrawn, closing switch E57 as mentioned above, and is held in withdrawn position as illustrated in Patent No. 2,700,334 until the last of the notches, namely, E96-4, on the timing disc E95 has passed the stop pawl so that the stop pawl E93 when conditioned by the homing solenoid E60 does not engage any of the three notches E96-2-3-4 associated with short spacing of the tax bill and homes from and to notch E96-1.

In the first run of the tax bill, solenoid E60 is alone used, since at this time it is required to space the tax bill at its full length, that is, the timing disc on motor SRM travels repeatedly from and to home position.

It will thus be seen that so long as normally closed switch E80 associated with the sub-relay SR is closed, relay SR-1 will energize with the program switch in its No. 1 setting upon closure of a timing switch E70 or E71. Such closure of the timing switch occurs only as an incident to return of the platen 103 at the printing station PRS to its at rest position as mentioned, so consequently, after a particular bill form has been imprinted from embossures at the printing station PRS, the fan-fold feed motor SRM is effective to advance a new bill form to the printing station PRS.

First run on the tax bill—adding unit listing

It is advantageous during the first run on the tax bill through the primary printing unit 100 to print on a proof sheet at the adding unit AU as described in Patent Nos. 2,501,444 and 2,568,064, the data carried on the parcel devices in the form of punched openings on the control cards CC thereof. These data are restricted to register AC1 and registers AC2 and AC3 are to be neutralized during such proof sheet printing so that the total amount of assessed property valuations can be determined by taking a total from register AC1 at the end of the first run on the tax bill.

Operation of the adding unit AU is incidental to energization of the timing relay TR each time a parcel device is sensed in the manner explained above. The precise way in which the adding unit operates in the first run will be apparent from the second run on the tax bill to be explained in detail below, but briefly the sequence is as follows:

(1) Sensed punched hole data of a parcel device are transmitted from station SS of machine unit 100 to station 101A of machine unit AU in the usual fashion.

(2) Timing relay TR energizes to start an AU cycle and control relay CR remains deenergized as will be explained.

(3) Registers AC2 and AC3 are neutralized upon closure of a timing switch E141 to be explained. Slides 120A set up.

(4) Sensed parcel device amounts are printed on the proof sheet at the adding unit AU by energizing the solenoid 450A described above to release the type hammers 112A.

(5) Slides 120A restore and amounts are entered only in register AC1.

(6) Proof sheet is fed for the next item as explained in Patent No. 2,501,444.

(7) Sensing cables 100A are restored mechanically by unit AU as described in Patent No. 2,501,444.

Failure of the timing relay TR to pull in upon the occurrence of a special assessment or delinquent device at the sensing station SS determines that the adding unit is not cycled in the first run on the tax bill. Consequently, the punched hole accounting data carried on the control cards CC of these devices are not acted upon by the adding unit. Since the cables 100A are nevertheless set up, these must be restored other than by the cam operated

cable restoring means operated from the main cam shaft 140A of the adding unit AU (inoperative at this time) as described in Patent No. 2,501,444. Such restoration of the cables 100A is under control of solenoid E100 shown in the wiring diagram as connected to one side of the power source by wires E101 and 102. This solenoid corresponds to solenoid 224 of Patent No. 2,501,444. The other side of solenoid E100 is connected to a normally open switch E105 controlled by a cam 105CM which is effective in each cycle of the machine unit 100 wherein the master clutch is operative. The timing for cam switch E105 is shown in the timing diagrams. From switch E105, circuit for the other side of solenoid E100 extends to normally closed contacts E106 under control of the timing relay TR, and from thence to the carrier bar safety switch E53.

It is advantageous to number the entries printed on the proof sheet at the adding unit during the first run on the bill, and the numbering attachment described in Patent No. 2,501,444 enables this to be accomplished. Thus, by presetting the numbering attachment for serial numbers that may appear on the tax bill as shown in Fig. 8, corresponding numbers can be listed on the proof sheet for cross-checking. To this end, a numbering solenoid EN for controlling the numbering attachment 543 of Patent No. 2,501,444 is afforded at the adding unit. This solenoid EN enables the related numbering attachment of Patent No. 2,501,444 to operate only when deenergized at times when the hammers 112A are operated, and is used only on the first run of the bill for numbering the proof sheet as was mentioned or on the run of the machine with the program switch on its "S" setting. Thus, the numbering solenoid EN is connected at one side to a wire E146 to be described leading to one side of the power source, and at the other side solenoid EN is connected to the switch blade of level PN of the program switch. Contact No. 2 (second run of the machine) of level PN of the program switch is wired to the other side of the power source through timing switch E141 to be described. The "S" and No. 1 contacts of switch level PN are open, and the numbering attachment of Patent No. 2,501,444 operates when program switch level PN is on either of these two settings. When the program switch is set for the second run of the machine to be described below, solenoid EN will be held energized inasmuch as No. 2 contact of switch level PN completes circuit to switch E141 which is closed substantially for the entire cycle of the adding unit, and solenoid EN when thus held energized serves to operate a mechanical lock-out device described in Patent No. 2,501,444 as rendering the aforesaid numbering attachment ineffective at certain times.

Second run on the tax bill

The fundamental operations described above in connection with the first run of the tax bill had merely to do, when considered in its broadest aspect, with the way in which the parcel devices alone control operation of the imprinting platen 103, the return of the platen to its initial position after effecting an imprint being accompanied by closure of the timing switches E70 and E71 causing in turn a new bill to be fed forward to printing position by the motor SRM. These operations were programmed by the program switch in its No. 1 setting. For the second run of the tax bill now to be described the program switch is set to its No. 2 setting. Further, sheet feed means of the kind described in Patent No. 2,700,334 is now to operate at the adding unit AU where the tax amounts are to be printed on the bill forms as B1 and B2.

Previous to the second run on the tax bill, the computing devices CD described above are selected for each deck and are worked into the decks ahead of the parcel devices PD so that these are the first fed through the machine. It will be appreciated that the printing devices in this instance are again arranged in the supply magazine SM of the machine and are fed to the sensing station SS

in the usual fashion. However, no imprinting is to be effected at printing station PRS in this instance, and any printing that is accomplished occurs as an incident to setting of the type segments 110A of the adding unit AU. In this connection, it will be observed that upon setting of the program switch to its No. 2 setting, level PS-2 of the program switch breaks circuit to the platen solenoid.

It is of course necessary in the second run of the tax bill to have the master clutch of the machine unit 100 pulled in, and the circuit whereby this is accomplished is not the same as described above. Thus, it will be observed that level PS-1 of the program switch which was in the circuit of the master clutch solenoid E8 for the first run does not contact wire E4 in its No. 2 setting. Instead, a shunt circuit is extended from wire E3 around switch level PS-1 to a normally closed switch E170 to be described and from switch E170 through a wire E107 to one side of the power source. Accordingly, when the start switch E14 is operated, the circuit for solenoid E8 includes switch E170 which is closed. Solenoid E8 energizes, the printing and control devices are advanced one by one from the supply magazine to the sensing station SS, and the sensing head SH is effective through its usual sensing stroke in each cycle of the machine unit 100.

It was mentioned above in connection with the first run of the machine that a special pin at 240 was used to prevent operation of the platen delay solenoid E30 upon the occurrence of a special assessment or delinquent device bearing a No. 13 tab at the sensing station. Such pin is known as a "reversing" pin, but in this run of the machine a "regular" pin is used at 240, and the result of this will be pointed out below.

It is of course essential in this second run that the adding unit be cycled each time the sensing head SH operates which is every cycle of the primary printing unit 100, and accordingly the way in which the selector switch E40 in the second run on the tax bill is effective to start the adding unit AU in operation will now be described.

The adding unit AU is set in operation by a solenoid E110 which when energized enables the clutch to engage which transmits power to the main cam shaft 140A of the adding unit, and in this connection it may again be pointed out that this clutch is the clutch 246 described in Patent No. 2,501,444 which when engaged drives the cam shaft 108 of Patent No. 2,501,444 corresponding to cam shaft 140A in the present instance.

Solenoid E110 is connected to one side of the power source by wires E101 and E102 mentioned above, and to the other side of the power source in part by wires E112 and E113 through level PS-7 of the program switch, the program switch in each level now being on its No. 2 contact. The circuit is extended from level PS-7 of the program switch to normally open contacts E115 under control of the timing relay TR, and from the normally open contacts E115 through the carrier bar safety switch E53 to the bus on the other side of the power source. This circuit is the same for No. 1 and No. 2 setting of switch level PS-7, so it will be seen that in the first run on the tax bill solenoid E110 will energize to start the adding unit in each cycle where the timing relay TR is energized to close switch E115. For the first run, this occurs each time a parcel device PD having no No. 13 tab is sensed.

Thus, when the timing relay TR energizes, solenoid E110 will be energized to institute engagement of the clutch "246" mentioned above used to impart drive to the cam shaft 140A of the adding unit AU, thereby setting the adding unit in operation.

Second run—computing devices

It will be recalled that a computing device CD when stopped at the primary sensing station SS will have its numerical data sensed and set up at station 101A of the adding unit. Being a computing device, these numerical data are to be accumulated only in register AC1 of the

adding unit AU. This of course requires operation of the adding unit as afforded by energization of the clutch control solenoid E110 and also requires registers AC2 and AC3 to be set in neutral position during restoration of the slides 120A.

5 Additionally, the bill forms which are now being fed through the adding unit AU between the platen 114A of the adding unit and the type segments 110A is to be held stationary, since amounts carried by the computing devices are not to be printed by the adding unit, and moreover the hammers 112A normally operative to print an amount set up by the slides 120A are to be suppressed. These control aspects emanate from the selector switch E40 and the program switch which will be recalled as on its No. 2 setting, and the 10 way in which these control aspects are accomplished will 15 now be described.

The computing devices carry no sensing tabs such as the tabs CT shown in connection with the special assessment and the delinquent devices. Accordingly, when 20 a computing device is sensed at station SS, the mounting bar on the sensing head SH on which the tab sensing pins as 240 are located remains stationary and the selector switch E40 remains in its restored position. The timing relay is therefore energized as follows:

25 The V-notch safety switch E36 is assumed to be closed. Circuit extends from the timing relay TR to level PS-3 of the program switch on its No. 2 setting. Circuit is then extended through wires E120 and E121 to the normally open contact E122 of the control relay CR. However, this contact does not close until the 30 control relay is energized, and the control relay is energized as follows: Wire E125 extends from the side of the control relay opposite the side associated with the switch E36 to level PS-4 of the program switch on its No. 2 setting, and from level PS-4 through the normally closed contacts E41 of the control relay No. 3 contact of the selector switch E40, the normally open timing relay cam switch E52 mentioned above, and normally closed carrier bar safety switch E53 to the other side 35 of the power source. The master clutch of the printing machine unit 100 is of course engaged, and consequently switch E52 will be closed eventually at the proper time thereby energizing the control relay CR.

Control relay CR will not energize in the first run, 40 because circuit thereto is broken at PS-4.

45 When the control relay CR is energized in the second run, its contacts E122 close, and the timing relay TR is energized. Nothing happens to the platen delay solenoid E30, because circuit to this solenoid is broken at level PS-2 of the program switch, and it may be mentioned 50 that this condition prevails throughout the second run.

When the timing relay TR energizes its normally open contact E115 closes, and therefore the adding unit clutch control solenoid E110 energizes, causing the adding unit AU to cycle.

55 The slides 120A in the adding unit accordingly are set up in accordance with the punched hole data in the computing device transmitted to the set-up station 101A of the adding unit AU.

60 The control relay establishes its own holding circuit as follows: through its normally open contacts E127 which close when CR energizes; through wire E128 to a normally closed switch E129 under control of a cam 129CM on the main cam shaft 140A of the adding unit AU; through a normally closed switch E130 controlled 65 by a cam 130CM carried on sleeve 600A of the total unit 590A; and through a wire E131 to the other side of the power source. Consequently, the control relay is held in at this particular time until switch E129 reverses (opens circuit to relay CR) late in the adding unit cycle 70 as will be observed from the timing charts. The total unit 590A is not in operation at this time, so switch E130 remains in its normal setting shown.

As was mentioned above in connection with control over the registers AC1, AC2 and AC3, solenoids as 75 385A, Fig. 31, when energized upon closure of a related

switch 381A, 382A, or 383A shift the gear segments 175A from an add position to a neutral position, and it was also mentioned that upon actuation of the corresponding link 390A a holding switch 391A is closed. In the wiring diagram, the corresponding solenoids for registers AC2 and AC3 are identified as the solenoids E132 and E133 respectively, and the associated holding switches are identified as E132H and E133H. The control switches 382-3A mentioned above are shown in the wiring diagrams as switches E132A and E133A corresponding to registers AC2 and AC3 respectively.

It will be further recalled that the computing devices have no punched opening in column 27 of the control cards thereon. Therefore, when a computing device is sensed in the second run the register control slide 120A1 remains in restored position, and incidental to this sole-noids E132 and E133 are both energized upon closure of switches E132A and E133A. At the same time, the holding switches 132H and 133H are closed to thereby hold the respective solenoids E132 and E133 for registers AC2 and AC3 energized until dropped out by a timing switch as will now be described.

Thus, wires E134 and E134' are common to switches E132A and E133A, and wire E134 is connected to one side of the power source through wire E101. Another wire E135 is directed to one side of the power source, and is connected to the holding switches 132H and 133H, as will be observed. The other sides of the solenoids E132 and E133 are connected to a common wire E139, and wire E139 is associated with a wire E140 that leads through a normally open switch E141 having a timing cam 141CM, and circuit is extended from switch E141 to the other side of the power source. The timing cam 141CM is mounted on the cam shaft 140A of the adding unit AU, and as shown in the timing diagrams this switch is closed for substantially the entire cycle of the adding unit. Accordingly, registers AC2 and AC3 are adapted to be neutralized at about 130° in the adding unit cycle at the time when switches E132A and E133A are closed.

In the first run, registers AC2 and AC3 are neutralized at the instant when switch E141 closes practically at the commencement of the cycle of the adding unit each time a parcel device is sensed at the sensing station SS. The way in which this occurs will be explained below.

Inasmuch as amounts on the computing devices transferred to the adding unit in the second run are not to be printed on the bill at the adding unit AU, the hammer suppressing blade 435A must be held in the position shown in Fig. 10 which means that its solenoid 450A, Fig. 37, is to be held deenergized. Solenoid 450A is identified in the wiring diagram as solenoid E145. This solenoid is connected by wires E146 and E147 to the wire E101 mentioned above so as to extend circuit for solenoid E145 to one side of the power source. The other side of solenoid E145 is connected by a wire E150 to normally closed contacts E151 under control of the control relay CR, and from the normally closed contacts E151 circuit is extended by wire E155 to wire E140 that leads through the timing switch E141. However, it will be recalled that for a computing device at station SS the control relay CR was energized. This opens the contacts E151, breaking circuit to solenoid E145 which continues to hold the type segment hammers 112A inoperative, and in this way the computing device tax data that were transferred from the sensing station SS as to the set-up mechanism 101A of the adding unit are not printed on the bill but merely accumulate in register AC1.

In the first run on the bill through station PRS, the control relay CR, it will be recalled, was not operative. During the first run then, contacts E151 remained closed, and sensed amounts on the parcel devices were adapted to be printed on the proof sheet in the adding unit AU after the slides 120A were set up.

Each bill form as B1 or B2 in position to be printed at the adding unit during the second run is not to be fed forward upon the occurrence of computing devices since no amounts are printed on the tax bill from the computing devices. In other words, motor SRM is not energized at any time for a computing device, and this is accomplished by holding relays SR-1 and SR-2 deenergized upon the occurrence of a computing device at the sensing station SS during the second run. Thus, levels 5 PS-5 and PS-6 of the program switch are on their No. 2 contacts, and it will be recalled that these levels of the program switch control circuit to relays SR-1 and SR-2. Thus, considering relay SR-1, switch level PS-5, being on contact No. 2 for this run, contacts a wire 10 E156, and wire E156 is in turn associated with normally 15 open contacts E157 and E158 under control of relay AR mentioned above and another relay BR. Inasmuch as these relays are deenergized at this time no circuit is established for relay SR-1.

20 As to relay SR-2, switch level PS-6 is on its No. 2 contact contacting a wire E163 which extends circuit to a normally open timing switch E165, under control of a cam 165CM mounted on the cam shaft 140A, to the wire E150 associated with circuit for the hammer solenoid 25 E145. Therefore, even though the cam shaft 140A is operative in this cycle, relay SR-2 will not be energized since no circuit is established for solenoid E145 when a computing device is sensed.

The foregoing conditions are established for each 30 computing device in the deck passing to and from the sensing station SS, so that in each instance the numerical amounts punched in the control cards of these devices are merely accumulated in register AC1 and no amounts are printed on the related bill form at the adding unit. In this connection 35 it will be realized that the printing machine unit 100 runs continuously at such times and cycles the adding unit repeatedly through the timing switch E52. The data transmitting cables 100A are restored by a cam operative as an incident to cycling of the cam shaft 140A as described in Patent No. 2,501,444.

Second run—arrival of a parcel device at the sensing station

The arrival of a parcel device at the sensing station 45 SS is one requiring printing of the bill at the adding unit with the numerical amounts punched in the various fields of the control card on the parcel device as was mentioned above. Also, the parcel device requires a subtotal of the amount standing in register AC1 to be taken 50 and printed on the bill at position "S," Fig. 8, and then restored back to register AC1. Registers AC2 and AC3 are again to be neutralized so that there is no interference 55 of amounts in these registers which are reserved for other purposes as was mentioned. After the printing of the bill with the sub-total amount (current tax) the bill being printed is to be spaced forward a short space from its "S" position, Fig. 8, if there is a special assessment or delinquent device in the deck following the parcel device. This will be assumed for present purposes, and 60 the conditions prevailing when the parcel device is the last device in the deck will be described under a separate heading herein.

The particular sequence of control that is here involved 65 is this: the adding unit AU first goes through what may be termed an idle cycle as described above in connection with the computing devices, that is, since the parcel device PD shown in Fig. 9 bears no tab as CT carried by the special assessment and delinquent devices (relay CR energizes upon closure of switch E52), the punched hole 70 amounts first sensed and transferred to the adding unit merely set up the slides 120A so that these amounts transfer in to register AC1 without being printed, and of course, the registers so far as the accumulating wheels 145A are concerned are split so that there is no confusion 75 in the registers between the data punched in fields F1,

F2, F3 and F4, Fig. 9, on the control card of the parcel device and the accumulated fractional tax amounts TC, TH and TT stored in register AC1. Therefore, the first result is to transfer to the slides 120A the numerical amounts on the control card of the parcel device, and during return of the slides 120A during what has been referred to as the idle cycle of the adding unit, these amounts are transferred to register AC1, but so far as significant tax amounts are concerned only the five mil punch 5M in column 26, Fig. 9, of the control card on the parcel device will have an effect on what has been stored in register AC1 by way of accumulation of the previously sensed computing devices. However, this additional aspect is involved, namely, that following the idle cycle a sub-total "S" is next to be printed on the bill under the heading "Current Tax" together with the other punched hole amounts in fields F1, F2, F3 and F4 on the parcel device that were transferred to register AC1 in the aforementioned idle cycle of the adding unit for the parcel device. This means that the adding unit must go through an additional printing cycle, and operation of the printing unit 100 of the machine is interrupted temporarily in this printing cycle as will be described.

Since what has been referred to above as the idle cycle of the adding unit corresponds to that described above in connection with the computing devices, this need not be repeated, and hence the cycle in which the bill is actually printed under control of the parcel device will now be described. It should be first mentioned, however, that toward the end of this idle or accumulating cycle, cam 129CM, Fig. 46, is effective to open switch E129 to break the holding circuit for relay CR. This at the same time conditions the total unit 590A for a sub-total operation as will be explained.

Continuous operation of the printing machine unit 100 during the second run of the tax bill is under control of what will be referred to as column twenty-seven switch E170 which, as shown in Figs. 39 and 46 is normally closed, and it will be recalled that switch E170 is in the starting circuit for the master clutch solenoid E8, Fig. 45. This switch is allocated to a sensing pin among the sensing pins 220 at the sensing station SS which sense the control data on the control cards of the printing and control devices. When a parcel device PD bearing a punched opening at code position "2" in column twenty-seven of the control card thereon is sensed, switch E170 is actuated breaking circuit to solenoid E8 thereby interrupting operation of the printing machine unit 100 at the end of the cycle in which the parcel device having code "2" was first sensed. This drops out the holding switch E15 which is closed only when the master clutch is engaged, and therefore it is necessary to restart the printing machine unit 100 for its next cycle by a separate circuit to solenoid E8 as will be mentioned below, but in the meantime the adding unit AU and total unit 590A take over as will now be explained.

When switch E170 is actuated upon the occurrence of a parcel device at the sensing station SS breaking the circuit to solenoid E8, circuit is extended to a wire E175 which is connected to a wire E176 leading through the sub-relay SR, and the other side of relay SR is connected to the power source through wires E177 and E178 back to level PS-2 of the program switch which is on its No. 2 contact, and from level PS-2 to the safety switch E36. Accordingly relay SR is energized when the column twenty-seven sub-total switch E170 is actuated.

As shown in Fig. 39, relay SR controls circuit to solenoid 602A of the total unit 590A mentioned above, that is, relay SR is a relay which when energized shortly results in actuation of the Bowden cable 526T2 mentioned above as producing rocking movement of the sub-total shaft 325A to set the sub-total cam 590A for a sub-total operation.

When relay SR is energized, the following are some of the sequence of events involved: solenoid 602A of the

total unit 590A is energized and the sub-total shaft 325A is set to its sub-total position; register AC1 is placed under control of the total rack 220A rather than add rack 190A, and solenoids E132 and E133 effect neutralization of registers AC2 and AC3; the adding unit AU is started; solenoid E145 for releasing the hammers is energized so that a print of the sub-total amount can be made on the bill; after the bill has been printed, a short space impulse is delivered to the feed motor SRM for the bill form; the adding unit is stopped; and the printing machine unit 100 re-starts.

When relay SR is energized upon closure of switch E170, a holding circuit for relay SR is established as follows: A wire E190 leads from the side of relay SR opposite the wires E177 and E178 to normally open contacts E191 under control of relay SR, so that these contacts E191 close when relay SR is energized. From the closed contacts E191 circuit is extended to a normally closed switch E193 under control of a cam 193CM mounted on the sleeve 600A of the total unit 590A, and from switch E193 to the other side of the power source. When switch E193 opens and then closes at about 215° of the cycle of the total unit 590A operating as an aspect of sub-totalling the holding circuit for relay SR is broken.

The solenoid 602A, Fig. 39, described above for instituting actuation of the sub-total control cable 526T2 is identified in the wiring diagram as solenoid E200, and it may be pointed out that the companion solenoid 603A mentioned above which institutes a total operation is identified in the wiring diagram as solenoid E201. These two solenoids it will be noted are wired directly to one side of the power source. To extend circuit for solenoid E200 to the other side of the power source, wires E205 and E206 are directed from solenoid E200 to normally open contacts E210 under control of the sub-relay SR, so that these contacts close when relay SR is energized in the way mentioned above. Circuit is extended from contacts E210 by a wire E211 leading to a normally open switch E212 under control of the same cam 129CM which controls the normally closed switch E129. Cam 129CM it will be recalled is mounted on the cam shaft 149A of the adding unit AU. It will be further recalled that toward the end of the cycle of the adding unit, cam 129CM is effective to open switch E129 to deenergize relay CR. This of course was entailed during the idle cycle of the adding unit when the punched hole data on the parcel device at the sensing station SS were first transferred to the setup station 101A of the adding unit. Therefore, at the end of this idle cycle at the time when relay SR had already been energized and held in through switch E193, switch E212 was closed by cam 129CM, and this further extends circuit for solenoid E200 through the normally closed switch E130 described above as mounted on the sub-total sleeve 600A of the total unit 590A, so that circuit for solenoid E200 is completed through wire E131 to the other side of the power source.

It will be seen from the foregoing that solenoid E200 energizes toward the end of the idle or accumulating cycle of the adding unit AU related to a parcel device PD. The adding unit AU is stopped at this time. Moreover, machine unit 100 stops due to switch E170 having been actuated, and the control relay CR is held deenergized because switch E52 is open when unit 100 is idle.

When solenoid E200, Fig. 47, is energized, the related cam disc 604A, Fig. 39, is released setting the sub-total sleeve 600A and the timing cams associated therewith in operation and actuating the sub-total control cable 526T2. In this way, cable 526T2 is effective in the way described above to set the sub-total shaft 325A and the sub-total cam 590A for a sub-total operation, the net effect of this being to shift the gear segment 175A of register AC1 from the add rack 190A to the total rack 220A so that forward setting of the slides 120A of the adding unit will cease when register AC1 is zeroed.

The total unit 590A now being in operation, the adding unit AU is started by energizing the adding unit clutch control solenoid E110. It will be recalled that solenoid E110, Fig. 47, is wired by wires E101 and E102 to one side of the power source, and that its circuit is adapted to be extended to the other side of the power source by a wire E112. However, at this time, the timing relay TR is deenergized, since switches E52 and E122 are open. Therefore, an independent shunt circuit for solenoid E110 is afforded by a normally open switch E220, Fig. 47, connected to wire E112. This switch is under control of a corresponding cam 220CM mounted on the sub-total sleeve 600A of the total unit which is in motion at this time. Accordingly, switch E220 is eventually closed at about 100° of rotation of sleeve 600A as shown in the timing charts. A wire E221 leads from switch E220 to the other side of the power source, so that solenoid E110 which controls the clutch of the adding unit AU is energized to institute operation of the adding unit shortly after the total unit 590A starts.

The taking of a sub-total requires that registers AC2 and AC3 be neutralized at least prior to return of the slides 120A after having set up to the amount standing in register AC1. This again occurs as an incident to closure of switches E132A and E133A since the register control slide 120A1 is stationary for a parcel device. These switches as will be observed from the timing charts are closed at about 130° of the adding unit cycle when the timing switch E141 is closed, which is prior in time to restoration of the slides 120A, so that during restoration of the slides 120A no amounts are entered in registers AC2 and AC3.

However, inasmuch as the sub-total cam 509A has been set in its effective position at the commencement of the adding unit cycle as timed by cam 220CM and the related switch E220, forward movement of the slides 120A will cause the accumulator wheels 145A in register AC1 to zeroize, thereby positioning the slides 120A to the amount standing in register AC1.

Since the sub-total thus obtained from register AC1 is to be printed on the tax bill as "S," Fig. 8, solenoid E145 needs to be energized. This will occur when the timing switch E141 of the adding unit is closed, because again the control relay is deenergized at this time and its contacts E151 remain closed.

After the sub-total and the related parcel device punched hole data have been printed, it is necessary to advance the bill printed at "S," Fig. 8, with a sub-total forwardly a short space to enable the next tax amount to be printed thereon, namely, the delinquent tax amount, and it may be mentioned that the timing disc E95, Fig. 40, will be standing in its E96-2 position while the sub-total amount is being printed. The short space required is equivalent to the disc E95 turning to its E96-3 position. Such short spacing of the bill form requires a short space impulse to the motor SRM driving disc E95 from E96-2 to E96-3 position, and as was mentioned above this is under control of the short space solenoid E61 in turn under control of relay SR-2. Thus, when the sub-relay SR deenergizes toward the end of the cycle of the total unit 590A upon opening of switch E193, its contacts E80, Fig. 47, close extending circuit to the short spacing control solenoid SR-2 from one side of the power source. Program switch level PS-6, Fig. 47, is on its No. 2 contact, and circuit is extended through this switch level to switch E165, Fig. 47, under control of cam 165CM on the cam shaft 140A of the adding unit. Accordingly, when switch E165 is closed during operation of the adding unit wherein the sub-total was printed, circuit is extended through wires E166 and E150 to normally closed switch E151 of the control relay CR, and from the switch E151 through wire E155 to the adding unit timing switch E141.

Switch E220 which instituted operation of the adding unit clutch solenoid E110 opens at about 150° in the cycle

of operation of the sub-total sleeve 600A of total unit 590A. Accordingly, solenoid E110 was deenergized about midway of the cycle of the total unit, and the adding unit stops at the end of its cycle in which the sub-total was printed on the bill. The total unit solenoid was deenergized when holding switch E193 was opened at about 265° of the total unit cycle.

It is necessary to restart the printing machine unit 100 while the total unit 590A is in operation, and this occurs as follows: When cam 130CM is effective to open switch E130, another switch E223 is closed by cam 130CM at the same time, extending circuit to normally closed contacts E224 under control of relay BR. From switch E224, circuit extended by a wire E225 to the master clutch control solenoid E8 of the machine unit 100. The unit 100 starts a new cycle, advancing the parcel device PD out of the sensing station SS and advancing the next device in the deck, namely, the delinquent device DD from the supply magazine to the sensing station SS.

20 Second run—delinquent device

Referring to Fig. 9, the present circumstance, it will be recalled, is one wherein the parcel device is followed by a delinquent device, and this of course requires that the delinquent tax amount be printed on the bill beneath the current tax item and that the delinquent tax amount be added in registers AC1 and register AC3. These results are determined by the No. 13 tab on the delinquent device and code "5" which is punched in column 27 thereof, bearing in mind that the bill form has been positioned to be printed with the delinquent tax amount.

It was mentioned in connection with the first run on the bill that a special pin at 240, Fig. 5, was used in connection with the No. 13 tabs on delinquent and special assessment devices, causing the selector switch E40 to be set with its wiper blade E46 on no contact. For this run on the bill, a pin as 240 is selected at the sensing head SH which upon engaging a No. 13 tab on a delinquent or special assessment device sets the selector switch E40 with its blade E46 on No. 2 contact of the selector switch E40 and the crescent arm E49, while shifted in part remains engaged with No. 6 contact of the selector switch E40.

Thus, during the second run on the bill a delinquent device following the parcel device at the sensing station SS causes the selector switch E40 to be set in the position just mentioned, and the timing relay TR energizes as follows to start an adding unit cycle. Level PS-3 of the program switch is on its No. 2 contact and circuit is extended to wire E120. From wire E120 a wire E120' extends to No. 2 contact of selector switch E40 and across to No. 6 contact. Circuit is extended from No. 6 contact of switch E40 to the timing switch E52 associated with the machine unit 100, and accordingly the timing relay TR is energized when switch E52 closes, assuming of course that the safety switches E36 and E53 are closed. Solenoid E110 which controls the clutch of the adding unit is energized at the same time upon closure of contacts E115 which are controlled by the timing relay, and the adding unit AU starts its cycle. The control relay CR remains deenergized inasmuch as the wiper E46 of the selector switch E40 passed off No. 3 contact. Failure of the control relay to energize maintains switch E151 closed and therefore solenoid E145 is adapted to be energized to enable the type hammers 112A upon closure of switch E141 to be operative on the type segments 110A to print the delinquent amount on the tax bill.

Thus, the adding unit commences its cycle, the slides 120A are set up in accordance with the sensed data carried by the delinquent device, and these data are printed on the bill at the proper place. During restoration of the slides 120A, the corresponding delinquent tax amounts will be entered in registers AC1 and AC3 only as will now be explained.

75 When the sensed data on the delinquent device are

transferred to the setup station 101A, code "5" in column twenty-seven of its control card CC, Fig. 9, was transmitted to the column of the setup station allocated to slide 120A1. Accordingly, slide 120A1 sets up in its No. 5 position during operation of the adding unit, and it will be recalled that when thus set switch E132A allocated to energization of register control solenoid E132 for register AC2 will alone be energized, thereby neutralizing register AC2.

After the delinquent amount has been printed on the bill, the bill as B1, Fig. 8, so printed with the delinquent amount is then to be fed forward a short space in position to receive the special assessment amount. In other words, the short space relay SR-2 has to be energized, and this will occur in the manner described above in connection with short spacing of the bill following the printing of the sub-total or current tax amount.

Inasmuch as no holding circuit was broken for solenoid E8 that controls the master clutch of the printing machine unit 100, unit 100 will continue to operate to advance the delinquent device out of the sensing station SS and to advance the next device, namely, the special assessment device forwardly from the supply magazine SM to the sensing station SS.

Second run—special assessment device

The special assessment device SAD, Fig. 9, being the last device in the particular deck here under consideration, requires the following to be accomplished:

(1) Printing of the tax bill with the special assessment amount.

(2) Interruption of the machine unit 100.

(3) Addition of the special assessment amount to registers AC1 and AC3.

(4) Advancement of the bill form from its special assessment data receiving position to its total tax data receiving position shown in Fig. 9.

(5) Institution of a total-taking operation of the total unit 590A.

(6) Re-start of the adding unit AU to print the total tax amount.

(7) Advancement of a new bill form to its initial position in the adding unit.

(8) Re-start of the machine unit 100.

The first and third of the above steps involved for the special assessment device is a repeat of what was described in connection with the delinquent device, namely, the special assessment amount punched in its control card is transmitted to the adding unit, the adding unit is started, the special assessment amount is printed on the bill and is added in registers AC1 and AC3 during restoration of the slides 120A, these steps occurring as an incident to the occurrence of a No. 13 tab on a special assessment device as shown in Fig. 9 and code "5" in column 27 of the control card thereon allocated to control over solenoids E132 and E133.

However, the special assessment device also carries a No. 1 tab as will be observed in Fig. 9, and this tab when sensed closes a normally open total control switch E230 which was earlier described as located in the sensing station SS in position to be actuated by the switch rocker arm 268 associated with a special purpose sensing pin as 240 corresponding to the No. 1 tab position. Thus, switch E230 is connected to the side of the power source corresponding to wire E7 by a wire E231 terminating at No. 2 contact of the program switch PS-1. The other side of switch E230 is connected by a wire E235 to normally closed contacts E236 under control of the sub-total control relay SR which is deenergized at this time. From contacts E236, circuit is extended by a wire E239 to relay AR, and relay AR at the other side is connected by a wire E240 to the other side of the power source.

A holding circuit for relay AR is established as follows: Wires E244 and E244' lead through normally open contacts E245 under control of relay AR and to a normally closed holding switch E246 under control of a corre-

sponding cam 246CM mounted on total sleeve 601A of the total unit 590A. From switch E246, a wire E250 shunts around switch E230 to the other side of the power source. Hence, so long as switch E246 is held closed 5 relay AR is held energized and relay AR energizes of course when the special assessment device is first sensed.

It was mentioned in the sequence list set forth above that the machine unit 100 is at this time to be interrupted at the completion of the cycle in which the special assessment device was sensed. Thus, the energizing circuit for the master clutch solenoid E8 includes a switch E9, as was earlier mentioned, and the contacts of this switch are under control of relay AR, so that when relay AR is energized contacts E9 open deenergizing solenoid E8. Cam 246CM also controls a normally open switch E251. This switch is adapted to re-establish circuit to solenoid E8 when switch E246 is opened as will be described hereinbelow.

The special assessment amount having been printed 20 on the bill and the machine unit 100 having been conditioned to be interrupted in its operation subsequent to sensing the special assessment device, conditions are established for taking out of register AC1 the total tax amount standing therein, printing this amount at "A," 25 Fig. 8, on the bill, feeding forward a new bill form as B2 to the printing station of the adding unit and re-starting machine unit 100. This of course entails operation of the total unit 590A to actuate cable 526T1, and also requires a re-start of the adding unit to enable the 30 total tax to be printed. Preliminary to the printing of the total at position "A," Fig. 8, on the bill is the need to feed the bill forward in position to receive the total amount. This, it will be recognized from Fig. 8, is a relatively long spacing of the bill, and referring to Fig. 40 35 the entailed spacing can be described as one equivalent to advancement of the timing disk E95 from its E96-4 position to its E96-1 home position.

Thus, the bill is spaced in accordance with the foregoing by energizing the homing solenoid E60 for the 40 motor SRM that feeds the bill form, and this is accomplished as follows:

It was mentioned earlier that the circuit for relay SR-1 which controls the homing solenoid E60 includes a switch E157. This switch it will be observed is normally open but is under control of relay AR so that 45 when relay AR is energized upon sensing the special assessment device switch E157 closes and relay SR-1 will be energized when switch E165 is closed under control of the cam 165CM on the cam shaft 140A of the adding unit AU, this occurring of course during that 50 cycle of the adding unit when the special tax assessment amount was printed on the tax bill. Relay SR-2 will be energized also upon closure of switch E165, bearing in mind that the sub-total relay SR is deenergized and its switch E80 closed at this time. In other words, 55 as the adding unit lapses into the end of its cycle wherein the special assessment amount was printed on the bill, a long impulse will be delivered to motor SRM, and its timing disc will travel from its last short spacing (E96-4) position to its home position (E96-1).

The tax bill form as B1 having thus been positioned to be printed with the total tax, the total unit 590A is now effective to institute a total taking and printing cycle of the adding unit AU. Mention was made of solenoid E201, Fig. 39, which when energized enables the total 60 sleeve 601A of the total unit 590A to be driven, and when this occurs the cam 616A on the cam disc 615A, Fig. 39, is effective to actuate the total control cable 526T1 to set up the total shaft 330A in its first position shown in Fig. 24 whereat register AC1 is under control 65 of the total rack 220A, register AC2 is under control of the add rack 190A and register AC3 is in neutralized position.

Solenoid E201 which serves in part to institute the foregoing total taking operations is connected by a wire 70 E260 directly to one side of the power source, this wire

being common to solenoids E200 and E201. The other side of solenoid E201 is connected by a wire E261 to a wire E265 leading through normally open contacts E266 under control of relay AR. Thus, when relay AR is energized upon closure of the total switch E230, contacts E266 closed and circuit was extended to the normally open switch E212 associated with cam 129CM of the adding unit. Cam 129CM, it will be recalled, and as shown in the timing charts, is effective toward the end of the adding unit cycle to open switch E129, and at the same time switch E212 is closed. Such closure of switch E212 occurred toward the end of the adding unit cycle in which the special assessment tax amount was printed on the bill, and hence as the adding unit AU lapsed into the end of its special assessment tax printing cycle, switch E212 was closed. Closure of switch E212 extends circuit to normally closed switch E130 which is associated with cam 130CM on the sub-total sleeve 600A of the total unit 590A. Sleeve 600A is not in operation, so that circuit for solenoid E201 is further extended to wire E131 which leads to the other side of the power source.

Thus, from the foregoing, it will be seen that solenoid E201 was energized substantially at the termination of the adding unit cycle in which the special assessment tax amount was printed, and this set the total sleeve 601A of the total unit 590A in operation.

As will be observed from the timing charts, the cable 526T1 which controls the total shaft 330A is actuated shortly after commencement of rotation of the total sleeve 601A of the total unit 590A thereby setting the total shaft to its first total setting mentioned above. It will be further recalled that at this time solenoid E133 of the register control solenoids is alone to be energized since register AC2 is to remain standing in its add position so as to receive the tax total from register AC1 during restoration of the slides 120A after printing the total tax amount. To this end, a normally open switch E270 and a related normally closed switch E270' are arranged adjacent the total shaft 330A and are adapted to be reversed by a corresponding cam 270CM mounted on the total shaft 330A. This double pole switch E270—E270' has one of the fixed contacts thereof connected by a wire E271 to No. 2 contact of a level PS-9 of the program switch, and the program switch PS-9 is connected by a wire E273 to one side of the power source. The other stationary contact of this switch is connected by a wire E274 to the "S" contact of switch level PS-9, and the "S" and No. 1 contacts it will be observed are wired together. The movable or cam-operated arm of switch E270—E270' is connected by wires E275 and E276 to a wire E277 connected to one side of solenoid E133. Accordingly, when switch E270 is closed and switch E270' opened upon operation of the total shaft 330A, solenoid E133 will be energized upon closure of the timing switch E141 when the adding unit is started through its total printing cycle.

It may be mentioned at this point that the circuit thus afforded for solenoid E133 in part enables an AC1 total to be taken and printed on the proof sheet mentioned above as desirably associated with the adding unit on the first run of the tax bill. Thus, when the level PS-9 of the program switch is on its No. 1 setting, as it will be on the first run for the tax bill, contact No. 1 of this switch shunts switch E270 to normally closed switch E270', thereby extending circuit directly to wires E275 and E276. Another level PS-10, Fig. 48, of the program switch is associated with solenoid E132 as will be observed in the wiring diagram. When switch level PS-10 is on its No. 1 contact, it will be observed that circuit is extended by a wire E280 to the solenoid E132. In the first run, then, any time an amount is added to register AC1, registers AC2 and AC3 will be neutralized upon closure of switch E141. Moreover, by setting manually the total shaft 330A at any time during the

first run on the tax bill to its first position shown in Fig. 24, a total can be taken from register AC1, and this total will be transferred to registers AC2 and AC3 since switch E270' will be opened upon operation of the total shaft 330A. Thus, circuit to solenoids E132 and E133, Fig. 48, is thereby broken and the gear segments 175A thereof will remain engaged with the add rack 190A so as to receive whatever total is taken from register AC1. Further in this connection, a manually operable normally open switch E285, Fig. 47, is afforded at the adding unit when it is desired to take and print a total from register AC1 during the first run on the tax bill. The circuit whereby solenoid E145 is energized to print a total on the first run will be readily apparent, relay CR remaining deenergized.

To return to what occurs at the adding unit during the taking of a total tax amount during the second run on the tax bill, the control solenoid for register AC3 is alone adapted to be energized since switch PS-10 is completely open on its No. 2 setting and hence no circuit is established for solenoid E132 upon closure of the total control switch E270. Conditions have therefore been established for taking a total from register AC1 and adding this in register AC2, and accordingly solenoid E110 is to be energized to start the adding unit cycle.

It will be recalled that when solenoid E201 was energized, the total unit 590A was set in operation insofar as the total sleeve 601A is concerned. Thus, solenoid E110 is energized at this time upon closure of a normally open switch E290 under control of a related cam 290CM mounted on the total sleeve 601A, and this cam is effective on its switch E290 short of midway of the total unit cycle as will be observed in the timing chart of Fig. 41. Switch E290 it will be noted shunts around switch E220 described above.

Relay CR being deenergized, its switch E151 remains closed and the hammers 112A are therefore operative to print on the tax bill the total taken from register AC1, and prior to restoration of the slides 120A, which were set up by zeroization of register AC1, the total taken from register AC1 is added into register AC2. AC1 has of course been zeroized, and hence is conditioned to accumulate tax amounts on the next deck of printing and control devices.

When switch E290 opens upon further rotation of sleeve 601A, the adding unit solenoid control clutch E110 is deenergized thereby stopping the adding unit at the end of its cycle in which the total was printed.

The tax bill as B1, Fig. 8, has been completely prepared when the total tax amount is entered thereon as at "A" position. It is therefore necessary to feed a new bill form as B2 to printing position at the adding unit and to restart the printing machine unit 100 to commence feeding of the computing devices CD which are related to the next bill form as B2 which is to be printed. Accordingly, the feed motor SRM is operative at this time to advance the bill form fan-fold BFF from what amounts to the "A" position of the last bill form printed to the "S" position of the next bill form to be printed with its subtotal or current tax amount. This requires operation of the bill form spacing solenoid E61 which will enable the motor SRM to drive until the cam disc E95 presents notch E95-2 to the stop pawl E98.

This occurs as an incident to energization of relay SR-2 which energized when switch E165 closed during the course of the cycle of the adding unit AU in which the total tax amount was printed.

It will be recalled that the printing machine unit 100 was stopped when relay AR energized, this occurring as an incident to opening of switch E9 under control of relay AR, and when solenoid E8 deenergized its holding switch E13 opened. It is therefore necessary in energizing solenoid E8 to shunt around switch E13.

Such shunt circuit is in part afforded by switch E251 which is closed when switch E246 opens, thereby extending circuit from wire E250 to a wire E295, and wire E295 it will be noted is in circuit with wires E224 and E225 described above.

Parcel device as last device in the deck

In the instance where no special assessment or delinquent device is present in the deck, the parcel device will then bear a control tab CT at the No. 1 position as shown for a special assessment device SAD of Fig. 9. Under such circumstances, the following sequence of operations is entailed:

(1) Register AC1 of the adding unit will alone be operative to receive amounts on the parcel device during restoration of the slides 120A.

(2) Operation of the machine unit 100 is to be interrupted at the end of its cycle in which the parcel device was sensed.

(3) The adding unit is to be recycled to print on the bill at position "S" the sub-total standing in register AC1, this sub-total having been accumulated from the computing devices that preceded the parcel device.

(4) The bill form after having been printed with the sub-total tax amount is to be spaced forward to its total tax receiving position.

(5) The total unit is to be operated through a total-taking cycle.

(6) The adding unit is again to be recycled to print at position "A" on the tax bill the total tax which will be the same as the sub-total printed at "S" on the tax bill. Register AC1 is to be cleared, and the total tax is to be transferred to register AC2.

(7) A new tax bill form is to be advanced to printing position in the adding unit.

(8) Re-start machine unit 100.

Thus, when the parcel device is the last device in the deck the total switch E230 will be closed since the parcel device now carries a No. 1 tab. Moreover, column twenty-seven switch E170 will be closed at the same time since the parcel device also bears code "2" in column twenty-seven of the control card thereon. The parcel device will not carry a No. 13 tab, since the No. 13 tab is allocated specifically to delinquent and special assessment devices in order to prevent energization of the control relay CR so as to hold its switch E151 closed to enable the hammer solenoid E145 to energize for printing on the bill delinquent and special assessment tax amounts. Therefore, the parcel device not having a No. 13 tab, the selector switch E40 remains in its restored position shown in the wiring diagram which produces energization of the control relay thereby assuring that solenoid E145 will not energize during the cycle of the adding unit in which the sensed amounts on the parcel device are to be added in register AC1 without being printed. In other words, the adding unit goes through an idle, that is, a non-printing cycle precisely like that described above in connection with the previously described parcel device.

When switch E170, Fig. 46, was closed incidental to the provision of a code "2" punch in column twenty-seven of the parcel device now under consideration, this broke circuit to solenoid E8 for the master clutch of the machine unit 100, thereby preventing the next normally successive cycle of the machine unit 100. At the same time, the sub-total control relay SR, Fig. 45, is energized as was described above to condition the total unit 590A for a sub-total operation, and again this sub-total operation is a repeat of what was described above in connection with the parcel device not having a tab in its No. 1 position. In other words, at the end of the aforementioned idle or non-printing cycle of the adding unit for the parcel device as the last device in the deck, switch E212, Fig. 46, was closed to complete circuit to the sub-total solenoid E200, Fig. 47, resulting in rotation of

sleeve 600A of the total unit. Accordingly, the adding unit is recycled in the manner described above so as to print on the bill the sub-total amount and related punched hole data in the parcel device, and a further or subsequent 5 total cycle is next involved as will be explained below.

In this instance where the parcel device is considered to be the last device in the deck, it is next necessary to advance the bill form from its sub-total data receiving position, and such spacing of the bill form is in part controlled by relay BR as will now be described.

Switch E230 was closed upon sensing of the No. 1 tab on the parcel device. When the sub-total relay SR energized, its switch E236 opened, and at the same time its normally open contacts E236' closed. This extends circuit from wire E235 to wires E300, E301 and E302 to one side of relay BR, and it will be observed that the other side of relay BR is connected to the other side of the power source through level PS-2 of the program switch and the safety switch E36. Therefore when the sub-relay 15 was energized relay BR was energized at the same time. A holding circuit for relay BR is established as follows:

Associated with relay BR is a normally open switch E310 under control of the relay BR so that when relay BR energizes switch E310 closes and this extends circuit 20 to the normally closed switch E246 under control of cam 246CM mounted on the total sleeve 601A of the total unit. It will be recalled that the homing solenoid E60 and the short spacing solenoid E61 which control the bill form feed motor SRM are under control of relays 25 SR-1 and SR-2, and in this instance it is necessary to energize both solenoids E60 and E61 so that the stop pawl E98, Fig. 40, will be held away from notches E96-3 and E96-4 to enable the timing disc E95 to travel in effect from its E96-2 position back to its home or E96-1 position. Thus, it will be recalled that when a sub-total tax 30 amount is being printed on a tax bill, the timing notch E96-2 is presented to the stop pawl E98.

When the holding switch E193 for the sub-relay opens in the latter half of the cycle of the total unit which produced the sub-total operation, the sub-relay SR deenergized of course and accordingly switch E80 closed. It was mentioned that circuit for relay SR-1 includes a normally open contact E158 under control of relay BR, and accordingly when relay BR energized switch E158 closed, 40 and relay SR-1 will be energized during the sub-total printing operation of the adding unit AU causing closure of switch E165. When switch E165 closes, relay SR-2 is energized, and therefore both the homing solenoid and the short spacing solenoid E60 and E61 respectively are 45 energized. Consequently, after the sub-total amount is printed, the tax bill form is spaced from its "S" position to its "A" position shown in Fig. 8, thereby positioning the tax bill to receive the total tax amount at the proper location, and such printing will of course occur in the 50 next cycle of the adding unit instituted by a total taking cycle of the total unit 590A.

Operation of the total unit 590A through a total taking cycle requires that solenoid E201 be energized to condition sleeve 601A for rotation, and such ordinarily would 55 entail energization of relay AR. Relay AR cannot be energized under this special circumstance here under consideration, because SR contacts E236 are held open and prevent circuit being established to relay AR. Moreover, when relay SR deenergizes to enable contacts E236 to close, the total switch E230 has already been opened since the sensing head of the machine unit 100 has in the meantime been raised.

Therefore, a separate energizing circuit is afforded for the total relay E201 at this time shunting around switches 60 E212 and E266. Thus, circuit is extended from wire E261 to a wire E315 which leads to a normally open switch E320 under control of a cam 320CM on the sub-total sleeve 600A of the total unit 590A, and as will be observed from the timing chart, switch E320 closes toward the end of the sub-total cycle.

Circuit is extended from switch E320 to a wire E325 and from wire E325 to a normally open switch E330 having contacts under control of relay BR. Relay BR was energized simultaneously with relay SR, and is held energized by the normally closed holding switch E246 controlled by a cam on the total sleeve 601A. Therefore, switch E330 is closed at this time to complete circuit to wire E131, and accordingly the total solenoid E201 is energized at completion of the sub-total cycle to institute immediately a total cycle of the total unit 590A and the adding unit AU. Relay BR eventually drops out when switch E246 opens during the total-taking cycle, and at the same time switch E251 is closed to re-start the printing machine unit 100 to feed the computing devices of the next deck to the sensing station SS.

At the end of the second run on the tax bill when the machine has been stopped by virtue of switch E13 which opens when the last device D has been fed from the supply magazine SM, a proof total can be taken and printed from register AC2 and also a total from register AC3. To do this, the total shaft 330A is set manually to the corresponding second or third total taking position shown diagrammatically in Fig. 33. This causes the gear segments 175A of the register to be set by the cams as shown in Figs. 23-26 on the total shaft 330A. Then, the adding unit AU is cycled by manual closure of switch E285.

Such totals can be conveniently printed on a blank tax bill form, since all that is wanted is a machine proof. Thus, when the last tax bill was completed, a blank bill form would have been fed forward to its "S" position, and a total from register AC2 can be printed thereon, noting that relay CR is deenergized to hold switch E151 closed. In the AU cycle in which this total was printed, relay SR-2 was effective upon closure of switch E165 to impart a short space to the bill form used for proofing. Hence, a total can next be taken from register AC3 by setting the total shaft 330A appropriately and cycling the adding unit AU once more by closing switch E285.

"S" setting of the program switch

It was previously mentioned that the program switch has an "S" setting, and this setting imparts still further flexibility to the machine. Inasmuch as many of the operations described hereinabove in connection with the No. 1 and No. 2 settings of the program switch occur also with the program switch in its "S" setting, the description to follow will be largely restricted to differences that are entailed.

Thus, switch level PS-1 of the program switch when on its "S" setting will serve the purpose mentioned above in connection with the first run on the tax bill, inasmuch as the "S" and the No. 1 contacts of this level of the program switch are wired together. The platen 103 of the machine can be used or not with the program switch in its "S" setting. Thus, when level PS-2 of the program switch is on its "S" setting, circuit is extended to a wire E360, and from wire E360 to an off-on switch E361 which is on one side of the platen solenoid E30. It will be noted that level PS-2 in its "S" setting, relays BR and SR are cut out. Further, switch E230 is cut out.

At level PS-3 of the program switch in its "S" setting, circuit for the timing relay TR is extended to wire E365 leading to a manually settable print-skip selector switch E368 having a movable contact E370 which can either be set in a "P" setting at which setting printing and control devices D having a tab will be printed at the printing station if the platen 103 is to be used; an "S" setting whereat printing and control devices having a tab are skipped through the printing station PRS; and an "off" setting. In this connection, it should be pointed out that the control relay CR is cut out at level PS-4 of the program switch when the program switch is on its "S" setting, and the occurrence of a tab on a printing and control device (print tab or skip tab) will cause the selector

switch E40 to be set with its wiper arm E46 on contact No. 2 of switch E40.

Therefore, with switch E368 on its "P" or print-tab setting, conditions are established for energizing the timing relay TR when a printing and control device is sensed having a tab, and the timing relay will not be energized in the absence of a tab. Likewise, with switch E368 on its "S" or skip-tab setting the timing relay TR will not be energized when a printing and control device having a tab is sensed, because the selector switch E40 will be set with its contact arm E46 on contact No. 3 of switch E40.

In its "off" setting (print all devices D) switch E368 affords a shunt around the selector switch E40, so that circuit for the timing relay TR is extended directly to wire E51. In this instance, whether tabbed or not, the printing and control devices will have no effect on the selector switch E40.

As to levels PS-5 and PS-6 of the program switch, it will be observed that the "S" settings here drop out relays SR-1 and SR-2. This conditions the machine for utilization of proof sheet printing at the adding unit AU in the manner described in Patent Nos. 2,501,444 and 2,568,064.

The "S" setting for switch level PS-7 in effect opens wire E113, so that the adding unit clutch solenoid E110 cannot be energized through level PS-7 of the program switch. However, a wire E375 shunts around switch level PS-7 and extends to a switch E376 which when closed affords an independent circuit for solenoid E110 to the contacts E115 of the timing relay TR as will be observed. It will be recognized that if switch E376 is maintained open with the program switch on its "S" setting, the adding unit is in effect disabled from automatic operation, and can only be cycled by closing manually switch E285.

It was mentioned above that the data-transmitting cables 100A once actuated can either be restored mechanically by a cam-operated restoring lever controlled by a cam of the adding unit as described in the above-mentioned patents, or as an incident to energization of solenoid E100. Thus, it will be seen from the wiring diagram that solenoid E100, so long as the timing relay is deenergized to hold its contacts E106 closed, is adapted to be energized upon closure of switch E105. This of course will occur in those instances and at those times where the timing relay is deenergized, which is to say when the adding unit AU is not in operation, for if the adding unit is in operation the cables are to be restored by cam means of the adding unit, and if the adding unit is not in operation cable restoration is to be by way of solenoid E100. Therefore, since the timing relay may be energized in an instance where the adding unit is not to be operated, as for example in a run of the machine unit the program switch is in its "S" setting, it is necessary to shunt around switch E106 and the following circuit is afforded:

When switch E376, Fig. 47, is in the position shown (AU "off") an associated switch E380, Fig. 47, extends circuit from switch E105 to a level PS-11 of the program switch, and the "S" contact of this level is wired directly to one side of the power source.

In the course of running the machine with the program switch on its "S" setting, it may be desirable to take totals from register AC1 at predetermined intervals, and this is afforded by an interval counter of a known kind as will now be described. Thus, a counting solenoid E400, Fig. 45, of the usual kind is adapted to be connected to one side of the power source upon closure of a switch E401. The other side of solenoid E400 is connected to normally closed contacts E400' of the timing relay, and these contacts are connected to wire E38 so that a count is registered each time the timing relay TR operates. Solenoid E400 controls a stepping switch (not shown) which can be predetermined as to a particular count, and when the predetermined count condition has

been established, as is well known in the art, contacts E405 close.

When switch E401 is closed, a related switch E406 is closed (double pole switch) and switch E406 it will be observed is connected at one side by a wire E407 directly to one side of the power source. Switch E405 is wired by wires E408, E409 and E410 to the "S" contact of a level PS-12, Fig. 45, of the program switch, and level PS-12 extends circuit to the side of relay AR which is opposite wire E240. Accordingly, when contacts E405 close after completion of the predetermined count, relay AR is energized through level PS-12 of the program switch and wires E240 and E407. This institutes a total taking cycle of the total unit 590A, and this operation need not be re-described.

A reset solenoid E415, Fig. 45, is afforded for resetting the interval counter in a known fashion, and this solenoid is energized to enable the reset to be performed when relay AR is energized. Thus, circuit is extended by wires E416 and E417 to a normally open switch E420 under control of relay AR and from switch E420 to wire E131.

The reset solenoid can be energized manually by a momentary switch E425 which is normally open, so that by actuating this switch circuit is extended to wire E407 for the reset solenoid, and at the same time a related switch E425' opens so as to prevent energization of relay AR.

It is advantageous of course to afford a long space on the proof sheet after a total has been printed in the foregoing manner. A paper feed solenoid E430, Fig. 47, is afforded as described in Patent 2,501,444 which when energized overrides the mechanical paper feed so as to impart a long stroke to the paper feed mechanism associated with the proof sheet that is adapted to be used in the adding unit AU. This solenoid is connected to a wire E431 which leads to a list feed cam-operated switch E433 controlled by a cam 433CM, Fig. 39, on the total sleeve 601A. A wire E435 leads from switch E433 to the same terminal plate to which wire E417 is connected.

During the run of the machine with the program switch on its "S" setting, registers AC2 and AC3 are to be neutralized each time an amount is entered in register AC1. This particular register control aspect occurs in each cycle of the adding unit AU at the time when the timing switch E141 closes. Thus, levels PS-9 and PS-10, Fig. 48, of the program switch produce this result independently of switches E132A and 133A described above as being in part under control of the register control slide 120A1. Thus, switch E270' is closed so long as the total shaft 330A is in its restored position thereby completing circuit from wires E273 and E274 to wire E275.

When a total taking operation is instituted upon closure of the interval counter contacts E405, Fig. 45, during the run of the machine with the program switch on its "S" setting to energize relay AR, the total shaft 330A is of course operated as described above to its first setting, and cam 270CM is effective to open switch E270', and at the same time the gear segment 175A for register AC1 is shifted by cam 335A1 from its add position to its total position so as to be operated by the total rack 220A, Fig. 19. Switch E270' having thus been opened, the circuit to solenoids E132 and E133 is broken, and therefore the control segments 175A for these two registers remain in their add position, that is, so as to be operated under control of the add rack 190A. Accordingly, when a total is taken from register AC1 in this manner as an incident to satisfaction of the predetermined count of the interval counter, the total taken from register AC1 is transferred to registers AC2 and AC3. At the end of the run, totals can be taken from registers AC2 and AC3 by setting the total shaft 330A to either its second or third position, respectively, shown in Figs. 25 and 26 and Fig. 33.

It may be advantageous to take a sub-total from register AC1 during the run of the machine with the program switch on its "S" setting. To enable this to be accom-

plished, a pair of switches E432A and E433A are mounted adjacent the sub-total shaft 325A as shown in the wiring diagram of Fig. 48. Related cams 432CM and 433CM are mounted on the sub-total shaft 325A as shown in Fig. 548, and when the sub-total shaft is set manually for a sub-total operation these switches are closed by the cams 432CM and 433CM, thereby energizing solenoids E132 and E133 so that registers AC2 and AC3 assume the neutral setting shown in Fig. 27 at the time when register AC1 is conditioned for a subtotal operation.

Conclusion

It will be seen from the foregoing that the present invention makes possible the production of business instruments such as tax bills or the like having printed thereon legend or descriptive data in the form of addresses or the like printed by embossures on certain of the printing and control devices that are fed sequentially through the machine, and such legend imprinting occurs during a separate run of the machine. Thus, in the first run of the machine for printing a tax bill or the like only the devices of the order bearing a printing plate are used for imprinting at the primary printing station PRS, the action of the selector switch E40 being such at this time as to cause other devices present in the decks, of an order not having a printing plate, to be skipped past the primary printing station PRS without being used for printing, and this occurs as an incident to the presence or absence of control tabs as CT shown in Fig. 9 which affect the setting of the selector. After each such business instrument is printed in this manner at the primary printing station PRS, a completely new business form is fed forwardly at the printing station PRS in position next to be printed, so in this instance the feed motor SRM for feeding the sheets or forms to be printed in effect homes each time a driving impulse is delivered thereto subsequent to printing a business instrument. Such long drive impulses are accounted for by the homing solenoid E60 of motor SRM under control of its relay SR-1 which is timed by switch E70-E71, Fig. 48.

In the first run of the machine, the sensing pins in the sensing head are active of course to sense punched hole data carried on the control cards of the devices which bear a printing plate as well as the delinquent and special assessment devices which carry no printing plate, and as was mentioned these two kinds or orders of devices are identified by the presence or absence of a No. 13 control tab as CT. Such control indicia indicate the fundamental print-skip relation involved at primary printing station PRS and also determine in the first instance operation or non-operation of the adding unit AU in the first run. The net effect in this connection is that the timing relay TR is energized in the absence of a control tab so as to energize solenoid E110 and thereby set the adding unit in operation for enabling a proof sheet to be printed with the punched hole data carried by the related devices. Since the control relay CR is out at this time, the hammer suppressing means as represented by the solenoid E145 is disabled, and energization of the timing relay TR also accounts for energization of the platen delay solenoid E30 to establish conditions that eventually produce an imprint at the primary printing station PRS. In other words, neither the adding unit nor the platen 103 is operated in the first run upon the occurrence of a device bearing a control tab as CT.

Insofar as proof sheet printing in the first run is concerned, this in most respects is similar to that described in Patent No. 2,501,444. Thus, the sensed parcel device data transmitted to the data receiving means in the adding unit at the station 101A serve to control the forward setting-up movement of the slides 120A to their data representing position, and during such setting-up the slides 120A also set up the printing segments 110A to print on the proof sheet the sensed parcel device data. In the second half of the cycle of the adding unit, the slides 120A transfer sensed amounts to the accumulator

wheels of register AC1, and at this time registers AC2 and AC3 are maintained in neutral settings by virtue of levels PS-9 and PS-10 of the program switch, Fig. 48, so that no amounts are entered in the accumulator wheels thereof. In other words, the arrangement at this time is such that the gear segments 175A for registers AC2 and AC3, which serve when rocked to raise or lower the accumulator gear wheels in respect of the slides 120A to receive amounts from or transfer amounts to the slides 120A, are set in neutral position between the shiftable add rack 190A and the shiftable total rack 220A, and it will be appreciated that the racks 190A and 220A in effect are timers which determine the time at which an accumulator is to be associated with the slides 120A either in an adding relation or a total relation.

In the second run on the tax bill or similar business form, the numerical accounting items are entered on the business forms in the proper position, and at this time the computing devices which carry data of an order to be accumulated only are arranged in the deck in association with the related devices which carry data of an order to be accumulated or stored as well as to be printed. As was mentioned above, the data of the accumulative order (computing devices) and the data of the accumulative and printing order (delinquent parcel and special assessment devices) are identified by data in column twenty-seven of the control cards thereof. Thus, upon the occurrence of a computing device or parcel device having "no code" register control data in column twenty-seven of the control card thereon, register AC2 and AC3 control solenoids E132 and E133 responsive to such register control data are energized upon closure of the register control switches E132A and E133A. Energization of these solenoids produces actuation of the arms as 320A3, Fig. 22, which position the corresponding gear segments 175A in neutral position. This establishes a neutral condition for registers AC2 and AC3 through neutral positioning of the related AC2 and AC3 gear segments 175A, so that the data on the computing and parcel devices are transferred to register AC1 only.

The control relay CR in the second run is energized upon the occurrence of a device having no control indicia in the form of a No. 13 control tab as CT. This opens switch E151 thereby maintaining solenoid E145 de-energized to hold the hammer suppressing means as represented by the hammer suppressing blade 435A in its unreleased condition. Upon the occurrence of a device having positive indicia in the form of a No. 13 tab, the control relay is held deenergized, so that the data on the related device are accumulated or stored as well as printed.

The business instruments undergoing preparation in the second run of the machine are of course arranged to feed through the printing station of the adding unit AU, but not until after a device requiring the printing of amounts arrives at the sensing station SS is a particular business instrument fed forwardly to its next data receiving position. This usually will be a short spacing and is determined by the short spacing feed motor control relay SR-2.

The sensing of a device calling for a sub-total, that is, the parcel device in the second run requires that the data from the computing devices accumulated in register AC1 and the data on the parcel device stored in register AC1 be read out of register AC1 during totalizing or forward setting movement of the slides 120A and printed on the business instrument. Of course, the other punched hole data carried by the parcel device are printed on the business instrument at the same time. Such operations occur as an incident to sensing of the "code 2" data in column twenty-seven of the control card on the device which calls for a sub-total, and this causes the sub-total relay SR to energize. In other words, the control data on the parcel device is one of a special circumstance producing a sub-total operation of the total unit 590A.

Such operation of the total unit 590A automatically sets the sub-total cam 509A to its sub-total position which produces a sub-total setting for register AC1 wherein the amounts standing in register AC1 are taken there-

- 5 from during the forward or total movement of the slides 120A and are restored back into register AC1 during the return or add movement of the slides 120A. Registers AC2 and AC3 are again neutralized inasmuch as the slide 120A1 which controls setting of the register 10 control cam-operated switches E132A and E133A remains stationary as it does for the computing devices, thereby causing the gear segments 175A of these two registers which normally produce engagement of an accumulator with the slides 120A to stand in a neutral position 15 between the racks 190A and 220A thereby defining the neutral standings or conditions of registers AC2 and AC3.

To print the sub-total amount and the related punched hole data carried by the parcel device requires release 20 of the hammer suppressing blade 435A. This entails energization of solenoid E145 which controls releasing and unreleasing conditions of the hammer suppressing blade, and is accounted for by the control relay CR being deenergized due to a lapse in the cycle of the machine 25 unit 100 at this time.

Following the parcel device, that is, the device calling for a sub-total, there may occur a device carrying additional data to be accumulated in register AC1 with the computing or first-order numerical data, but which additional 30 or second-order data are to be segregated or set apart for accounting purposes at least to the extent that these second-order data are to be accumulated in a separate register. Thus, under the present circumstances, all data to be part of the total individual tax are accumulated 35 in register AC1, but it is advantageous to separately accumulate the delinquent and special assessment tax data in register AC3. Accordingly, when a device carrying data of a second order is sensed, the register control slide 120A1 responsive to the sensing of register control indicia on this device is so set as to cause these data to be 40 transferred to registers AC1 and AC3. Moreover, these second-order data are to be printed on the business instrument, which is a further distinction between the handling of the two kinds of data.

45 The last device in the deck following the computing devices carries control indicia in the form of a No. 1 tab as CT, Fig. 9, requiring the taking of a total from register AC1, clearance of register AC1 and transfer of the total from register AC1 to register AC2. It will be 50 appreciated that prior to such total taking operations, tax data of an order to be accumulated and printed may intervene, and that printing of the total entails spacing the business form to its home or total position.

The run of the machine with the program switch 55 in its "S" setting has been explained as one wherein various selective operations are possible.

Hence, while we have illustrated and described the preferred embodiment of our invention, it is to be understood that these are capable of variation and modification, and we therefore do not wish to be limited to the precise details set forth, but desire to avail ourselves of such changes and alterations as fall within the purview of the following claims.

We claim:

- 65 1. In a printing and adding machine of the kind described adapted to print numerical amounts on a sheet and wherein there are adapted to be passed to a sensing station in the machine devices bearing numerical data, some of an order to be accumulated and others of an 70 order to be accumulated and printed, said orders being identified by the presence or absence of register control indicia on the devices, and wherein certain of said devices additionally bear control indicia demanding a sub-total and a total of accumulated numerical data of a 75 particular order, means at the sensing station adapted

to establish representations of said numerical data in each instance and to transmit these data to related data receiving means of an adding unit in the machine, said adding unit including a plurality of data storing registers assigned to the different orders of numerical data and each adapted to accumulate numerical data transmitted to said data receiving means, each such register being adapted to have taken therefrom a total of the amount accumulated therein and at least one of said registers being adapted to have a sub-total taken therefrom, means responsive to sensing of said register control indicia to direct transmitted numerical data to a register assigned a particular order of numerical data, printing means at a printing station operative unless suppressed to print on said sheet numerical data transmitted to said data receiving means and a sub-total or a total taken from a register, means to suppress operation of said printing means when a device of the first-named order has its numerical data transmitted to said data receiving means and to allow operation of the printing means when a device of the second-named order has its numerical data transmitted to the data receiving means, means responsive to the sensing of indicia on a device demanding a sub-total or total to take a sub-total or total of accumulated amounts from a particular register and to enable such sub-total or total to be printed by said printing means on the sheet, said sheet having assigned positions thereon for said numerical data of the order to be printed as well as the sub-total and the total amounts, and means to feed said sheet to its next assigned position after a numerical amount has been so printed.

2. In a printing and adding machine of the kind described adapted to print numerical amounts on a sheet and wherein there are adapted to be passed to a sensing station in the machine devices bearing numerical data, some of an order to be accumulated and others of an order to be accumulated and printed, said orders being identified by the presence or absence of register control indicia on the devices, and wherein certain of said devices additionally bear control indicia demanding a sub-total and a total of accumulated numerical data of a particular order, means at the sensing station adapted to establish representations of said numerical data in each instance and to transmit these data to related data receiving and representing slides of an adding unit in the machine, said adding unit including accumulator wheels in a plurality of data storing registers assigned to the different orders of numerical data each adapted to engage said slides to receive from and accumulate numerical data transmitted to said slides, each such register being adapted to have taken therefrom a total of the amount accumulated therein and at least one of said registers being adapted to have a sub-total taken therefrom by zeroizing said slides, means responsive to sensing of said register control indicia associated with a device bearing numerical data of a particular order to direct transmitted numerical data to a register assigned to that particular order of numerical data, printing means at a printing station under control of said slides and operative unless suppressed to print on said sheet numerical data transmitted to said slides and a sub-total or a total taken from a register to zeroize said slides, means to suppress operation of said printing means when a device of the first-named order has its numerical data transmitted to said slides and to allow operation of the printing means when a device of the second-named order has its numerical data transmitted to said slides, means responsive to the sensing of indicia on a device demanding a sub-total or total to take a sub-total or total of accumulated amounts from a particular register and to enable such sub-total or total to be printed on the sheet by said printing means, said sheet having assigned positions thereon for said numerical data of the

order to be printed as well as the sub-total and the total amounts, and means to feed said sheet to its next assigned position after a numerical amount has been printed thereon.

- 5 3. In a printing and adding machine of the kind described adapted to print numerical amounts on a sheet and wherein there are adapted to be passed to a sensing station in the machine devices bearing numerical data, some of an order to be accumulated and others of an order to be accumulated and printed, said orders being identified by the presence or absence of register control indicia on the devices, and wherein certain of said devices additionally bear control indicia demanding a sub-total and a total of accumulated numerical data of a particular order, settable means at the sensing station adapted when set to establish representations of said numerical data in each instance and to transmit these data to related data receiving slides of an adding unit in the machine, said adding unit including accumulator wheels in a plurality of data storing registers assigned to the different orders of numerical data each adapted when standing in an add position to accumulate numerical data transmitted to said slides and each adapted when standing in a total position to transfer to said slides a sub-total or a total of the amount accumulated therein, said registers each being adapted also to stand in neutral position wherein data can be neither transferred from nor added in its accumulator wheels, means responsive to sensing of register control indicia associated with a device bearing numerical data of a particular order to direct transmitted numerical data of that order to a register assigned that particular order of numerical data and to cause a register not to receive data of that order to stand in its neutral position, printing means at a printing station under control of said slides and operative unless suppressed to print on said sheet numerical data transmitted to said slides and a sub-total or a total when taken from a register, means to suppress operation of said printing means when a device of the first-named order has its numerical data transmitted to said slides and to allow operation of the printing means when a device of the second-named order has its numerical data transmitted to said slides, means responsive to the sensing of indicia demanding a sub-total or total from a particular register to cause that register alone to stand in a total position to zeroize said slides and to enable such sub-total or total to be printed on the sheet, said sheet having assigned positions thereon for said numerical data of the order to be printed as well as the sub-total and the total amounts, and means to feed said sheet to its next assigned position only after an amount has been printed thereon.
4. In a printing and adding machine of the kind described wherein devices bearing numerical data of respectively different orders are passed to a sensing station, and wherein such different orders of numerical data are identified by the presence or absence of register control indicia on said devices, means at the sensing station adapted to sense and establish representations of numerical data and to sense and indicate status of register control indicia, means to transmit numerical data thus represented to data receiving means at an adding unit of the machine, a plurality of registers at the adding unit each adapted to be set up for add, neutral and total operations and to accumulate numerical amounts transmitted to the data receiving means only when set up for adding, said registers being assigned to the segregation of numerical data so that numerical data of one order are accumulated in at least one register and numerical data of another order are accumulated in at least one other register, means responsive to indication of register control status as aforesaid to maintain an add setting for a register assigned to an order of numerical data when data of that order are transmitted to the

data receiving means and to maintain a neutral setting for a register not assigned such order, numerical printing means at the adding unit settable in accordance with data received by said data receiving means normally to print on a sheet numerical amounts corresponding to sensed numerical data of all orders, means to suppress the printing of such amounts corresponding to an order of numerical data that are only to be accumulated in a register, and means to render inoperative said suppressing means when numerical data of an order to be accumulated and printed are transmitted to the data receiving means.

5. In a printing and adding machine of the kind described wherein devices bearing numerical data of respectively different orders are passed to a sensing station, and wherein such different orders of numerical data are identified by the presence or absence of control indicia on said devices, means at the sensing station adapted to sense and establish representations of numerical data and to sense and indicate status of register control indicia, settable means under control of the sensing means to transmit numerical data thus represented to data receiving slides at an adding unit of the machine, accumulator wheels in a plurality of registers at the adding unit associated with said slides so as to receive data from said slides and to transfer totals to said slides, said registers each being adapted to be set up for add, neutral and total operations so as to accumulate numerical amounts transmitted to the slides only when set up for adding, to transfer totals to said slides only when set up for totalling and to do neither when set up for neutral operation, said registers being assigned to the segregation of numerical data so that numerical data of one order are accumulated in one register and numerical data of another order are accumulated in at least one other register, means responsive to indication of register control status as aforesaid to maintain an add setting for a register assigned to an order of numerical data when data of that order are transmitted to the slides and to maintain a neutral setting for a register not assigned such order, printing means at the adding unit settable by said slides in accordance with data received by said slides normally to print on a sheet numerical amounts corresponding to sensed numerical data of all orders, means to suppress the printing of such amounts corresponding to an order of numerical data so that these data are only accumulated in a register, and means to render inoperative said suppressing means when numerical data of an order to be accumulated and printed are transmitted to the slides.

6. In a printing and adding machine of the kind described wherein devices are passed to a sensing station bearing numerical data some of an order to be accumulated without printing and some of an order to be printed, and wherein such different orders of numerical data are identified by the presence or absence for control indicia of said devices, means at the sensing station adapted to sense and establish representations of numerical data and to sense and indicate status of control indicia, means to transmit numerical data thus represented to data receiving means at an adding unit of the machine, a data storing register at the adding unit adapted to be set up for adding and total operations so as to accumulate numerical amounts transmitted to the data receiving means when in add setting and to transfer a total to said data receiving means when set up for a total operation, printing means at the adding unit settable in accordance with data received by said data receiving means normally to print on a sheet numerical amounts corresponding to sensed numerical data of all orders, means to suppress the printing of such amounts in each instance where the control indicia status is that data transmitted to the data receiving means are to be accumulated only, and means to render inoperative said suppressing means in

each instance where the control indicia status is that data transmitted to the data receiving means are to be printed.

7. In a printing and adding machine of the kind described adapted to print a legend and related numerical amounts including a total and a sub-total on a sheet having assigned areas for the legend and the numerical amounts, and wherein there are adapted to be passed to a sensing station in the machine devices bearing legend imprinting means, bearing numerical data of an order to be accumulated and bearing numerical data of an order to be accumulated and printed, said orders being identified by register control indicia on the devices, and wherein certain of said devices additionally bear control indicia demanding a sub-total and a total of accumulated numerical data: a primary printing unit and an auxiliary printing unit, printing means at the primary printing unit adapted to print such sheets with legends from successive of said devices having legend imprinting means sequentially advanced to the printing means of the primary printing unit, means at the sensing station adapted to establish representations of said numerical data and to transmit these data to related data receiving means of the auxiliary printing unit of the machine, said auxiliary printing unit including an adding unit having a plurality of data storing registers assignable to the different orders of numerical data and adapted to accumulate numerical data transmitted to said data receiving means and adapted to have taken therefrom a sub-total or a total of the amounts accumulated therein, means responsive to sensing of said register control indicia to direct transmitted numerical data to a register assigned a particular order of numerical data, the printing means of the auxiliary printing unit being operative unless suppressed to print on said sheets numerical data transmitted to said data receiving means and a sub-total or a total taken from a register, means to suppress operation of said auxiliary printing means when a device of the first-named order has its numerical data transmitted to said data receiving means and to allow operation of the auxiliary printing means when a device of the second-named order has its numerical data transmitted to the data receiving means, means responsive to the sensing of indicia demanding a sub-total or total to take a sub-total or total of accumulated amounts from a register and to print such sub-total or total on such a sheet, and means to feed each such sheet to its next assigned position at the auxiliary printing unit after an amount has been printed thereon.

8. In a printing and adding machine of the kind described adapted to print a legend and related numerical amounts including a total and a sub-total on a sheet having assigned areas for the legend and the numerical amounts, and wherein there are adapted to be passed to a sensing station in the machine a deck of related devices including a device bearing legend imprinting means, at least one device bearing numerical data of a computing order to be accumulated only and a special device bearing numerical data of an order to be accumulated and printed, said orders being identified by the presence or absence of register control indicia on the devices, and wherein certain of said devices additionally bear control indicia demanding a sub-total and a total of accumulated numerical data: a primary printing unit and an auxiliary printing unit, printing means at the primary printing unit adapted to first print such sheets with legends from successive of said devices having legend imprinting means sequentially advanced to the printing means of the primary printing unit, means at the sensing station adapted to establish representations of said numerical data and to transmit these data to related data receiving means of the auxiliary printing unit of the machine, said auxiliary printing unit including an adding unit having a plurality of data storing registers assignable to the different orders of numerical data and adapted to accumulate numerical data transmitted to said data receiving means and adapted to

have taken therefrom a sub-total or a total of the amounts accumulated therein, means responsive to the sensing of register control indicia on the computing devices to direct transmitted numerical data of that order to a particular register assigned thereto and responsive to the sensing of register control indicia on the special devices to direct transmitted data of that order to a distinct other register assigned thereto, the printing means of the auxiliary printing unit being operative unless suppressed to print on each of said sheets amounts corresponding to the numerical data transmitted to said data receiving means and a sub-total or a total taken from a register, means to suppress operation of said auxiliary printing means when devices of the computing order have their numerical data transmitted to said data receiving means and to allow operation of the auxiliary printing means when devices of the special order have their numerical data transmitted to the data receiving means, means responsive to the sensing of indicia demanding a sub-total or total to take a sub-total or total of accumulated amounts from a register and to print such sub-total or total on such a sheet, and means to feed each such sheet to its next assigned position at the auxiliary printing unit after an amount has been printed thereon.

9. In a printing and adding machine of the kind described wherein there are passed to a sensing station devices bearing numerical data some of an order to be accumulated and printed and others of an order to be accumulated only, means at the sensing station to sense the numerical data, an accumulating register including accumulator wheels for accumulating the numerical data of the two different orders, means to transmit numerical data from the sensing station to means settable to positions representative of the numerical data, said settable means being operative to transfer said data to said accumulator wheels and to set up numerical type segments to print numerical data thus transmitted, type hammers associated with said type segments and operative when unsuppressed to engage the type segments when set up to cause numerical data to be printed, hammer suppressing means common to all of said type hammers to suppress operation of the type hammers unless released, a solenoid for releasing the hammer suppressing means when energized, and means to hold said solenoid deenergized when data of an order to be accumulated only are transferred to the accumulator wheels and to energize said solenoid when data of an order to be accumulated and printed are transferred to said accumulator wheels.

10. In a printing and adding machine of the kind described wherein there are passed to a sensing station devices bearing numerical data some of an order to be accumulated and printed and others of an order to be accumulated only, means at the sensing station to sense the numerical data, an accumulating register including accumulator wheels for accumulating the numerical data of the two different orders, means to transmit numerical data from the sensing station to a data set-up station, slides settable to positions representative of the numerical data, means at the data set-up station to determine the positions of said slides, said slides being operative to transfer said data to said accumulator wheels and to set up numerical type segments to print numerical data thus transmitted, type hammers associated with said type segments and operative when unsuppressed to engage the type segments when set up to cause numerical data to be printed, hammer suppressing means common to all of said type hammers to suppress operation of the type hammers unless released, a solenoid for releasing the hammer suppressing means when energized, means to hold said solenoid deenergized when data of an order to be accumulated only are transferred to the accumulator wheels and to energize said solenoid when data of an order to be accumulated and printed are transferred to said accumulator wheels, and means at the sensing

station responsive to indicia on said devices identifying said orders of data to control said solenoid.

11. In a printing and adding machine of the kind described wherein there are passed to a sensing station in the machine devices bearing numerical data of different orders that are to be segregated at least to the extent that a particular accumulating register is to be restricted to data all of one order, and wherein at least one of the orders of numerical data is identified by positive indicia on the corresponding devices, a plurality of data accumulating registers in an adding unit of the machine, means at the sensing station to sense said identifying indicia where present and the numerical data of different orders and to transmit numerical data to the adding unit for storage in selected of said registers, said registers each being adapted to assume an add, neutral and total condition, register control means responsive to identifying indicia sensing to establish an add condition for one such register and simultaneously to establish a neutral condition for another such register when data to be restricted to said one register are transmitted to the adding unit, and printing means in the adding unit to print amounts transmitted to said registers.

12. In a printing and adding machine of the kind described wherein there are passed to a sensing station in the machine devices bearing numerical data of different orders that are to be segregated at least to the extent that a particular accumulating register is to be restricted to data all of one order, and wherein at least one of the orders of numerical data is identified by positive indicia on the corresponding devices, a plurality of data accumulating registers in an adding unit of the machine, means at the sensing station to sense said identifying indicia and the numerical data of different orders and to transmit numerical data to the adding unit for entry and storage in selected of said registers, said registers each being adapted to assume an add condition when an amount is to be entered therein, a total condition when a stored amount is to be taken therefrom, or a neutral condition when an amount is to be neither entered nor taken, register control means to establish an add condition for one such register and simultaneously to establish a neutral condition for another such register when data to be restricted to said one register are transmitted to the adding unit, said register control means being responsive to identifying indicia sensing, and printing means in the adding unit to print amounts transmitted to said registers.

13. In a printing and adding machine of the kind described wherein there are passed to a sensing station in the machine devices bearing numerical data of different orders that are to be segregated at least to the extent that a particular accumulating register is to be restricted to data all of one order, and wherein at least one of the orders of numerical data is identified by positive indicia on the corresponding devices, a plurality of data accumulating registers in an adding unit of the machine, each such register including a plurality of accumulating gear wheels on a common mounting shaft, slides having gear teeth engageable with said gear wheels in an entry or add movement in one direction to transfer amounts thereto, the gear teeth on said slides also being engageable with said gear wheels in an opposed read-out or total movement to take total amounts from the registers, rockable gear segments to bring about engagement between said gear teeth and said gear wheels by moving a related shaft having accumulator gear wheels thereon toward said slides, a shiftable add rack and a total rack to time operation of said gear segments in respect of add and total movements of the slides, gear segment control arms for individually positioning the gear segments in engagement with said add rack or said total rack or in a neutral position between the racks, register control solenoids individually assigned to operation of said gear segment control arms, each such solenoid hav-

ing its own energizing circuit, and means responsive to identifying indicia sensing to determine at least which solenoid is to be energized to accordingly control entry of amounts in said registers.

14. In a printing and adding machine of the kind described wherein there are passed to a sensing station in the machine devices bearing numerical data of different orders that are to be segregated at least to the extent that a particular accumulating register is to be restricted to data all of one order, and wherein at least one of the orders of numerical data is identified by positive indicia on the corresponding devices, a plurality of data accumulating registers in an adding unit of the machine, each such register including a plurality of accumulating gear wheels on a common mounting shaft, slides having teeth engageable with said gear wheels in an add movement in one direction to transfer amounts thereto, the gear teeth on said slides also being engageable with said gear wheels in an opposed register totalling movement to take total amounts from the registers, shaft actuating means individually associated with said shafts and positionable so as to bring about engagement between said gear teeth and said gear wheels thereon by moving said shafts towards said slides at times when the slides are undergoing an add or total movement, said shaft actuating means also having a neutral position to prevent engagement between the gear wheels and slide gear teeth, and control means for positioning the shaft actuating means, said control means including register control solenoids individually assigned to control over said shaft actuating means, each such solenoid having its own energizing circuit, and means responsive to identifying indicia sensing to determine which solenoid is to be energized to accordingly control entry of amounts in said registers.

15. In a printing and adding machine of the kind described wherein there are passed to a sensing station in the machine devices bearing numerical data of different orders that are to be separately treated by the machine at least to the extent that a particular accumulating register in the machine is to be restricted to accumulating data all of one order, and wherein the respective orders of numerical data are distinguished by identifying indicia on the devices, a data accumulating register in an adding unit of the machine, means at the sensing station to sense such identifying indicia and the numerical data of different orders and to transmit numerical data to the adding unit, means in the adding unit to transfer data to said register, said register being adapted to assume an add condition when data are to be transferred thereto, a total condition when amounts are to be taken therefrom, and a neutral condition when data are to be neither transferred nor taken, register control means responsive to the sensing of said identifying indicia to establish an add condition for said register at a time when the data of said one order are transmitted to the adding unit and to establish a neutral condition at a time when data not of said one order are transmitted to the adding unit, and printing means in the adding unit to print amounts transmitted to the adding unit.

16. In a printing and adding machine of the kind described wherein there are passed to a sensing station in the machine devices bearing numerical data of different orders that are to be separately treated by the machine at least to the extent that a particular accumulating register is to be restricted to accumulating data all of one order, and wherein the respective orders of numerical data are distinguished by identifying indicia on the devices, a data accumulating register in an adding unit of the machine, means at the sensing station to sense such identifying indicia and the numerical data of different orders and to transmit numerical data to the adding unit for printing or for storage in said register, means to cause said register to assume an add condition when an amount is to be entered therein, a total condition when a stored

amount is to be taken therefrom, or a neutral condition when an amount is to be neither entered nor taken, register control means to establish an add condition for said register when data of said one order are transmitted to the adding unit and to establish a neutral condition for said register when data not of said one order are transmitted to the adding unit, said register control means being responsive to identifying indicia sensing, and printing means in the adding unit to print amounts transmitted to said registers.

17. In a printing and adding machine of the kind described adapted to print numerical amounts on a sheet and wherein there are adapted to be passed to a sensing station in the machine devices bearing numerical data, some of an order only to be successively accumulated for a total amount before being printed and others of an order to be successively accumulated and printed individually at the same time, said orders being identified by the presence or absence of register control indicia for the devices, and wherein certain of said devices additionally bear control indicia demanding such a total: means active upon sensing to establish representations of said numerical data in each instance and to transmit these data to related data receiving means of an adding unit in the machine, said adding unit including a plurality of data receiving registers assigned to the different orders of numerical data and each adapted to accumulate numerical data transmitted to said data receiving means, the one of said registers assigned to data of the first-named order being adapted to have a total taken therefrom, means responsive to sensing of said register control indicia to direct transmitted numerical data to the register assigned to the particular order of numerical data, printing means at a printing station operative unless suppressed to print on said sheet numerical data transmitted to said data receiving means and a total when taken from said one register, means to suppress operation of said printing means when a device of the first-named order has its numerical data transmitted to said data receiving means and to allow operation of the printing means when a device of the second-named order has its numerical data transmitted to the data receiving means, means responsive to the sensing of total-demanding indicia on a device to take a total of accumulated amounts from said one register and to enable such total to be printed by said printing means on the sheet, said sheet having assigned positions thereon for numerical data of the second-named order to be successively printed as well as for the total amount of data of the first-named order, and means to feed said sheet to its next assigned position after a numerical amount has been so printed.

18. In a printing and adding machine of the kind described adapted to print a legend and related numerical amounts including a total on a sheet having assigned areas for the legend and the numerical amounts, and wherein there are adapted to be passed to a sensing station in the machine devices bearing means enabling a legend to be printed, bearing numerical data of an order to be accumulated and bearing numerical data of an order to be accumulated and printed, said orders being identified by register control indicia for the devices, and wherein certain of said devices additionally bear control indicia demanding a total of accumulated numerical data: a primary printing unit and an auxiliary printing unit, printing means at the primary printing unit adapted to print such sheets with legends from successive of said devices sequentially advanced to the printing means of the primary printing unit, means active upon sensing to establish representations of said numerical data and to transmit these data to related data receiving means for the auxiliary printing unit of the machine, said auxiliary printing unit including an adding unit having a plurality of data receiving and storing registers assignable to the different orders of numerical data and adapted to accumulate numerical data transmitted to said data receiving means

and adapted to have taken therefrom a total of the amounts accumulated therein, means responsive to sensing of said register control indicia to selectively direct transmitted numerical data to the register assigned a particular order of numerical data, the printing means of the auxiliary printing unit being operative unless suppressed to print on said sheets numerical data transmitted to said data receiving means and a total taken from a register, means to suppress operation of said auxiliary printing means when a device of the first-named order has its numerical data transmitted to said data receiving means and to allow operation of the auxiliary printing means when a device of the second-named order has its numerical data transmitted to the data receiving means, means responsive to the sensing of indicia demanding a total to take a total of accumulated amounts from a register and to print such total on such a sheet, and means to feed each such sheet properly to its next assigned position at the auxiliary printing unit after an amount has been printed thereon.

19. In a printing and adding machine of the kind described wherein there are passed to a sensing station different ordered devices bearing numerical data some of an order to be accumulated and printed and others of an order to be accumulated only, said orders being distinguished by identifications on at least one of the two orders of devices, means at the sensing station to sense the numerical data as well as said identifications, an accumulating register for accumulating the numerical data of the two different orders, means to transmit numerical data from the sensing station to means settable to positions representative of the numerical data, said settable means being operative to transfer said data to said register and to set up numerical type segments at a printing station to print numerical data thus transmitted, sheet feed means to feed a sheet to be printed in a step-wise fashion through the printing station, type hammer means associated with said type segments at the printing station and operative when un suppressed to strike the type segments when the latter are set up for printing numerical data on said sheet, 40 type hammer suppressor means operative to suppress

operation of the type hammer means unless the suppressor means is released, and electrical control means in turn under control of said identification sensing means, said electrical control means including a circuit common to the sheet feed means and the suppressor means and effective to hold the suppressor means unreleased and the sheet feed means inoperative when data of an order to be accumulated only are so identified and transferred to said register and effective to release the suppressor means and render operative the sheet feed means when data of an order to be accumulated and printed are so identified and transferred to said register.

5 20. In a printing and adding machine of the kind described wherein there are passed to a sensing station different ordered devices bearing numerical data some of an order to be accumulated and printed and others of an order to be accumulated only, said orders being distinguished by identifications on at least one of the two orders of devices, means at the sensing station to sense the 15 numerical data as well as the identifications, an accumulating register for accumulating the numerical data, means to transmit numerical data from the sensing station to said register, printing means at a printing station settable in accordance with the data transmitted to said register to print numerical data thus transmitted, sheet feed means to feed a sheet to be printed in a step-wise manner through the printing station, means to suppress operation of the printing means unless released, and electrical control means in turn under control of said identification 25 sensing means to maintain the suppressor means effective and the sheet feed means inoperative in each instance where data of an order to be accumulated only are so identified, and to release the suppressor means and render the sheet feed means operative when data of an order to 30 be accumulated and printed are so identified.
